ABSTRACT OF THE DISCLOSURE

The point or points at which a word of text may properly be hyphenated are determined automatically by a process of first selecting a variety of possibilities and, second, choosing a particular weighted probability from among them. Specifically, the sequence of letters (or characters representing these letters) in the text word under consideration is analyzed in subsets to ascertain all of the possible arrangements of characters within pairs of subsets (each pair embracing a possible hyphen point) that hypothetically could produce acceptable hyphenation of the word. The particular arrangement of these subsets which most probably would produce correct hyphenation then is selected according to established statistical rules. In the disclosed embodiment, the letters of the word to be analyzed are first converted into a reduced character set, which then is broken up in various ways into all of its possible syllable combinations, and out of these possible syllabifications the most probable syllable pattern is selected.

This is a continuation of application Ser. No. 375,714, filed June 17, 1964, now abandoned.

This invention relates to a scheme for hyphenating words in textual material, and more particularly to a statistical scheme for automatically hyphenating words.

The trend toward automation has recently been extended to the newspaper and other publishing industries. This trend has manifested itself in automatic type composing machines and in numerous schemes for automatically justifying lines of type in these machines. However, one problem which has consistently plagued these efforts at automatic line justification is the inability of the machines to properly hyphenate words at the end of a line. Existing and proposed solutions to this hyphenation problem have involved: (a) the use of an enormous dictionary in which all possible words which may appear in the text being printed are stored, and (b) the performance of a table look-up type operation to find the word and its proper hyphenation pattern each time a word is to be hyphenated.

There are two serious disadvantages to the table look-up scheme for automatic hyphenation. First, with almost any sample of text, the number of words involved in much larger than it is economically feasible to store in a high-speed memory such as a magnetic core matrix array. Therefore, the table has to be stored in a low-speed memory. As a result, each table look-up is relatively time consuming, causing the overall speed of the automatic printing operation to be substantially reduced.

Another, more serious, shortcoming of table look-up automatic hyphenation schemes is that no dictionary can ever be complete. This is particularly true in newspaper work where proper names consistently appear in the text to be operated upon. This means that even with a very large dictionary, the machine will still not be able to hyphenate a substantial percentage of the words applied to it, and there will be a need to perpetually update the dictionary in order to maintain any desired degree of hyphenation capability and accuracy.

2

It is therefore the primary object of this invention to provide an improved automatic hyphenation scheme.

A more specific object of this invention is to provide an automatic hyphenation scheme which does not require the use of a large table of stored entries.

Another object of this invention is to provide a high-speed scheme for automatic word hyphenation.

A further object of this invention is to provide a scheme for automatically hyphenating words, the storage requirements of which are such that all tables may be economically stored in high-speed memory arrays.

A still further object of this invention is to provide an automatic hyphenation scheme which is capable of hyphenating proper names and other unusual words in a sample of text.

Another object of this invention is to provide an automatic hyphenation scheme which is capable of accurately hyphenating a very high percentage of the words applied to it from a given sample of text.

A feature of this invention is the conversion of the word to be hyphenated to a reduced character set and the operation on the characters of the word in the reduced character set in a statistical manner to determine the most probable hyphenation pattern for the word.

The foregoing and other objects, features and advantages of the invention will be apparent from the following more particular description of a preferred embodiment of the invention, as illustrated in the accompanying drawings.

In the drawings:

FIG. 1 is a general flow diagram of the method of this invention.

FIG. 2 is a detailed flow diagram of the test-for-two-or-more-vowels step in the flow diagram of FIG. 1.

FIG. 3 is a diagram illustrating how FIGS. 3A-3B may be combined to form a flow diagram of the form-syllable-patterns step in the flow diagram of FIG. 1.

FIGS. 3A-3B when taken together form a flow diagram of the form-syllable-patterns step in the flow diagram of FIG. 1.

FIG. 4 is a flow diagram of the select-preferred-pattern step in the flow diagram of FIG. 1.

FIG. 5 is a diagram illustrating how FIGS. 5A-5T are combined to form a detailed block diagram of a circuit which may be used to practice the automatic hyphenation scheme of this invention.

FIGS. 5A-5T when taken together form a detailed block diagram of a circuit which may be used to practice the scheme of this invention.

FIG. 6 is a table with illustrative entries used in performing the scheme of this invention.

FIG. 7 is a supplementary table with illustrative entries used in performing the scheme of this invention.

FIG. 8 is a table for converting characters to the reduced character set.

FIG. 9 is an illustrative series of entries in a word register of the embodiment shown in FIGS. 5A-5T.

In addition to the figures described above, pages A1 to A37 at the end of the specification contain an appendix showing in table form the turn-on condition for each of the single-shot multivibrators in the clock of FIG. 5T, and the functions performed during the period that each of the multivibrators is in its ON state, the functions performed when it switches to its OFF state, and the single-shot (SS) which is in its ON state during the following time period.

INTRODUCTION

This invention provides a statistical scheme for performing automatic word hyphenation. The method is based on two observed facts about word hyphenation. First, in a word, there are letter combinations between

which, as a rule, a hyphen may never occur, and there are letter combinations between which hyphens must fall. Therefore, there are only a limited number of ways in which any given word may be hyphenated. However, since there are generally several ways in which a word might possibly be hyphenated, a weight factor must be introduced in order to enable a proper choice to be automatically made between conflicting patterns. But, since the number of possible syllable types is very large, this scheme would not, at first glance, appear to give any advantage over a straight dictionary look-up scheme. However, a second observable fact is that many letters are equivalent for the purpose of syllabification. For example, in phonetic terms, one stop is the same as another stop; one vowel is the same as another vowel; and one lateral is the same as another lateral for the purpose of syllabification. With the reduced character set to be presented later, all possible hyphenation patterns may be stored in a relatively small dictionary.

The scheme for automatic hyphenation of this invention involves, as a preliminary step, the analyzing of a reasonable sample of the type of text to be automatically printed to determine the syllable patterns which appear in it and the relative frequency of their occurrence. These syllable patterns and their determined relative frequencies are then stored in a high-speed memory array.

Then, when it is determined that a word is to be hyphenated, it is stored in an input register and applied, a character at a time, to a coder which converts it to the reduced character set. The output from the coder is applied to an argument register. The information in this argument register is compared with the possible syllables stored in the high-speed memory, and, when a match is found, the syllable and its relative frequency are transferred to another memory. This practice continues until the maximum number of letters which it has been determined that a syllable can contain have been transferred into the argument register, or until the end of the word is reached. An attempt is then made to find syllables starting with subsequent letters in the word, and, when a successful match is made, the syllable and its associated frequency are also stored in the second memory array. A chain address to the possible syllable preceding that stored is also stored with this syllable. This practice is continued until all possible syllables for the word have been stored.

The relative frequencies stored with the syllables are then used to determine the most likely syllable pattern for the word being operated upon. A suitable criteria for this determination will be presented later. When the most probable hyphenation pattern is determined, the word is hyphenated in accordance with this pattern.

Since many words are not hyphenable, a considerable saving in operating time can be achieved by determining this fact before the above operations are performed on the word. It has been determined that if one of three criteria exists, the word is not hyphenable. First, if the end of line occurs on the first or second letter of the word, the word generally cannot and, as a rule, should not be hyphenated. The circuit of this invention therefore tests to determine whether the end of line occurs on either the first or second letter of a word, and, if this condition is detected, a not-hyphenable indication is given. Secondly, if a word has four or less letters, present practice is not to hyphenate it. A second test is therefore made to determine if the word has four or less letters, and, if this condition exists, the not-hyphenable indication is given. Finally, it has been determined that if the word has less than two vowel groups, it is not hyphenable. The criteria for determining vowel groups will be given later. A final test is therefore made to determine if the word has two or more vowel groups, and, if this test fails, a not-hyphenable indication is given.

While the above scheme accurately hyphenates a sufficient percentages of the words applied to it for most prac-

tical applications, it has been found that in any given text sample there is a limited number of words which are hyphenated in some odd manner and would therefore lead to consistent errors with a statistical hyphenation scheme such as that proposed above. The accuracy of the above scheme can therefore be substantially increased by providing a small dictionary of most frequent errors which is quickly checked before the statistical procedure is initiated.

10 GENERAL DESCRIPTION OF OPERATION

Assume that a determination has been made as to the desired number of index positions in a line of text to be printed and that successive characters of text are fed into and stored on the printing device until an indication is received generally in the middle of a word, that the pre-determined number of index positions has been received. An overflow signal is then generated.

Referring now to FIG. 1, it is seen that when the overflow condition occurs on line 200, the first thing which is done is to determine whether the word is hyphenable or not. This is a three-step operation which involves:

20 (1) Determining whether the overflow occurred on the first or second character, this being indicated by box 202 in the flow diagram;

(2) Determining whether the word is four or less characters long, this step being illustrated by box 204 in the flow diagram; and

25 (3) Determining if the word has two or more vowel groups, this being illustrated by box 206 in the flow diagram. If the answer in steps 1 or 2 is "yes," or if the answer in step 3 is "no," then OR box 208 gives an indication that the word in question is not hyphenable. It should be noted that, as in the above sentence, the box numbers in the flow diagrams are used throughout the discussion to designate the various steps in the operation.

30 The steps performed by boxes 202 and 204 are fairly straight-forward and do not require further explanation, except to illustrate, as will be done later, how they might be accomplished in the embodiment of the invention shown in FIGS. 5A-5T. However, further explanation is required for the vowel-group-counting operation illustrated by box 206. In this operation, it is vowel groups rather than vowels which are being counted. It is assumed that each syllable contains a vowel group and therefore that the number of syllables will be equal to the number of vowel groups. While the vagaries of English spelling prevent this assumption from being 100% accurate, it is sufficiently accurate for the purpose for which it is being employed. For the purposes of this determination, most vowels and most vowel sequences are counted as one vowel group. The exception to this general rule are as follows:

35 "i-a" is counted as two vowels; "y" is counted as a vowel only if it follows a consonant; a final "e" is not counted as a vowel unless it is preceded by a stop letter (b, d, g, j, k, p, or t) followed by an "l"; an "e" before a final "d" is counted only if the letter preceding the "e" is a "t" or a "d"; an "e" before a final "s" is counted only if the preceding letter is an "s," a "c," a "g," an "h," or an "x."

40 For example, in the word "diarchy," the first and second exceptions above are used, leading to a determination that the word has three syllables which, in fact, it does. FIG. 2 is a flow diagram graphically illustrating the above described procedure for counting vowel groups and also illustrating the clock cycles during which the various operation shown therein are performed. The significance of the various clock times appearing in the flow diagrams will be apparent later. This diagram is self-explanatory and will therefore not be described at this point; however, it will be referred to again later to assist in understanding how the circuit of FIGS. 5G-5J operates to perform these functions.

45 Referring again to FIG. 1, it is seen that once a de-

termination has been made that word is hyphenable, a check is made to determine whether the word is contained in a short list of most frequent errors. This step is indicated by box 210 in the flow diagram. The words in this list are ones which, due to the vagaries of the English spelling, are not hyphenated in accordance with the most probable hyphenation pattern which is determined in a manner to be described presently. Since this list is short, it may economically be stored in a high-speed memory array, and its inclusion does not substantially increase the time required to perform the hyphenation routine. While the step required to perform the hyphenation routine. While this step has been included in the preferred embodiment of the invention, it should be understood that it is optional, and satisfactory hyphenation can be achieved without it. However, it has been found that the inclusion of this step can lead to a 15 to 20% increase in the percentage of words which are accurately hyphenated.

As may be seen from the flow diagram of FIG. 1, if a word is found in the most-frequent-error list, the proper hyphenation pattern is read into an output-word register. If the word is not found in the most-frequent-error list, the process proceeds to box 212, which is the next step in the operation.

As shown by box 212, the next step in the operation is to form the syllable patterns. This rather involved step is illustrated in detail by the flow diagram of FIGS. 3A-3B. Referring to FIG. 3A, it is seen that the first step in the form-syllable-patterns operation is to code the first character of the word, read it into an argument register, and to associate this syllable on a table of acceptable syllable patterns. This step is represented by box 220 in the flow diagram of FIG. 3A. Included in this box and in the remaining boxes of this flow chart are the clock times, designated CL, during which these operations are performed. While these clock times have no significance for the present discussion, their significance will become apparent later.

Assume first that a match is had on the coded character or group of characters stored in the argument register and being associated on during step 220. In this event, the circuit proceeds to create a table entry as indicated by step 222. FIG. 6 shows the table entry format and a group of table entries for an illustrative word. The significance of the particular entries shown in FIG. 6 will be described later. However, at this point the format of the table will be described briefly. The table starts at a particular address position, in FIG. 6 the address 100, and succeeding entries are stored in succeeding address positions in the memory. Each entry contains a possible syllable and a figure representing the relative frequency for that possible syllable. As indicated previously, the relative frequency figure is derived by analyzing a representative sample of text of the type to be hyphenated. In addition, each table entry has four additional fields. A level termination mark is stored in the first of these fields if the syllable of that entry is the last possible syllable which starts with the letter that that syllable starts with. The second of the fields is the next-character-number field. This field contains the character number of the character following the last character in the syllable of that entry. The third additional field is a chain-address field. This field contains a zero if there is no possible syllable which starts with the letter following the last letter of the syllable of the entry; a two if the syllable of the table entry is the last syllable of the word (i.e. contains the last letter of the word); and the table address of the first table entry starting with the letter following the last letter of its own syllable if such an entry exists. The last additional field is a used-bit field. This field initially contains all zeros. The significance of a one bit in this field will be described later.

During step 222 of FIG. 3A, only the syllable and relative frequency fields of the table entry are filled. In an appropriate situation, the level-termination-mark (LTM) field of the entry may also be filled during this step.

Once a table entry has been created, one of three steps may follow. If this is the first table entry starting with a particular letter other than the first letter of the word, then a flip-flop in the circuit referred as the used flip-flop is in its ON state. The significance of this flip-flop being in its ON state is to indicate to the circuit that the address in the table at which the present entry is being stored should be read into the chain-address field of a previous entry, the syllable of which ends with the letter preceding the letter which the syllable of this entry starts with. Referring to the flow diagram of FIG. 3A, it is seen that, after a table entry has been made, if the used flip-flop is in its ON state, the process proceeds to step 224, during which the chain address is written into the proper position in the table. From step 224, the circuit proceeds to step 226, during which step an entry is made in what will be referred to as the supplementary table.

FIG. 7 shows the format for the supplementary table. The entries shown in FIG. 7 relate to the same illustrative example as that which gave rise to the entries shown in previously mentioned FIG. 6. Comparing FIGS. 6 and 7, it is seen that the next-character-number field of the supplementary table, FIG. 7, contains all character numbers which appear in the next-character-number field of the table, FIG. 6, and the chain-address field of the supplementary table contains the chain addresses from the table of FIG. 6 corresponding to the next character numbers. The purpose of the supplementary table is to avoid repeated look-ups when two different syllable strings are identical from a certain point. Before the chain address for a particular entry is determined and entered, a search is made in the supplementary table to see if a chain address for this next character number has been previously determined. If it has been previously determined, then this chain address is entered into the chain-address field of the table entry, and no further determination is required.

It is noted that in addition to a table entry being created during step 222, if a syllable containing six letters is in the argument register, a level termination mark is, as was mentioned previously, written into the level-termination-mark field of the table entry being created. The reason for this is that, for the embodiment of the invention being described, syllables over six letters long are not considered. A counter called the letter-per-word counter (abbreviated l/w) keeps track of the number of characters read into the argument register and has a count of seven in it when there are six characters in the argument register. The notation $l/w=7$ on the flow chart of FIG. 3A therefore means that a six-letter syllable is in the argument register. After the table entry, including the level termination mark, has been created in step 222, if a syllable containing six letters is in the argument register, the circuit proceeds to find the next-character number in a manner to be described later. Finally, if, after a table entry is created, it is found that the used flip-flop is in its OFF state and that a syllable containing less than six letters is in the argument register, the process returns to step 220.

Assume now that a match is not had on the character or group of characters being associated on during step 220. The next operation is then that indicated by box 228, namely a determination as to whether the argument register contains a six-letter syllable or whether the end of the word has been reached. If neither of these conditions exists, step 220 is returned to, causing an additional character to be coded and read into the argument register and a new association to be made.

As was indicated previously, it has been assumed, for purposes of the illustrative embodiment, that syllables in excess of six letters will not be encountered. Therefore, when six characters have been read into the argument register, it is assumed that all possible syllables beginning with the first letter in the argument register have been

found and the circuit is ready to seek additional syllables starting with later letters in the word. Of course, when the end of word is reached, there can be no additional syllables beginning with the first letter in the argument register, and, under this condition, the circuit is also ready to seek syllables beginning with subsequent letters in the word. Therefore, if either of the tests indicated by box 228 lead to an affirmative answer, the operation proceeds to step 230 during which a determination is made as to whether a table entry has been made for any of the letters starting with the first letter in the argument register.

Assume that the determination made in box 230 indicates that a table entry has not been made for this syllable string. This means that there are no possible table entries which can start with the first letter now in the argument register and therefore any possible syllable which ended with the letter preceding this first letter in the argument register is not a valid syllable for the word being tested. This is indicated by writing a zero into the chain-address field of this previously recorded table entry, thereby indicating that no subsequent syllable is chained to this syllable and therefore it is an invalid one. In the flow chart of FIG. 3A, this step is indicated by the box 232. If the operation of box 230 indicates a table entry has been made for the particular syllable string being investigated, the circuit proceeds to previously described step 226. The circuit also proceeds to step 226 after a chain address of zero has been entered into the proper table entry during step 232. If step 226 is arrived at from step 230, during step 226 a level termination mark is written into the LTM field of the last entry starting with the letter which is then the first letter in the argument register.

If the argument register contains a six-letter syllable or the end of the word has been reached, the process proceeds from step 224 to step 234, regardless of whether a table entry has been created or not. During step 234, the next-character-number (NCN) field of the first table entry whose NCN field has not been previously looked at is found. The process then proceeds to step 236 during which this field is looked at to determine if it is blank. If this field is blank, it means that the syllable just looked at is a possible last syllable for the word, and a two is then written into the chain address of this table entry during step 238. A determination is then made as to whether this is the last table entry. If it is not the last table entry, the circuit proceeds back to step 234 to find a new next-character number. If it is the last table entry, the circuit proceeds on to the next step in the forming of the syllable patterns, which step will be described later.

If during step 236 it is found that the next-character-number field for the entry being looked at is not blank, the process proceeds to step 240. During this step, a search is made in the supplementary table (see FIG. 7) to see if this next-character number has been previously used. If syllable strings starting with this next-character-number have not previously been formed, the circuit proceeds to step 242 during which time the circuit is set up to cause the character of the input word indicated by the next-character-number field to be selected. From step 242, the process proceeds back to step 220 to cause the previously described character to be coded and read into the first position of the argument register. The circuit then proceeds as previously indicated to find and record possible table entries starting with this letter and succeeding letters.

If during step 240 it is found that syllables starting with the character in question have already been found and entered in the table, or that there are no possible syllable patterns starting with this particular character, then there is no need to perform this search and record operation again. The process therefore proceeds to step 224 during which the chain address for this next-character-number as found in the supplementary table, is read

5 into the chain-address field of the current table entry. From step 244, the circuit proceeds back to step 234 to find a new character at which syllables may begin.

10 Referring now to FIG. 3B, it is seen that when the last table entry is found during step 238, the circuit proceeds to step 250. Up until this point, the circuit has been searching for possible syllables and storing these syllables with their relative frequency when found. The remainder of step 212 (FIG. 1) is concerned with forming these possible syllables into syllable patterns and computing various statistics for these patterns.

15 During step 250, a table entry is selected and looked at. The first time step 250 is performed, the table entry looked at is the first entry in the table shown in FIG. 6. Later, other criteria are used for selecting the particular table entry to be looked at. During step 250, the used-bit field of the selected table entry is looked at to determine if it contains a one bit. A one bit in this field means that the particular table entry in question has been previously looked at and recorded and that the required statistics relating to it have already been computed. Therefore, if the used-bit for the table entry is a one, the process proceeds to step 252 to select the succeeding table entry. From step 252, the process returns to step 250 to look at this table entry and determine whether its used-bit is a one.

20 If the used bit of the selected table entry is a zero, it means that this table entry has not yet been used and that it should be investigated further. When the used bit is a zero, the circuit therefore proceeds from step 250 to step 254. During step 254, the circuit investigates the chain-address field of the table entry to determine if it has a chain address of zero. It will be remembered that if an entry has a chain address of zero, it means that there are no acceptable syllable patterns starting with the letter following the last letter of the syllable for that entry and therefore that the syllable for that entry is not a proper one for the word being investigated. Therefore, if an entry has a chain address of zero, it need not be investigated further, and the process proceeds to step 255 to determine if the entry has a mark in its level termination field.

25 A zero bit in the LTM field (i.e., no mark) means that the succeeding entry starts with the same letter as this entry and is therefore a possible syllable for the pattern being formed. Therefore, if there is a zero in the LTM field of the entry the process proceeds to step 252 to select the next table entry. If, on the other hand, there is a mark in the LTM field of the entry (i.e. the LTM field does not contain a zero) this means that the entry is the last one beginning with the particular letter and, since it has a chain address of zero, that the syllable pattern being formed cannot be completed (i.e. that it is not a possible syllable pattern for the word in question). The process therefore proceeds directly to step 264 to determine if all possible syllable patterns have been formed. Step 264 will be discussed later.

30 If during step 254 it is found that the entry does not have a chain address of zero, then this table entry may be a proper one for the word being investigated, and the process proceeds to step 256. During this step, the syllable, its frequency, and its address are stored in various registers. From this step, the circuit proceeds to step 258. During step 258, a determination is made as to whether the chain address for the entry is equal to two. If the chain address is equal to two, then the end of the word has been found and a complete possible syllable pattern has been formed. If the chain address is not equal to two, then the circuit proceeds back to step 252. However, when step 252 is entered in this manner, it is the address indicated by the chain-address field of the previously selected entry which is now selected rather than the next address, as was previously the case.

35 It can be seen that the process described above causes all the syllables in a chain to be read, in sequence, into a storage register, which register is referred to as a word

register. The last syllable in the chain will have a chain address of two. Therefore, when the entry for the last syllable is being operated upon, the circuit proceeds from step 258 to step 260.

During step 260, various statistics for the possible syllable pattern previously determined are generated. While various statistics might be employed in determining the most probable hyphenation pattern, it has been found that the most accurate results are obtained when the statistic used is the ratio of the average frequency to the square root of the sum of the squares of the deviations of the individual syllable frequencies from the average. Therefore, during step 260, the above described ratio is computed for a selected syllable pattern. When this ratio has been computed, the process proceeds to step 262 during which the computed ratio is stored in the word register with the syllable pattern it is associated with.

The process then proceeds to beforementioned step 264 during which a determination is made as to whether all possible syllable patterns have been formed (i.e. a determination is made as to whether the ratio just computed was for the last of the possible syllable patterns). If there are still possible syllables in the table which have not been used, then the process proceeds to step 266 during which a used bit is read into the used bit field of the next-to-the-last entry looked at and a word position is selected in the word register to store a new possible syllable pattern. If the process enters step 264 from step 255, the word position selected during step 266 is the same position previously used whereas if step 264 is entered from step 262, the following word position is selected during step 266. From step 266, the process proceeds back to step 252 to select a new table entry which may be the first syllable of a new possible syllable pattern.

When, during step 264, it is determined that all possible syllable patterns have been formed, the process proceeds to step 270 (FIG. 1). Referring to FIG. 1, it is seen that during step 270 the preferred pattern is selected. FIG. 4 is a detailed flow diagram of the individual steps which are performed during the select-preferred-pattern operation 270. Referring to FIG. 4, it is seen that the first step of the select-preferred-pattern operation is to select a word from the word register. The word selected by this step (step 272) is the word in the first word position of the word register. Having decided that the most significant statistic for selecting the preferred syllable pattern is the ratio of the average frequency to the square root of the sum of the squares of the deviations of the frequencies of the individual syllables from the average frequency, the selecting of the preferred pattern becomes a relatively straight-forward matter. The particular criteria which have been found to be the most effective is that the preferred pattern be that with a ratio greater than one. Where there is more than one possible syllable pattern with a ratio greater than one, the preferred pattern is that with the fewest syllables. Where these two criteria are not sufficient to identify a preferred syllable pattern, the preferred pattern is that with the highest ratio.

FIG. 4 shows the steps which are performed to implement the above criteria. During step 274, the ratio field of the position in the word register selected during step 272 is investigated to determine if it contains a ratio greater than one, less than one, or blank. If there is a possible syllable pattern in the selected position of the word register, the ratio field will not be blank. Therefore, a blank indication means that all possible syllable patterns have been investigated and is used as an indication that step 270 of the process has been completed. If during step 274 it is found that the ratio in the ratio field is less than or equal to one but is not a blank, then, according to the criteria indicated above, the pattern yielding this ratio is not a possible syllable pattern for the word in question, and the process proceeds to step 276. During step 276, the word following the word which was just looked at is selected. From step 276, the process proceeds back to

step 274 to lock at the ratio field of the now selected word.

If, during step 274, it is found that the ratio in the ratio field of the selected word position is greater than one and this is the first word found with such a ratio, a register is set to indicate that the word register position presently being investigated contains the preferred word. This register will be referred to as the preferred-word register. The setting of the preferred-word register is effected during step 278. From step 278, the process proceeds to step 276 to cause the next position in the word register to be selected.

If during step 274, it is found that the ratio field of the selected position contains a ratio greater than one, and it is further determined that this is not the first such ratio greater than one that has been found, the process proceeds from step 274 to step 280. During step 280, a comparison is made between the number of syllables in the word presently being looked at and the number of syllables in the word contained at the memory register position indicated by the preferred-word register. If the word at the memory position indicated by the preferred-word register has the lesser number of syllables, then this is still the preferred word, and the process proceeds to step 276 to investigate the next possible syllable pattern. If the word presently being investigated has the lesser number of syllables, then this is the preferred word, and the process proceeds to step 278 to set the word register position of this word into the preferred-word register. If the word presently being investigated and the word at the address indicated in the preferred-word register both have the same number of syllables, then the process proceeds to step 282 to determine which has the highest ratio. If the word presently being investigated has the highest ratio, then the process proceeds to step 278 to set the register position of this word into the preferred-word register. If the ratio of the word in the preferred-word register is greater than or equal to that of the word presently being investigated, then this is still the preferred word, and the process proceeds to step 276 to investigate a new word pattern.

If during step 274, it is found that the ratio field contains a blank, then, as has been previously indicated, all possible syllable patterns have been investigated and, since it has been found that the above described procedure will lead to at least one syllable pattern with a ratio greater than one, that a preferred syllable pattern has been selected. The process is therefore ready to proceed to step 290 (FIG. 1) and read out this preferred pattern. Since the preferred pattern in the word register is stored in the reduced character set, it is necessary, when reading this preferred pattern into the output register, to read the letters from the input register into the output register rather than from the word register. The read-out operation 290 therefore involves the reading of characters from the input register to the output register under control of the hyphenation pattern indicated in the word register.

GENERAL CIRCUIT DESCRIPTION

Having seen from the flow diagrams of FIGS. 1-4, the process for performing automatic word hyphenation in accordance with the teachings of this invention, the circuitry for performing these functions shown in FIGS 5A-5T will now be investigated. Before describing in detail the various elements shown in this figure, the major elements of the circuit will be identified, and the inter-relation of these major elements to perform the automatic hyphenation function will be briefly described. To assist in distinguishing the major elements to be described now from the remainder of the circuit, heavier lines have been used in drawing these elements, and heavier characters have been used for the reference numerals designating these elements.

Input words are initially applied a letter at a time through lines 300 (FIG. 5A) to input-buffer register 302. If an overflow condition is not detected by overflow-

detection circuit 304 (FIG. 5C) before an end-of-word signal is applied to line 306 from the input circuit, a signal is generated on line 308 to reset input-buffer register 302. An overflow is indicated at the end of a word by a signal on line 309 from overflow-detection circuit 304. As each input character is applied to input-buffer register 302, a signal is also applied through line 310 (FIG. 5C) to increment letter-per-word (*l/w*) counter 312.

The elements described above are the basic elements in performing steps 202 and 204 of FIG. 1. If overflow-detection circuit 304 (FIG. 5C) generates a signal on line 309 indicating that an overflow has occurred and letter-per-word counter 312 indicates that there are two or less characters in input-buffer register 302, AND gate 314 generates an output signal which ultimately results in a do-not-hyphenate signal on output line 316 from OR gate 318. If *l/w* counter 312 indicates that there are four or less letters in input-buffer 302 at the same time that an end-of-word indication is received on line 306, AND gate 320 is fully conditioned to generate an output signal through OR gate 318 to do-not-hyphenate line 316.

If the overflow did not occur on the first or second character and the word is more than four characters long, AND gate 322 is fully conditioned, causing an output signal on test-for-number-of-vowels line 324.

It will be noticed that output line 324 bears the legend SS-50. Legends such as SS, XX or CL, XX appear throughout FIGS. 5A-5T. These legends refer to inputs or outputs respectively, to and from clock circuit 326 (FIG. 5T), which clock controls the sequencing and timing of the various operations performed by the circuit. The operation and function of this clock will not be considered in this section, but will be considered in detail with reference to the Appendix in the "Detailed Circuit Description" and "Detailed Operations Description" sections. For purposes of the present discussion, it will be assumed that proper timing and sequencing of operations have occurred without specific mention being made thereof.

FIGS. 5G-5J show a decoding circuit 328 for counting the number of vowel groups contained in the word stored in input-buffer register 302 according to the criteria for counting vowel groups previously stated. These criteria are schematically indicated in the flow diagram of FIG. 2. Selected letters of the input word are applied to vowel-group-counting circuit 328 from input-buffer register 302 (FIG. 5A) through OR gates 330 and lines 332. If it is found by vowel-group-counting circuit 328 that the word contained in input-buffer register 302 contains less than two vowel groups, an output signal appears on line 334 (FIG. 5J) which is applied through OR gate 318 (FIG. 5C) to do-not-hyphenate line 316. A signal on line 316 is applied to the printing device (not shown) to cause the word which it has been determined cannot be hyphenated to be omitted from the line of text when it is printed. If, on the other hand, it is found that the word in input-buffer register 302 contains two or more vowel groups, vowel-group-counting circuit 328 generates an output signal on line 336 (FIG. 5J) which causes step 210 (FIG. 1) of the automatic hyphenation process to be initiated.

Referring now to FIG. 5A, it is seen that the circuit includes an associative memory 338 and an argument register 340. Associative memory 338 has an argument portion 341 which contains a short list of words which are encountered with some degree of frequency and which would be erroneously hyphenated if hyphenated in accordance with the statistical procedure of this invention. Function portion 342 of the associative memory contains the proper hyphenation pattern for each of these words. Since the list is a short one, it may be stored in a small memory and rapidly scanned. Lines 344 connect the output from function portion 342 of associative memory 338 to an output register 346 (FIG. 5L) AND gates 350 and

354, (FIG. 5A), having output lines 348 and 352 respectively, are provided for detecting the result of the associate operation.

To perform step 210 of the process (to determine if the word in input-buffer register 302 is in the list of most frequent errors) the word in input-buffer register 302 is read into argument register 340. An association is then performed. If the association is successful, the proper hyphenation pattern is generated on lines 344 and applied to output register 346. An indication is given on line 348 from AND gate 350 that the hyphenation procedure has been completed. If, on the other hand, the word is not found in the table of associative memory 338, a signal is generated on output line 352 from AND gate 354, causing the circuit to proceed to step 212, the form-syllable-patterns step in the process.

In addition to applying the contents of input-buffer register 302 (FIG. 5A) to vowel-group-counting circuit 328, lines 332 also apply the characters of the input word, 20 a character at a time, through coder 358 (FIG. 5B) to selected positions in argument register 360. The code conversion effected by coder 358 is shown in FIG. 8. The reduced character-set characters stored in argument register 360 are compared with acceptable syllable patterns 25 in the reduced character set stored in an associative memory 362. The relative frequency of occurrence of each syllable pattern is stored in associative memory 362 with the syllable pattern.

Therefore, to perform step 220 (FIG. 3A), a selected 30 character of the input word is applied through OR gates 330, lines 332, and coder 358 to argument register 360. The syllable pattern then stored in argument register 360 is compared with acceptable-syllable pattern stored in associative memory 362.

Referring now to FIG. 5F, table entries of the type 35 shown in FIG. 6 and supplementary table entries of the type shown in FIG. 7 are stored in a high-speed magnetic-core memory 364. Inputs are applied to core storage 364 through memory-buffer register (MBR) 368. The six possible fields in the memory-buffer register are shown in FIG. 5F. These fields correspond to the six nonaddress fields in the table of FIG. 6. Line 370 from associative 40 memory 362 (FIG. 5B) applies syllable and frequency data to the appropriate fields in memory-buffer register 368. The address at which information contained in memory-buffer register 368 is to be stored in core storage 364 or from which information is to be read from core storage 364 into memory-buffer register 368 is controlled 45 by memory-address register (MAR) 372 (FIG. 5E). Other important components during this phase of the 50 operation are used-flip-flop 374 (FIG. 5B) and gating circuit 376.

If during step 220 (FIG. 3A) a matching is found, the 55 circuit is conditioned to read the matched-on-possible syllable and its associated frequency through lines 370 into memory-buffer register 368. If at the same time letter-per-word counter 312 (FIG. 5C) contains a count of seven, gate 378 (FIG. 5F) is conditioned to gate a one bit from generator 380 into the level-termination mark field of MBR 368. From MBR 368, the information is read 60 into core storage 364 at the address indicated in MAR 372. At this point, one of three things can occur, depending on the state of used-flip-flop 374 (FIG. 5B) and on the count in letter-per-word counter 312 (FIG. 5C). If used flip-flop 374 is in its OFF state and letter-per-word 65 counter 312 has a count of less than seven in it, gating circuit 376 (FIG. 5B) generates an output signal on line 382 causing the circuit to return to state 220 (FIG. 3A) to cause the next character to be read into argument register 360. If the used flip-flop is in its OFF state and the 70 count in letter-per-word counter 312 is equal to seven, then gating circuit 376 generates an output signal on line 384 which switches the circuit to state 234 (FIG. 3A). The circuitry for performing operations during this step 75 will be described later. Finally, if used flip-flop 374 is in

its ON state, gating circuit 376 generates an output signal on line 385 which switches the circuit to state 224 (FIG. 3A).

The principal elements employed during step 224 are table-address counter (TAC) 386 (FIG. 5D) and previous-address register (PAR) 390 (FIG. 5E). Anytime information is read into MAR 372, the address presently in MAR is transferred into PAR 390. TAC 386 is incremented after each table entry is made so that at any given time it contains either the address at which a table entry is being made or the address at which a table entry is about to be made.

To understand how step 224 (FIG. 3A) is performed, it should be remembered that when used-flip-flop 374 is in its ON state, it means that all possible syllable patterns starting with a particular letter have been found and that any syllable pattern now found will start with a letter following the last letter of a previously found syllable. Any syllable found at this time should therefore be chain addressed to the syllable preceding it which has a next-character number which is the same as the first letter of the syllable found. As will be seen later, under these circumstances the last access to memory 364 was to find the character at which a new search for syllables should begin. Any syllable found starting with that character should be chain addressed back to the address from which this next-character number was retrieved. Therefore, when the address in TAC 386 is transferred into MAR 372 to cause the syllable found to be properly entered during step 222 (FIG. 3A), the address at which it is desired to place the chain address is transferred into PAR 390.

Therefore, during step 224, the first operation is to transfer the address in PAR 390 into MAR 372. Circuitry is then energized to cause the address in TAC 386 to be transferred into the chain-address field of MBR 368. The desired chain address is therefore properly entered into memory 364.

From step 224, the circuit proceeds to step 226, which at this point, involves the making of a supplementary table entry. The major elements for performing this function are supplementary-address counter (SAC) 392 (FIG. 5D), next-character-number register 394 (FIG. 5F), and previously mentioned table-address counter 386 (FIG. 5D).

As a result of previous operations, at the start of step 226, register 394 contains the next-character number used in locating the syllable just entered, and TAC contains the address of this syllable. In order to make the supplementary table entry MBR 368 (FIG. 5F) is first cleared and then the contents of next-character register 394 are read into the next-character-number field of MBR and the contents of TAC 386 are read into the chain-address field of this register. Since SAC 392 contains the address at which a supplementary table entry is to be made, the address in SAC is transferred into MAR and the information in MBR 368 is then transferred into memory 364 at the address indicated by MAR. A supplementary table entry of the form shown in FIG. 7 is in this way created.

When the supplementary table entry has been made, gating circuit 396 (FIG. 5B) is used to determine whether the entry was made for a syllable which is the last syllable of a word or whether the syllable entered was a six-letter syllable. If either of these conditions exist, an output signal is derived on line 398 causing the circuit to proceed to step 234. If neither of these conditions exist, an output signal is derived on line 400, causing the circuit to return to step 220.

The function indicated in box 228 of FIG. 3A, namely the determination as to whether a six-letter syllable or the end of word has been stored in argument register 360 when a mismatch condition is detected during step 220, is performed by gating circuit 402 (FIG. 5B). If neither a six-letter syllable nor the end of word is in argument register 360, gating circuit 402 generates an

output signal on line 404 causing the circuit to return to state 220. If, however, either a six-letter syllable is in argument register 360 or the end of the word has been reached, gating circuit 402 generates an output signal on line 406 causing the circuit to proceed to step 230.

Step 230 is performed by table-entered-flip-flop 408 (FIG. 5A) and gating circuit 410. Table-entered-flip-flop 408 is switched to its ON state whenever a table entry is made. If, during step 230, this flip-flop is in its ON state, it means that a table entry has been made starting with the first letter then in argument register 360. If a table entry has been made, gating circuit 410 generates an output signal on line 412, causing the circuit to proceed to step 226 (FIG. 3A). During step 226, gate 378 (FIG. 5F) would be conditioned to write a level-termination mark into the proper field of MBR 368 in the manner previously described. Since no table entry is made during step 230 no supplementary table entry is made during step 226 when it is entered from step 230. If, during step 230, it is found that a table entry has not been made (flip-flop 408 is in its OFF state), then gating circuit 410 generates an output signal on line 414 causing the circuit to perform step 232.

Since no possible syllable pattern was found starting with the letter indicated in the next-character-number field of the table entry contained at the address indicated in MAR 372, it is now desired to write a zero into the chain-address field of this table entry. The major elements for performing this step are zero-signal-code generator 416 (FIG. 5E) and gates 418. During step 232, gates 418 are conditioned to pass the code for the zero signal into the chain-address field of MBR 368. From MBR, this zero is transferred into the chain-address field of the desired table entry. After step 232 has been performed, the circuit proceeds to write the proper chain address, in this case a zero, into an entry in the supplementary table in a manner previously described. Since no entry is made starting with the particular letter contained in the first position of argument register 360, a level-termination mark is not written during step 226 if this step follows step 232.

When, during step 226, it is found that either a six-letter syllable or the end of the word is contained in argument register 360, the circuit proceeds to step 234. The major element for performing this step is next-character-address counter 420 (FIG. 5D). This counter always contains the address in memory 364 of the table entry, the next-character-number field of which contains the character number of the next character which it will be attempted to begin syllables with. During step 234, the address in next-character-address counter 420 is transferred to MAR 372. The entry contained at this address is then transferred into MBR 368.

From step 234, the circuit proceeds to step 236. The major elements for performing this step are blank decoder 422 (FIG. 5F) which has the contents of the next-character-number field of MBR 368 applied to it through lines 424 and gating circuit 426 which samples the output from blank decoder 422. To perform step 236, the content of the next-character-number field of MBR 368 are applied through lines 424 to blank decoder 422. If the decoder indicates that the contents of this field are blank, gating circuit 426 generates an output signal on line 428 causing the circuit to proceed to step 238. If, on the other hand, blank decoder 422 indicates that the contents of this next-character-number field are not blank, gating circuit 426 generates an output signal on line 430, causing the circuit to proceed to step 240.

It will be remembered that if the next-character-number field of a table entry is blank, it means that this is a possible last syllable for the word; however, there may be other possible last syllables, and this therefore may not be the last table entry. Therefore, two things are done during step 238. First, a chain address of two is written into the current table entry; and second, an in-

vestigation is made to determine if this is the last table entry. The major elements for performing the first of these steps are coded-character "2," generator 432 (FIG. 5E) and gates 434. Compare-and-gating circuit 436 (FIG. 5D) is the major element for performing the second step.

In operation, gates 434 are conditioned to permit the coded-character "2" to be read into the chain-address field of the table entry then stored in MBR 368. This table entry is then read back into core storage 364. A comparison is then made in circuit 436 to determine if TAC 386 (FIG. 5D) and next-character-address counter 420 have the same count in them. If they do, as will be seen later, this means that the table entry looked at is the last table entry and compare-and-gating circuit 436 generates an output signal on line 438 causing the circuit to proceed to step 250. Step 250 will be described later. If, on the other hand, the last table entry has not been found, compare-and-gating circuit 436 generates an output signal on line 440, causing next-character-address counter 420 to be incremented one position. The circuit then proceeds back to step 234 to find a new next-character number.

Referring back to FIG. 3A, it is seen that if, during step 236, it is found that the next-character-number field is not blank, the circuit proceeds to step 240 to determine if a syllable string starting with the character indicated in the next-character-number field of the table entry presently in MBR 368 has previously been found. This requires that a search be made in the supplementary table (see FIG. 7). Major elements used in performing step 240 are compare-circuit 442 (FIG. 5F), gating-circuit 444, register 446 (FIG. 5D), compare-circuit 448, and gating-circuit 450. Previously mentioned supplementary-address counter 392 and next-character-number register 394 are also employed.

In operation, the first sub-step is to read the next character number being applied by MBR 368 to lines 424 into next-character-number register 394. The address of the start of the supplementary table is then applied to supplementary-address counter 392 (FIG. 5D), and from this register to MAR 372 (FIG. 5E). The next-character-number field of the supplementary table entry being investigated is then compared in compare circuit 442 (FIG. 5F) with the next-character-number register 394. If these next-character numbers are found to be equal, gating circuit 444 generates an output signal on line 452 causing the circuit to proceed to step 244 (FIG. 3A). If the two next-character-number fields are not equal, gating circuit 444 generates an output signal on line 454. A signal on line 454 does not, however, necessarily mean that the desired next-character number stored in next-character-number register 394 is not in the supplementary table. A further test must be made to determine if all entries in the supplementary table have been looked at. Therefore, the signal on line 454 causes a comparison to be made between the address in supplementary-address counter 392 (FIG. 5D) and the address of the last entry in supplementary-address counter 392 which has previously been transferred into register 446. This comparison is made in compare-circuit 448. If the entries are not equal, indicating that a search of the supplementary table has not been completed, gating circuit 450 generates an output signal on line 456 which causes the address in supplementary-address counter 392 to be incremented one position, resulting in a new supplementary-table entry being read into MBR 368. If compare-circuit 448 indicates that the entries are equal, this means that the next-character number stored in the next-character-number register 394 is not in the supplementary table, and gating circuit 450 generates an output signal on line 458 causing the circuit to proceed to step 242 (FIG. 3A).

As indicated previously, if the next-character number is in the supplementary-address table, the circuit proceeds

to step 244 (FIG. 3A) to write the chain address into the current table entry. The major elements for performing this step are chain-address register 460 (FIG. 5E) which receives an input from the chain-address field of MBR through lines 462 and previously described next-character-address counter 420 (FIG. 5D). To perform step 244, the chain-address field of the proper supplementary-table entry is read through lines 462 into chain-address register 460. The address in next-character-address counter 420 is then read into MAR 372. Finally, the chain-address in chain-address register 460 is read into the chain-address field of the table entry, the address of which has just been read into MAR. When step 244 has been completed, next-character-address counter 420 is incremented one position, and the circuit returns to step 234.

As indicated previously, if the next-character number contained in next-character-number register 394 is not in the supplementary table, gating circuit 450 (FIG. 5D) generates an output signal on line 458 causing the circuit to go to step 242 (FIG. 3A). During this step, a determination is made as to where to start looking for the next syllable string. This step is performed by the circuit of FIGS. 5A-5T in an indirect manner, which will not be described at this point. Suffice to say at this point that the effect of this step is to cause step 220 to commence with the character indicated in the next-character-number field of the entry at the address indicated in next-character-address counter 420. During this step, the next-character-address counter is also incremented by one, and many of the flip-flops and registers in the circuit are appropriately reset.

When it is determined that the last table entry has been made during step 238, the circuit is ready to form the possible syllables into syllable patterns. The circuit therefore proceeds to step 250 (FIG. 3B) to read a table entry. The first time this operation is performed, the first address at which an entry is made in the table is read into TAC 386 (FIG. 5D), and this address is transferred into MAR 372. The contents of this address are then transferred into MBR 368. The manner in which later entries are selected to be read into MBR 368 during step 250 will be described later. Having read the table entry into MBR 368, the circuit proceeds to determine whether the entry has a used bit of one. The elements for performing this function include decoder 470 (FIG. 5F) and gating-circuit 472. If the used bit is found by decoder 470 to be a zero, gating circuit 472 generates an output signal on line 474 causing the circuit to proceed to step 254 (FIG. 3B). If the used bit is found by decoder 470 to be a one, gating circuit 472 generates an output signal on line 476 causing the circuit to proceed to step 252 to select a new table entry. The reason for selecting a new table entry if the used bit in an entry is a one is that, as indicated in a previous section, the significance of a one in the used-bit field of an entry is that this has previously been used in forming syllable patterns. The function of the used bit is therefore to prevent the same operation from being repeated.

Step 252 is implemented by incrementing TAC 385 (FIG. 5D). From step 252, the circuit proceeds back to step 250 to read TAC into MAR 372.

If, during step 250, the used bit is found to be zero, this means that this table entry has not previously been used, and the circuit proceeds to step 254. The major elements employed in steps 254, 255, 256 and 258 of the operation are zero-detector 480 (FIG. 5E), two-detector 482, gating circuit 484, AND gate 485, gating circuit 486, flip-flop 487, word registers 488 (FIGS. 5R-5S), frequency register 490 (FIG. 5M) and zero-detector 512 (FIG. 5F). The input to both zero-detector 480 and two-detector 482 are lines 462 from the chain-address field of MBR 368. The input to zero-detector 512 is output line 520 from the LTM field of MBR 368. Gating circuit 484 allows address information from MAR 372 and

status and field information from the appropriate fields of MBR 368 to be passed through lines 492, 494 and 496 respectively to previously selected storage positions in word register 488 and frequency register 490. The manner in which positions are selected in word register 488 and frequency register 490 will be described later.

In operation, steps 254, 255, 256, and 258 of FIG. 3B are performed at substantially the same time. The signal applied by line 462 to zero-detector 480 causes an output which forms one input to gating circuit 486 if a zero is detected. If a zero is not detected, the output from detector 480 conditions the gates in gating circuit 484 to pass the syllable address, the syllable, and its frequency into selected positions in word registers 488 and frequency register 490. The outputs from both zero-detector 480 and two-detector 482 are applied to gating circuit 486. The output from the zero side of zero-detector 480 and the not-zero side of zero-detector 512 are connected as the inputs to AND gate 485. Output line from this AND gate is connected to switch flip-flop 487 to its ON state. This flip-flop is therefore in its ON state only when the chain-address field of the entry contain a zero and the LTM field of the entry contains a mark.

After an entry has either been made or attempted (if the output from zero-detector 480 is a zero, no entries are made) gating circuit 486 is sampled. If zero-detector 480 indicates that the chain address is a zero and flip-flop 487 is in its OFF state indicating that there is no mark in the LTM field, gating circuit 486 generates an output signal on line 499 causing the circuit to return through step 252 to step 250. TAC is incremented prior to this so that a new table entry is selected. If detectors 480 and 482 indicate that there is neither a zero nor a two in the chain-address field of the table entry, gating circuit 486 generates an output signal on line 500, which causes the address in the chain-address field to be read into MAR. Therefore, when the circuit subsequently returns to step 250, the table entry read will be that at the address indicated in the chain-address field. This is the manner in which a string of syllable patterns is formed in word register 488. If flip-flop 487 is in its ON state indicating that there is a zero in the chain-address field of the entry and a mark in the LTM field, gating circuit 482 generates an output signal on line 501 causing the circuit to proceed to step 264. Finally, if detector 482 indicates that the chain-address field contains a 2, gating circuit 486 generates an output signal on line 502 causing the circuit to proceed to step 260.

During step 260, the ratio of the average frequency for the formed syllable pattern to the square root of the sum of the squares of the deviations of the individual frequencies from the average frequency is computed. The major elements in performing this function are frequency register 490 (FIG. 5M) and calculate-circuit 504. In operation, when all of the syllables for a given syllable pattern have been found and their frequencies entered into frequency register 490, these frequencies are applied to calculate-circuit 504, which circuit computes the desired ratio and applies it to output lines 506. The ratio on lines 506 is stored in the ratio register for the particular word in word register 488 (FIG. 5S). The transferring of the ratio from compute-circuit 504 to word register 488 is accomplished during step 262 in the flow diagram of FIG. 3B.

Steps 264 and 266 of the flow diagram of FIG. 3B are performed more or less together. The major elements employed in performing these steps are column-select counter 508 (FIG. 5M), gating circuit 510, zero-detector 512, (FIG. 5F), and gating circuit 514. Column-select counter 508 indicates in which column of word register 488 a particular syllable should be placed. The number in this counter will therefore always be one more than the number of syllables in the particular syllable pattern.

Before describing how the circuit operates to perform steps 264 and 266, the theory of operation of these steps

will be explained. When an acceptable syllable pattern is found, or when it is determined that the syllable pattern being formed is not a possible syllable pattern the circuit then attempts to find alternative syllable patterns starting at any particular point in the word. The circuit therefore first attempts to see if there are alternate last syllables which may be used in conjunction with the syllable pattern formed up to that point. Failing in this, it proceeds back through the word, looking for a place at which a new possible syllable pattern may be begun. When the circuit gets back to possible first syllables and finds that there are no alternative first syllables which have not already been investigated, this phase of the operation is completed and the circuit is ready to proceed to step 272 (FIG. 4).

The above procedure is implemented in the circuit of FIGS. 5A-5T by initially decrementing column-select counter 508 to bring the column position of the last syllable entered in word register 488 into this counter. Gating circuit 510 then determines whether the count then in column-select counter 508 is zero. As will be seen later, if this count is zero, then all possible syllable patterns have been formed, and the circuit is ready to select a preferred pattern. In this situation, gating circuit 510 generates an output signal on line 516. If column-select counter 508 does not contain a count of zero, gating circuit 510 generates an output signal on line 518. A signal on line 518 causes the entry at the address indicated for the syllable indicated by column-select counter 508 to be read from memory 364 (FIG. 5F) into memory-buffer register (MBR) 368. A used bit is placed in the used-bit field of this entry at this time in a manner to be described later. The level-termination-mark field of this entry is then applied through line 520 to zero-detector 512. If there is a level-termination mark in this field, it means that this is the last syllable starting with the first letter of this syllable and that to find a new starting point for additional syllable patterns, the preceding syllable must be looked at. An output signal on line 522 from gating circuit 514 implements the above operation by causing column-select counter 508 to be decremented one position and the previously described sequence of operations to be repeated. It can be seen that if it were the level-termination field of a possible first syllable which was being looked at at this time, the last step described would cause the column-select counter to be decremented to zero, indicating that all possible syllable patterns have been formed as would in fact be the case. If the level-termination-mark field of the entry looked at does not contain a mark, gating circuit 514 generates an output signal on line 524, causing the proper word position in word register 588 to be selected and causing a new word pattern to be formed (i.e. causing the circuit to return to step 250) starting with the syllable presently being looked at.

As indicated previously, if all possible syllable patterns have been formed, the circuit generates an output signal on line 516 from gating circuit 510, causing the circuit to go to step 270 (FIG. 1) to select the preferred pattern. Referring to FIG. 4, it is seen that the first operation in selecting the preferred pattern is to select the first word from word register 488. The particular word being selected in word register 488 is determined by word-select counter 528 (FIG. 5P). Therefore, step 272 is easily effected by merely resetting word-select counter 528 to a count of one.

The next step, step 274 (FIG. 4), is to look at the ratio field in the selected word of word register 488. The major elements in performing this function are blank-detector 530 (FIG. 5P), compare-to-one circuit 532, first-time-through flip-flop 535, and gating circuit 534. Flip-flop 535 is set to its ON state during step 272 and is reset when the first ratio greater than one is detected. Information is applied to blank-detector 530 and comparison-circuit 532 from the selected one of the ratio fields through OR gate 536.

In operation, it will be remembered that a blank in the ratio field of the selected word means that all possible words have been investigated and that the circuit is ready to read out the preferred pattern (step 290, FIG. 1). When this situation occurs, gating circuit 534 generates an output signal on line 538. If during step 274 it is found that the ratio field is less than one but is not blank, gating circuit 534 generates an output signal on line 540 causing the circuit to advance to step 276. During step 276, word-select counter 528 is incremented by one. Therefore, when the circuit then returns to step 274, the ratio field of the word following that which was previously looked at is investigated.

If it is found that the ratio field contains a ratio greater than one and first-time-through flip-flop 535 indicates that this is the first time such a ratio has been located, gating circuit 534 generates an output signal on line 542. This signal is effective to reset first-time-through flip-flop 535 and to cause the circuit to proceed to step 278.

The major element in performing step 278 is preferred-word-register 544 (FIG. 5P). During step 278, the word in word-select counter 528 is transferred into preferred-word register 544. The significance of this transfer will be apparent later. From step 278, the circuit proceeds to step 276, advancing word-select counter 528 in the process and returns to step 274.

If compare-to-one detector 532 detects that the ratio in the ratio field is greater than one and first-time-through flip-flop 535 has been reset, then gating circuit 534 generates an output signal on line 546 causing the circuit to proceed to step 280 (FIG. 4). Comparison-and-gating circuit 548 (FIG. 5P) is the element employed in performing step 280. The number-of-syllable fields from the word indicated by word-select counter 528 and the number of syllables from the word indicated by preferred-word register 544 are applied to circuit 548 and an output is derived on line 550 if it is found that the syllable pattern of the word indicated by word-select counter 528 has less syllables than that indicated by the preferred-word register. Since this is now the preferred word, a signal on line 550 causes the address in word-select counter 528 to be transferred to preferred-word register 544 (i.e. causes step 278 to be performed). If the syllable pattern at the address indicated in the preferred-word register has fewer syllables, this is still the preferred pattern, and an output signal is generated on line 552, causing the word-select counter 528 to be incremented one position to allow the ratio field of the following word to be investigated. Finally, if the two words looked at have the same number of syllables, an output signal is derived on line 554 from circuit 548, causing the circuit to proceed to step 282.

Compare-and-gating circuit 556 (FIG. 5Q) is the element employed in performing step 282 (FIG. 4). The ratios contained in the ratio field of the words indicated by the word-select counter and a preferred-word register are applied to circuit 556, and an output signal is derived on line 558 from this circuit if the higher ratio appears in the word indicated by the word-select counter. This causes the word address in word-select counter 528 to be transferred into preferred-word register 544. If the ratio for the word indicated by the preferred word register is equal to or greater than the word indicated by the word-select counter, an output signal is derived on line 560 causing word-select counter 528 to be incremented by one, and the circuit to return to step 274.

When, during step 274 (FIG. 4) gating circuit 534 (FIG. 5P) generates an output signal on line 538 indicating that a blank has been detected in the ratio field of the word in the word register then being looked at, the address in the word register of the most probable syllable pattern is contained in preferred-word register 544. The circuit is therefore ready to proceed to step 290 (FIG. 1) to read out the preferred pattern.

The principal elements employed in performing step 290 if the operation are coded-word-hyphenation registers 564 (FIG. 5K), scan-control circuit 566, interpret-and-control circuits 568 (FIG. 5L), gating circuit 570, and hyphen generator 572. Output register 346 is also employed during this phase of the operation. There is an individual coded-word-hyphenation register for each possible syllable of a word, and it is assumed that there are enough of these registers to take care of the longest word which may be encountered. Since it has been assumed that syllables more than six characters long will not be encountered, each of the coded-word-hyphenation registers contains only six character positions.

In operation, just before step 290 is begun, the syllable pattern in the word indicated by preferred-word register 544 is transferred into coded-word-hyphenation registers 564. The syllables transferred into coded-word hyphenation registers 564 are in the reduced character set. Scan-control circuit 566 causes these characters to be applied in succession to interpret-and-control circuit 568. When a character is detected in a particular position in a coded-word-hyphenation register, a signal is applied through line 574 to gating circuit 570. The signal on line 574 causes gating circuit 570 to gate the corresponding character in input-buffer register 302 (FIG. 5A) through lines 576 (FIG. 5L) to output register 346. Successive characters of a syllable are in this manner read into output register 346. When the scan encounters a blank position in a particular one of the coded-word-hyphenation registers, this means that the end of a syllable has been reached. When this occurs, interpret-and-control circuit 568 generates an output signal on line 578, permitting a hyphen from hyphen generator 572 to be gated through lines 576 into the appropriate position in output register 346. Hyphens are in this manner applied to the proper positions in the output register. If instead of reaching a blank in a hyphenation register, the circuit instead reads out six characters from this register, the scan-control circuit gives an overflow indication to interpret-and-control circuit 568, resulting in a signal being applied to gating circuit 570 over line 580 to gate a hyphen into the proper position in output register 346. The word with its preferred hyphenation pattern is in this way read into output register 346. When interpret-and-control circuit 568 detects a blank in the scanned register position and scan-control circuit 566 gives an indication that this is the first character of a syllable, circuit 568 generates an end-of-operation signal.

DETAILED CIRCUIT DESCRIPTION

As indicated previously, the key element in controlling the operation of the circuit shown in FIGS. 5A-5T is clock 326 (FIG. 5T). This circuit consists of 128 single-shot multivibrators, each of which generates an output signal on a line 600 when it is in its ON state (note that four of these signals are not used), and an output signal on a line 602 when it times out (i.e. returns from its ON to its OFF state). Each of the single-shot multivibrators is switched from its OFF to its ON state by a signal applied to it over a line 604. In most cases, the turning off of one single-shot multivibrator causes the turning on of another single-shot multivibrator. Therefore, 95 lines of the 602 are shown as being fed back to become lines 604. Due to the large number of inputs to and outputs from clock circuit 326 and to the fact that these inputs and outputs come from and go to all portions of the circuit shown in FIGS. 5A-5T, no attempt has been made to show the actual connections between the clock circuit and the other elements of the circuit. Instead, the inputs to the clock circuit have been broken off at the particular elements generating them, and the outputs from the clock circuit have been broken off at the particular elements which these outputs are applied to. An appendix starting on page A1 of the specification shows in chart form the turn-on condition for

each of the single shots, the functions which are performed while the single shot is in its ON state, the functions which are performed when this single shot times out, and the next step which the clock circuit proceeds to. The sequence of operations in the circuit may be easily followed by use of the chart in the appendix.

Referring now to FIG. 5A, it is seen that in addition to data-input line 300 and reset line 605, input-buffer register 302 has two inputs which have not previously been mentioned. These are control lines 606 from input-control ring 608 and control lines 610 from output-control ring 612. The input and the output-control rings are registers having a number of positions equal to the number of character positions in input-buffer register 302. Output-control ring 612 also has an overflow position at its lower end. Each of these registers generates an output on only one of its output lines at any given time. Line 308 from overflow detection circuit 304 (FIG. 5C) is connected as one input to OR gate 611 (FIG. 5A). The other input to this OR gate is line 613. A signal is applied to line 613 when power is applied to the circuit and at the end of each cycle of operation. Output line 605 from OR gate 611 is connected to reset input-buffer register 302, and to reset input-control ring 608. Input-control ring 608 is decremented by a signal applied to line 614. The control signals applied to line 614 are from the external circuitry.

Output-control ring 612 is reset by a signal applied to line 616. A signal is applied to reset line 616 when power is applied to the circuit and at the end of each cycle of operation. A signal is also applied to line 616 when either single-shot 0, 33w, 50 or 120 of clock circuit 326 is in its ON state. Output-control ring 612 is decremented by a signal applied to line 618. A signal is applied to line 618 when either single-shot 1b, 57, 58, 59, 65, 66, 67, 71, 72, 73, or 78 is in its ON state. Output-control ring 612 is incremented by a signal applied to line 620. A signal is applied to line 620 when either single-shot 1a, 33x, 51, 51a, 53, 55, 63, 76, 122, or 126 is in its ON state.

The signal on a line 606 from input-control ring 608 determines where data applied to input lines 300 will be stored in input-buffer register 302. Similarly, a signal on an output line 610 from output-control ring 612 determines where in input-buffer register 302 data will be derived to be applied to output lines 622. Lines 622 are connected as the inputs to OR gates 330. One additional input to OR gates 330 is derived from gates 624, the conditioning input to which is derived from the overflow position of output-control ring 612 and the information input to which is blank-code generator 626. Blank generator 626 therefore applies a blank code to OR gate 330 when output-control ring 612 has been decremented beyond the first letter in input-buffer register 302.

Output line 322 from OR gate 330 is connected as the input to blank decoder 628 (FIG. 5B), as the information input to gates 630, as information input to decoder 632 (FIG. 5G) in vowel-count circuit 328, and as the information input to gates 634 (FIG. 5L) in gating circuit 570. Output line 636 from blank decoder 628 is connected through capacitor 638 to the ON-side input of end-of-word flip-flop 640. Capacitor 638 converts the level output from blank decoder 628 into a pulse level suitable for switching flip-flop 640. The reset input to end-of-word flip-flop 640 is line 642. A signal is applied to line 642 when power is applied to the circuit, at the end of each cycle of operation, and when SS-33t of clock 326 is in its ON state. Output line 644 from the ON side of end-of-word flip-flop 640 is connected as one input to AND gate 646 in gating circuit 396, as one input to AND gate 648, as one input to AND gate 650 in gating circuit 402, as one input to AND gate 651 (FIG. 5E), and as a control input to coder 358 (FIG. 5B). Output line 652 from the OFF side of end-of-word flip-

flop 640 is connected as one input to AND gate 654 in gating circuit 396, as one input to AND gate 656, and as one input to AND gate 657 (FIG. 5C). The other input to AND gates 648 and 656 is line 658. A pulse appears on line 658 when SS-1a transfers from its ON to its OFF state. As indicated previously, such a pulse is designated by the single-shot number followed by the Greek letter tau (τ). Output line 659 from AND gate 648 is connected to switch SS-1b to its ON state and output line 661 from AND gate 656 is connected to switch SS-2 to its ON state.

Output lines 622 (FIG. 5A) from input-buffer register 302 are also connected as the information inputs to gates 660. A conditioning input is applied to these gates by line 668. A signal appears on line 668 when single-shot 115 is in its ON state. Output lines 664 from gates 660 are connected as the information inputs to argument register 340. An associate signal applied to line 666 causes the contents of argument register 340 to be compared against the argument portion 341 of associative memory 338. A signal is applied to line 666 when SS-116 is in its ON state. The signal applied to line 668 when SS-115 is in its ON state also applied to associative memory 338 to switch all the control circuits therein to their match state and to the ON-side input of match flip-flop 670. After an association has been made in associative memory 338, a test signal is applied to line 672. If there has been no match during the associate operation, this signal passes through associative memory 638, causing an output signal on line 674, which signal switches flip-flop 670 to its OFF state. A test signal is applied to line 672 when SS-117 is in its ON state. ON-side output line 676 from flip-flop 670 is connected as one input to AND gate 350. OFF-side output line 678 from flip-flop 670 is connected as one input to AND gate 354. The other input to AND gates 350 and 354 is line 680. A signal appears on line 680 when SS-117 switches from its ON to its OFF state. An output from AND gate 350 on line 348 indicates that the circuit has found the desired syllable pattern and that the end of the operating cycle has been reached. An output from AND gate 354 on line 352 causes SS-0 to be switched to its ON state. As indicated previously, lines 344 connect the function portion 342 of associative memory 338 to output register 346 (FIG. 5L).

As was indicated previously, the information input to gates 630 (FIG. 5B) is lines 332. The conditioning input to these gates is line 682. A signal appears on line 682 when either SS-1 or SS-1c is in its ON state. Output lines 684 from gates 630 are connected as one input to OR gates 686. The other inputs to OR gates 686 are output lines 638 from gates 690. The information input to gates 690 are the output lines 692 from asterisk-code generator 694. The conditioning input to gates 690 is line 696. A signal appears on line 696 when either SS-0a or 1e is in its ON state. Output lines 698 from OR gates 686 are applied as the principal input to coder 358. The code conversion which is effected in coder 358 is shown in FIG. 8. It is noted in this figure that a different code is used for a final "e" and a final "g" than is used for these letters when they are not the final letter of a word. Line 644 from end-of-word flip-flop 640 supplies the additional input to coder 358 to enable it to perform the code conversion properly when one of these two characters is involved.

Out lines 700 from coder 358 are connected as the information inputs to argument register 360. Since the longest syllable to be matched on by the circuit contains six characters, argument register 360 need have a capacity of only seven characters. The reason for the seventh character is that there are some syllables which may appear only at the beginning or only at the end of a word. Therefore, an asterisk is inserted in argument register 360 before the first syllable is applied to the register and is

put into argument register 360 at the end of the word. If a possible first or last syllable of a word were to be six characters long, a seventh position would be needed for the asterisk. The position in argument register 360 at which an output from coder 358 is stored is determined by a signal on an output line 702 from input-control ring 704. As with the previously described control rings, control ring 704 generates an output on only one of its output lines 702 at any given time. Control ring 704 is reset to its first position by a signal applied to line 706. A signal is applied to reset-line 706 when SS-0 or SS-33z is in its ON state. Control ring 704 is incremented by a signal applied to line 708. A signal is applied to line 708 when either SS-0b or SS-1d is in its ON state.

Argument register 360 is reset by a signal applied to line 710. A signal is applied to line 710 when power is applied to the circuit, at the end of each cycle of operation, and when SS-33z is in its ON state. A comparison is made between the contents of argument register 360 and the contents of associative memory 362 (it being remembered that acceptable syllable patterns and their relative frequency are stored in memory 362), when a signal is applied to associate line 712. A signal is applied to associate line 712 when SS-2 is in its ON state.

A signal applied to line 714 causes all of the control circuits in associative memory 362 to be set to their match condition. The signal on line 714 is also applied to reset match flip-flop 716 to its OFF state. A signal is applied to line 714 when SS-1 is in its ON state. The condition of the control circuits in associative memory 362 is tested by a signal applied to line 718. If all of the control circuits in associative memory 362 are in their no-match state when a signal is applied to line 718, a signal appears on line 720, causing match flip-flop 716 to be switched to its ON state. A signal is applied to line 718 when SS-3 is in its ON state.

Output line 722 from the OFF side of match flip-flop 716 is connected as one input to AND gate 724. Output line 726 from the ON side of match flip-flop 716 is connected to one input of AND gates 650, 728, and 730 of gating circuit 402. The final input to AND gates 650 and 724 and the second input to AND gates 728 and 730 is line 732. A signal appears on line 732 when SS-3 switches from its ON to its OFF state. The final input to AND gates 728 and 730 will be described later. Output line 734 from AND gate 724 is connected to switch SS-20 to its ON state. Output lines 736 and 738 from AND gates 650 and 728 respectively are connected as the two inputs to OR gates 740. Output line 406 from OR gate 740 is connected to switch SS-4 to its ON state. Output line 404 from AND gate 730 is connected to switch SS-0b to its ON state.

If the signal applied to test line 718 should find one of the match indicators in associative memory 362 switched to its match state, the associated syllable and frequency are read out through lines 370 to the syllable and frequency fields of memory-buffer register (MBR) 368 (FIG. 5F). In addition, a signal is also applied to line 742 to fully condition AND gate 657. Output line 743 from AND gate 657 is connected as the conditioning input to gates 744 (FIG. 5D). The information input to gates 744 is derived through lines 746 from next-character-number counter 748. During the reading of characters into argument register 360 (FIG. 5B), next-character-number counter 748 always contains the number of the character following the character which was just read into the argument register. Counter 748 is reset to a count of one by a signal applied to line 750. A signal is applied to line 750 when either SS-0 or SS-33z is in its ON state. Counter 748 is incremented by a signal applied to line 752. A signal is applied to line 752 when either SS-1 or SS-33x is in its ON state. Output lines 754 from gates 744 are connected as one input to OR gates 756 (FIG. 5F). The other input to these OR gates will be described later. Out-

put lines 758 from OR gates 756 are connected as the input to the next-character-number field of MBR 368.

Looking now at FIG. 5C, it is seen that the end-of-word (i.e. space) signal on line 306 from the external circuit is applied through delay 760 and line 762 to the reset-to-zero input of letter-per-word counter 312. The signal on line 306 is also applied to one input of AND gates 764 and 766 of overflow-detection circuit 304. A signal on line 768 causes l/w counter 312 to be set to a count of one. A signal is applied to line 768 when SS-0 is in its ON state. Signals on lines 770 from gates 772 (FIG. 5F) cause the contents of the next-character-number field in MBR 368 to be stored in l/w counter 312 when a conditioning signal is applied to gates 772 through line 774. A signal is applied to line 774 when SS-33z is in its ON state. Letter-per-word counter 312 is decremented by a signal applied to line 776. A signal is applied to line 776 when SS-33y is in its ON state.

Output lines 778 from l/w counter 312 are connected as the input to decoder 780. When the contents of l/w counter 312 are equal to seven, decoder 780 generates an output signal on line 782 which is applied as the final input to AND gate 728 (FIG. 5B), as one input to AND gate 784 (FIG. 5B) in gating circuit 376, as one input to AND gate 786 (FIG. 5E), and as one input to AND gate 788 (FIG. 5B) in gating circuit 396. When l/w counter 312 contains a count other than seven, decoder 780 generates an output signal on line 790, which is connected as the final input to AND gate 730 (FIG. 5B), as one input to AND gate 792 in gating circuit 376, and as the second input to AND gate 654 in gating circuit 306. The final input to AND gates 646, 654, and 788 in gating circuit 396 is line 794. A pulse appears on line 794 when SS-31 switches from its ON to its OFF state. Output lines 796 and 798 from AND gates 646 and 788 respectively are connected as the inputs to OR gates 800. Output line 398 from OR gate 800 is connected to switch SS-32 to its ON state. Output line 400 from AND gate 654 is connected to switch SS-0b to its ON state.

Output line 802 from the OFF side of used flip-flop 374 (FIG. 5B) is connected as a second input to AND gates 784 and 792 of gating circuit 376. Used flip-flop 374 is switched to its OFF state by a signal applied to line 804. A signal is applied to line 804 when power is turned on to the circuit, at the end of each cycle of operation, and when SS-23 is in its ON state. Used flip-flop 374 is switched to its ON state by a signal applied to line 806. A signal is applied to line 806 when SS-33z is in its ON state. Output line 808 from the ON side of used flip-flop 374 is connected as one input to AND gate 810 in gating circuit 376 and as one input to AND gate 812 in gating circuit 410. The final input to AND gates 784, 792, and 810 is line 814. A pulse appears on line 814 when SS-22 switches from its ON to its OFF state. Output line 384 from AND gate 784 is connected to switch SS-32 to its ON state. Output line 382 from AND gate 792 is connected to switch SS-0b to its ON state. Output line 385 from AND gate 810 is connected to switch SS-23 to its ON state.

A second input to AND gate 812 (FIG. 5A) of gating circuit 410 is derived from OFF-side output line 816 of table-entered flip-flop 408. Output line 818 from the ON side of this flip-flop is connected as one input to AND gate 820 of gating circuit 410. Line 818 is also connected as one input to AND gate 822 (FIG. 5E). Table-entered flip-flop 408 is reset to its OFF state by a signal applied to line 824. A signal is applied to line 824 when power is turned on to the circuit, at the end of each cycle of operation, and when SS-33z is in its ON state. Flip-flop 408 is switched to its ON state by a signal applied to line 826. A signal appears on line 826 when SS-22 is in its ON state. The final input to AND gates 812 and 820 of gating circuit 410 is derived from line 828. A pulse appears on line 828 when SS-4 switches from its ON to its OFF state. Output line 412 from AND gate 820 is applied to switch

SS-31 to its ON state. Output line 414 from AND gate 812 is connected to switch SS-5 to its ON state.

In addition to output lines 782 and 790, decoder 780 (FIG. 5C) has output lines 830, 832, and 833. Output line 830 is connected as one input to AND gate 320 and through inverter 834 as one input to AND gate 322. A signal appears on line 830 when a count of one, two, three or four appears in *l/w* counter 312. Output line 832 is connected as one input to AND gate 314. Output line 832 has a signal applied to it when a count of one or two is in *l/w* counter 312. Output line 833 is connected as one input to AND gate 836 and through inverter 838 to one input of AND gate 840. Line 833 has a signal on it when *l/w* counter 312 has a count of one in it. The other input to AND gates 836 and 840 is line 842. Line 842 has a pulse applied to it when SS-33y is switched from its ON to its OFF state. Output line 844 from AND gate 836 is connected to switch SS-33z to its ON state. Output line 846 from AND gate 840 is connected to switch SS-33x to its ON state.

Overflow-detection circuit 304 (FIG. 5C) has three inputs. The first of these inputs is the previously described end-of-word line 306. The second input to overflow-detection circuit 304 is bit line 310, which, it will be remembered, has a signal applied to it each time a character is applied to input-buffer register 302 (FIG. 5A). A signal on line 310 is applied to increment character counter 848. A signal on line 310 is also applied through delay 850 and line 852 to one input of AND gate 854, and through OR gate 856 and line 858 to the increment input of *l/w* counter 312. The other input to OR gate 856 is line 860. A signal is applied to line 860 when SS-1 is in its ON state. The final input to overflow-detection circuit 304 is "spaces/line" lines 862. Lines 862 are connected as the input to line-size register 864. Before the start of the print operation, signals are applied to lines 862 indicating the number of spaces which are to be permitted in a line of text, and this information is stored in line-size register 864.

Output lines 866 and 868 from character counter 848 and line-size register 864, respectively, are connected to the two inputs of compare circuit 870. Compare circuit 870 generates an output signal on line 872 when the two inputs to it are equal. Line 872 is connected as the other input to AND gate 854. Output line 874 from AND gate 854 is connected to the ON-side input of an overflow flip-flop 876. Overflow flip-flop 876 is reset to its OFF state by a signal applied to line 878. A signal is applied to line 878 when power is turned on and at the end of each operating cycle. Output line 880 from the OFF side of overflow flip-flop 876 is connected as the second input to AND gate 766. Output line 308 from AND gate 766 is connected to reset input-buffer register 302 (FIG. 5A) and input-control ring 608. Output line 882 from the ON side of flip-flop 876 is connected as the second input to AND gates 314 and 764. Output line 309 from AND gate 764 is connected to stop the flow of input data to input-buffer register 302 and is also connected as an input to AND gates 320, 322, and 886. Output line 888 from AND gate 314 is connected to the ON-side input of flip-flop 890. Line 892 is connected to the OFF-side input of this flip-flop. A signal appears on line 892 when power is applied to the circuit and at the end of each cycle of operation. Output line 894 from the OFF-side of flip-flop 890 is connected as the final input to AND gate 322 and output line 896 from the ON side of flip-flop 890 is connected as the final input to AND gate 886. Output line 324 from AND gate 322 is connected to switches SS-50 to its ON state. Output lines 898 and 900 from AND gates 320 and 886 respectively are connected as two inputs to OR gate 318. As indicated previously, output line 316 from OR gate 318 is connected to external circuitry to indicate that the word in input-buffer register 302 should not be hyphenated.

Referring now to FIG. 5G, it is seen that, as previously

indicated, a character from input-buffer register 302 is applied through lines 332 to decoder 632 in vowel-count circuit 328. Decoder 632 generates an output signal on line 902 if the character applied to it is an "a," on output line 903 if the character applied to it is a "b," on output line 904 if the character applied to it is a "c," on output line 905 if the character is a "d," on output line 906 if the character is an "e," on output line 907 if the character is a "g," on output line 908 if the character is an "h," on output line 909 if the character is an "i," on output line 910 if the character is a "j," on output line 912 if the character is a "k," on output line 913 if the character is an "l," on output line 914 if the character is an "o," on output line 915 if the character is a "p," on output line 916 if the character is an "s," on output line 917 if the character is a "t," on output line 918 if the character is a "u," on output line 919 if the character is an "x," on output line 920 if the character is a "y," and on output line 921 if the character is a blank.

Output line 902 for the letter "a" is connected as one input to vowel-detector OR gate 924, as one input to OR gate 926, through inverter 928 and line 930, as one input to AND gate 932, and as one input to AND gate 934. Output line 903 for the letter "b" is connected as one input to OR gate 936. Line 904 for the letter "c" is connected as one input to OR gate 938. Line 905 for the letter "d" is connected as one input to OR gate 940, as one input to AND gate 942, as one input to OR gate 944, and as a second input to OR gate 936. Line 906 for the letter "e" is connected as a second input to OR gate 924, and as one input to AND gate 946. Line 907 for the letter "g" is connected as a second input to OR gate 938 and as a third input to OR gate 936. Line 908 for the letter "h" is connected as a third input to OR gate 938. Line 909 for the letter "i" is connected as a third input to OR gate 924 and as one input to AND gate 948. Line 910 for the letter "j" is connected as a fourth input to OR gate 936. Line 912 for the letter "k" is connected as a fifth input to OR gate 936. Line 913 for the letter "l" is connected as one input to AND gate 950 and through inverter 952 and line 954 as one input to AND gate 956. Line 914 for the letter "o" is connected as a fourth input to OR gate 924 and as a second input to OR gate 926. Line 915 for the letter "p" is connected as a sixth input to OR gate 936. Line 916 for the letter "s" is connected as a second input to OR gate 940, as one input to AND gate 958 and as a fourth input to OR gate 938. Line 917 for the letter "t" is connected as the second input to OR gate 944 and as the seventh and final input to OR gate 936. Line 918 for the letter "u" is connected as a fifth input to OR gate 924 and as the third input to OR gate 926. Line 919 for the letter "x" is connected as the fifth and final input to OR gate 938. Line 920 for the letter "y" is connected as a sixth input to OR gate 924, and as an input to AND gate 960. Blank line 921 is connected as the seventh and final input to OR gate 924, as a third and final input to AND gate 940, as an input to AND gates 962, 964, 965, and 966, and through inverter 968 and line 970, as an input to AND gates 972, 974, 976, and 978.

Output line 980 from OR gate 924 is connected through inverter 982 and line 984 to one input of AND gates 986 and 988 (FIG. 5H). Output line 990 from OR gate 940 (FIG. 5G) is connected through inverter 992 and line 994 to one input of AND gates 996 and 998. Output line 1000 from OR gate 938 is connected as one input to AND gate 1002. Output line 1004 from OR gate 944 is connected as one input to AND gate 1006. Output line 1008 from OR gate 936 is connected as one input to AND gate 1010. Output line 1012 from OR gate 926 is connected as one input to AND gates 1014 and 1016.

Referring to FIG. 5H, it is seen that the number of vowels in the word is counted by number-of-vowels counter 1018. This counter is reset to a count of zero by a signal applied to line 1020. A signal is applied to line

1020 when power is applied to the circuit and at the end of each operating cycle. Counter 1018 is incremented by a signal applied to output line 1022 from OR gate 1024. The inputs to OR gate 1024 will be described later. Counter 1018 generates an input signal on line 1026 when it contains a count of less than two, and an output signal on line 1028 when it contains a count of two. Line 1026 is connected as one input to AND gates 1030, 1032, 1034, 1036, and 1038, and as a second input to AND gates 1016, 965, 974, 966, 978, 942, 958, 964, 962, and 996. Equal-to-two line 1028 is connected as one input to AND gates 1040, 1042, 1044, 1046, 1048, 1050, 1052, 1054, and 1056.

The other input to AND gate 1014 (FIG. 5I) is line 1058. A signal appears on line 1058 when SS-52 is in its ON state. The other input to AND gates 946, 948, 960, 1016, 1056, 962, and 986 is line 1060. A pulse appears on line 1060 when SS-52 is switched from its ON to its OFF state. Output line 1062 from AND gate 986 (FIG. 5G) is connected to switch SS-51a to its ON state. Output line 1064 from AND gate 962 is connected as one input to not-hyphenable OR gate 1066. Output line 1068 from AND gate 1014 (FIG. 5I) is connected as an input to OR gate 1024. Output line 1070 from AND gate 1056 is connected as an input to OR gate 1072. Output line 1074 from AND gate 1054 is connected as the second input to OR gate 1072. Output lines 1076, 1078, and 1080 from AND gates 1052, 1050, and 1048 respectively are also connected as inputs to OR gate 1072. Output line 1082 from AND gate 1016 (FIG. 5I) is connected to switch SS-51 to its ON state. Output line 1084 from AND gate 960 is connected to switch SS-78 to its ON state. Output line 1086 from AND gate 948 is connected to switch SS-75 to its ON state and output line 1088 from AND gate 946 is connected to switch SS-53 to its ON state.

Line 1090 is connected as the second input to AND gate 998 (FIG. 5G). A signal is applied to line 1090 when SS-54 is in its ON state. Output line 1092 from AND gate 998 is connected as an input to OR gate 1024. Line 1094 is connected as an input to AND gates 1054 (FIG. 5I), 942 (FIG. 5G), 958, 964, and 996. A signal appears on line 1094 when SS-54 switches from its ON to its OFF state. Output line 1096 from AND gate 996 is connected to switch SS-51a to its ON state. Output line 1098 from AND gate 964 is connected to switch SS-71 to its ON state. Output line 1100 from AND gate 958 is connected to switch SS-55 to its ON state. Output line 1102 from AND gate 942 is connected to switch SS-63 to its ON state.

Line 1104 forms one input to AND gate 972 (FIG. 5G). A signal appears on line 1104 when SS-56 is in its ON state. Output line 1106 from AND gate 972 is connected as an input to OR gate 1024. Line 1108 is connected as an input to AND gates 1052 (FIG. 5I), 965 (FIG. 5G), and 974. A pulse appears on line 1108 when SS-56 switches from its ON to its OFF state. Output line 1110 from AND gate 965 is connected to switch SS-57 to its ON state. Output line 1112 from AND gate 974 is connected to switch SS-52 to its ON state.

Line 1114 is connected as an input to AND gate 1002 (FIG. 5G). A signal appears on line 1114 when SS-60 is in its ON state. Output line 1116 from AND gate 1002 is connected as an input to OR gate 1024. Line 1118 is connected as an input to AND gates 1034 (FIG. 5I) and 1050. A signal appears on line 1118 when SS-60 switches from its ON to its OFF state. Output line 1120 from AND gate 1034 is connected as an input to not-hyphenable OR gate 1066.

Line 1122 is connected as an input to AND gate 976 (FIG. 5G). A signal is applied to line 1122 when SS-64 is in its ON state. Output line 1124 from AND gate 976 is connected as an input to OR gate 1024. Line 1126 is connected as an input to AND gates 1048, 966, and 978. A signal appears on line 1126 when SS-64 switches from its ON to its OFF state. Output line 1128 from AND gate

966 is connected to switch SS-65 to its ON state. Output line 1130 from AND gate 978 is connected to switch SS-52 to its ON state.

Line 1132 is connected as one input to AND gate 1006. A signal appears on line 1132 when SS-68 is in its ON state. Output line 1134 from AND gate 1006 is connected as an input to OR gate 1024. Line 1136 is connected as an input to AND gates 1046, and 1036. A pulse appears on line 1136 when SS-68 switches from its ON to its OFF state. Output line 1138 from AND gate 1046 is connected as the final input to OR gate 1072. Output line 1140 from OR gate 1072 is connected as an input to OR gate 1142. Output line 1144 from AND gate 1036 is connected as an input to not-hyphenable OR gate 1066.

Line 1146 is connected as an input to AND gates 950 (FIG. 5J) and 956. A pulse appears on line 1146 when SS-72 times out. Output line 1148 from AND gate 950 is connected to switch SS-73 to its ON state. Output line 1150 from AND gate 956 is connected as an input to not-hyphenable OR gate 1066.

Line 1152 is connected as an input to AND gate 1010 (FIG. 5J). A signal appears on line 1152 when SS-75 is in its ON state. Output line 1154 from AND gate 1010 is connected as an input to OR gate 1024. Line 1156 is connected as an input to AND gates 1032 and 1044. A signal appears on line 1156 when SS-74 switches from its ON to its OFF state. Output line 1158 from AND gate 1032 is connected as an input to OR gate 1066. Output line 1160 from AND gate 1044 is connected as an input to OR gate 1142.

Line 1162 is connected as an input to OR gate 1024 (FIG. 5H). A signal appears on line 1162 when SS-75 is in its ON state. Line 1164 is connected as an input to AND gates 1030 and 1042. A pulse appears on line 1164 when SS-75 switches from its ON to its OFF state. Output line 1166 from AND gate 1030 is connected to switch SS-76 to its ON state. Output line 1168 from AND gate 1042 is connected as an input to OR gate 1142.

Line 1170 is connected as an input to AND gates 932 and 934. A signal appears on line 1170 when SS-77 switches from its ON to its OFF state. Output line 1172 from AND gate 932 is connected to switch SS-51a to its ON state. Output line 1174 from AND gate 934 is connected as an input to OR gate 1142.

Line 1176 is connected as an input to AND gate 988 (FIG. 5H). A signal appears on line 1176 when SS-79 is in its ON state. Output line 1178 from AND gate 988 is connected as an input to OR gate 1024. Line 1180 is connected as an input to AND gates 1040 and 1038. A pulse is applied to line 1180 when SS-79 switches from its ON to its OFF state. Output line 1182 from AND gate 1038 is connected to switch SS-51 to its ON state. Output line 1184 from AND gate 1040 is connected as an input to OR gate 1142. Output line 336 from OR gate 1142 is connected to switch SS-115 to its ON state.

Referring now to next-character-address counter 420 (FIG. 5D), it is seen that an input is applied to this counter through lines 1190. The address of the first table storage position in core storage 364 is read into next-character-address counter 420 when power is turned on to the circuit and at the end of each cycle of operation. The count in the next-character-address counter is incremented by a signal applied to line 1192. A signal is applied to line 1192 when SS-33b or SS-33r is in its ON state. Output lines 1194 from counter 420 are connected as the information input to gates 1196 and as one input to compare-circuit 1198 of comparison-and-gating circuit 436. Line 1200 is connected as the conditioning input to gates 1196 and as one input to OR gate 1202. A signal is applied to line 1200 when SS-32, 33j, or 33q is in its ON state. Output lines 1204 from gates 1196 are connected as one input to OR gates 1206 (FIG. 5E).

A suitable address is also stored in starting-point register 1208 (FIG. 5D) and supplementary-starting-point register 1210 when power is turned on to the circuit and

at the end of each cycle of operation. The input to starting-point register 1208 is on lines 1212. The address stored in this register is the address one position behind the address at which it is desired to begin storing a table of the type shown in FIG. 6 in core storage 364. The input to supplementary-starting-point register 1210 is on lines 1214. The signal on these lines contains the address at which it is desired to start storing a supplementary table of the type shown in FIG. 7 in core storage 364.

Output lines 1216 from starting-point register 1208 are connected as the information input to gates 1218. The conditioning input to these gates is on line 1220. A signal is applied to line 1220 when SS-0 or 85a is in its ON state. Output lines 1222 from gates 1218 are connected as one set of inputs to OR gates 1224. The other inputs 1226 from OR gates 1224 are connected as the information inputs to table-address counter (TAC) 386. As indicated previously, TAC 386 is the register in which the next table address to be looked at is determined.

TAC 386 is incremented by a signal applied to line 1228. A signal is applied to line 1228 when SS-20, 85b, 87b, or 88 is in its ON state. Output lines 1230 from TAC 386 are connected as the other set of inputs to compare-circuit 1198 in compare-and-gating circuit 436, and as the information inputs to gates 1232 and 1234. Line 1236 is connected as the conditioning input to gates 1232 and as one input to OR gate 1202. A signal is applied to line 1236 when either SS-21 or SS-86 is in its ON state. The conditioning input to gates 1234 is line 1238. A signal is applied to line 1238 when either SS-25 or SS-28 is in its ON state. Output lines 1240 from gates 1232 are connected as one set of inputs to OR gates 1206. is derived on line 1250, which line is connected as one set of inputs to OR gates 1244.

The two inputs to compare-circuit 1198 (FIG. 5D) in compare-and-gating circuit 436 have been previously indicated. If the inputs to this circuit are equal, compare-circuit 1198 generates an output signal on line 1246, which line is connected as one input to AND gate 1248. If the inputs to compare-circuit 1198 are not equal, an output is derived on line 1250, which line is connected as one input to AND gate 1252. The second input to AND gates 1248 and 1252 is line 1254. A signal is applied to line 1254 when SS-33v switches from its ON to its OFF state. Output line 438 from AND gate 1248 is connected to switch SS-85 to its ON state. Output line 440 from AND gate 1252 is connected to switch SS-33b to its ON state.

Referring back to supplementary-starting-point register 1210, output lines 1256 from this register are connected as the information input to gates 1258. The conditioning input to these gates is line 1260. A signal is applied to line 1260 when either SS-0 or SS-33e is in its ON state. Output lines 1262 from gates 1258 are connected as one set of inputs to OR gates 1264. The other set of inputs to these OR gates will be described later. Output lines 1266 from OR gates 1264 are connected as the information inputs to supplementary-address counter (SAC) 392. As indicated previously, this is the register in which the address at which an entry is to be made in the supplementary table is determined. The count in supplementary-address counter 392 is incremented by a signal applied to line 1268. A signal is applied to line 1268 when either SS-30a or 33p is in its ON state.

Output lines 1270 from supplementary-address counter 392 are connected as the information inputs to gates 1272 and 1274 and as one input to compare-circuit 448. The conditioning input to gates 1274 is line 1276. A signal is applied to line 1276 when SS-33d is in its ON state. Output lines 1278 from gates 1274 are connected as the information inputs to register 446. Output lines 1280 from register 446 are connected as the information input to gates 1282 and as the second input to compare-circuit 448. The conditioning input to gates 1282 is

line 1284. A signal is applied to line 1284 when SS-33n is in its ON state. Output lines 1286 from gates 1282 are connected as the other set of inputs to OR gates 1264.

Referring now to previously mentioned compare circuit 448 (FIG. 5D), when the two inputs to this compare circuit are equal, an output is derived on line 1288, which line is connected as one input to AND gate 1290 in gating circuit 450. When the inputs applied to compare-circuit 448 are not equal, an output is derived on line 1292 which line is one input to AND gate 1294. The other input to AND gates 1290 and 1294 is line 1296. A pulse appears to line 1296 when SS-33o switches from its ON to its OFF state. Output line 458 from AND gate 1290 is connected to switch SS-33q to its ON state. Output line 456 from AND gate 1294 is connected to switch SS-33p to its ON state.

Referring back to gates 1272 (FIG. 5D), line 1298 is the conditioning input to these gates and is also one input to OR gate 1202. A signal is applied to line 1298 when either SS-30 or SS-33f is in its ON state. Output lines 1300 from gates 1272 are connected as one set of inputs to OR gates 1206.

Referring now to core storage 364 (FIG. 5F), it is seen that it is caused to perform a memory cycle (either read or write) when a signal is applied to line 1302. A signal is applied to line 1302 when either SS-6, 22, 24, 26, 31, 33, 33g, 33k, 33m, 33s, 33v, 87, 102, or 104 is in its ON state. Whether a memory cycle of core storage 364 will be a read cycle or a write cycle is determined by memory-status flip-flop 1304. This flip-flop is switched to its ON or write state by a signal applied to line 1306. A signal is applied to line 1306 when SS-5, 21, 25, 33l, 3u, or 103 is in its ON state. Flip-flop 1304 is switched to its OFF or read state by the signal applied to line 1308. A signal is applied to line 1308 when SS-23, 32, 33f, 33r, 86, or 101 is in its ON state. Output line 1310 from the ON side of flip-flop 1304 is applied to core storage 364 to cause it to operate in its write mode. Output line 1312 from the OFF side of flip-flop 1304 is applied to core storage 364 to cause it to operate in its read mode.

As indicated previously, an entry is read into core storage 364 from MBR 368 or is read out of core storage into MBR. This register is cleared by a signal applied to line 1314. A signal is applied to line 1314 when SS-7 or 27 is in its ON state. A signal is also applied to this line when power is turned on to the circuit and at the end of each cycle of operation.

The first field in MBR 368 is the syllable field. The manner in which information is read into this field has been previously described. Output lines 1316 from this field are connected as the information input to gates 1318 (FIG. 5E) in gating circuit 484. The next field in MBR 368 is the frequency field. The manner of storing information in this field has likewise been previously described. The information contained in this field is applied through output lines 1320 to the information input of gates 1322 in gating circuit 484.

The next field in MBR 368 is the level-termination-mark field (LTM field). An input is applied to this field from gates 378 through lines 1324. The information input to these gates is from coded-character-one generator 380 through lines 1326. The conditioning input to gates 378 is from OR gate 1328 (FIG. 5E) through line 1330. The inputs to OR gate 1328 are lines 1332, 1334, and 1336 from AND gates 786, 651, and 822 respectively. Previously mentioned lines 782, 644, and 818 form one input to AND gates 786, 651, and 822 respectively. The other input to AND gates 651 and 786 is line 1338. A signal appears on line 1338 when SS-20 is in its ON state. The other input to AND gate 822 is on line 1340. A signal appears on line 1340 when SS-4 is in its ON state.

As indicated previously, output line 520 from the LTM field of MBR 368 is connected as the input to zero-detector 512. When there is a mark in this field, detector

512 generates an output signal on line 1342, which signal is applied as one input to AND gate 1344 of gating circuit 514 and as one input to AND gate 485 (FIG. 5E). When there is no mark in the LTM field, detector 512 generates an output signal on equal line 1345, which signal is applied as one input to AND gate 1346 and as one input to AND gate 1343 in gating circuit 486 (FIG. 5E). The other input to AND gates 1344 and 1346 is line 1347. A signal is applied to line 1347 when SS-103 times out. Output line 522 from AND gate 1344 is connected to switch SS-100 to its ON state, and output line 524 from AND gate 1346 is connected to switch SS-104 to its ON state.

The next field in memory-buffer register 368 is the next-character-number (NCN) field. The input to this field has been previously described. Output line 424 from this field is connected as one input to compare-circuit 442, as the information input to gates 1348, as the information inputs to previously described gates 772, and as the input to blank decoder 422. The conditioning input to gates 1348 is line 1350. A signal appears on line 1350 when either SS-25 or SS-33c is in its ON state. Output lines 1352 from gates 1348 are connected as the information input to next-character-number register 394. Output lines 1354 from next-character-number register 394 are connected as the second input to compare-circuit 442 and as the information input to gates 1356. The conditioning input to gates 1356 is line 1358. A signal appears on line 1358 when SS-29 is in its ON state. Output lines 1360 from gates 1356 are connected as the other set of inputs to previously described OR gates 756.

The two inputs to compare-circuit 442 (FIG. 5F) have been described in the previous paragraph. When these inputs are equal, a signal appears on equal-line 1362, which line forms one input to AND gate 1364 in gating circuit 444. When the two inputs applied to compare-circuit 442 are not equal, a signal appears on line 1366, which line forms one input to AND gate 1368 of gating circuit 444. The other input to AND gates 1364 and 1368 is line 1370. A pulse appears on line 1370 when SS-33h switches from its ON to its OFF state. Output line 452 from AND gate 1364 is connected to switch SS-33i to its ON state, and output line 454 from AND gate 1368 is connected to switch SS-33o to its ON state.

Blank decoder 422 (FIG. 5F) determines whether the next-character-number field of MBR 368 contains a character or not. If there is no character in this field, an output signal appears on line 1372, which line forms one input to AND gate 1374 of gating circuit 426. If a character is in the NCN field, decoder 422 generates an output signal on line 1376, which line forms one input to AND gate 1378 of gating circuit 426. The other input to AND gates 1374 and 1378 is line 1380. A pulse appears on line 1380 when SS-33a switches from its ON to its OFF state. Output line 428 from AND gate 1374 is connected to switch SS-33u to its ON state, and output line 430 from AND gate 1378 is connected to switch SS-33c to its ON state.

The next field in MBR 368 is the chain-address field. Inputs are applied to this field through OR gates 1244 and lines 1382. One input to OR gates 1244 is from gates 434 through lines 1384. The information input to gates 434 is derived from character-two-code generator 432 through lines 1386. The conditioning input to gates 434 is line 1388. A signal is applied to line 1388 when SS-33u is in its ON state. A second input to OR gates 1244 is derived from gates 418 through lines 1390. The information input to gates 418 is from zero-character-code generator 416 through lines 1392. The conditioning input to gates 418 is line 1394. A signal appears on line 1394 when either SS-5 or SS-8 is on its ON state. A third input to OR gates 1244 is from gates 1396 through lines 1398. The conditioning input to gates 1396 is line 1400. A signal appears on line 1400 when SS-33l is in its ON state. The information input to gates 1396 will be described later.

The final input to OR gates 1244 on lines 1242 has been previously described.

Output line 462 from the chain-address field of MBR 368 is connected as the input to two-detector 482 (FIG. 5E), as the input to zero-detector 480, and as the information input to gates 1402 and 1404. The conditioning input to gates 1402 is line 1406. A signal appears on lines 1406 when SS-33i is in its ON state. Output lines 1408 from gates 1402 are connected as the input to chain-address register 460. Output lines 1410 from chain-address register 460 are the information input to previously described gates 1396. Two-detector 482 generates an output signal on equal line 1412 when the chain-address field of MBR 368 contains a 2. Line 1412 is connected as one input to AND gate 1414 in gating circuit 486. Two detector 482 generates an output signal on line 1416 when a count other than 2 appears in the chain-address field of MBR. Line 1416 is connected as one input to AND gate 1418 in gating circuit 486 and as one input to AND gate 1420. Zero-detector 480 generates an output signal on equal line 1422 when a zero is in the chain-address field of MBR. Line 1422 is connected as one input to AND gate 485 and as a second input to AND gate 1343 in gating circuit 486. Zero-detector 480 generates an output signal on line 1426 when a count other than zero is in the chain-address field of MBR. Line 1426 is connected as one input to AND gate 1428 and as a second input to AND gate 1418. The final input to AND gates 485 and 1428 is line 1432. A signal appears on line 1432 when SS-88 is in its ON state. Output line 498 from AND gate 485 is connected to switch flip-flop 487 to its ON state. Line 1424 is connected to switch flip-flop 487 to its OFF state. A signal appears on line 1424 when SS-85a is in its ON state. Output line 1427 from the ON side of flip-flop 487 is connected as one input to AND gate 1429 in gating circuit 486 and to AND gate 1431. Output line 1433 from the OFF side of flip-flop 487 is connected as a third input to AND gate 1343 and as an input to AND gate 1435. The final input to AND gates 1414, 1418, 1343, and 1429 is line 1430. A pulse appears on line 1430 when SS-88 switches from its ON to its OFF state. The final input to AND gates 1431 and 1435 is line 1437. A signal appears on line 1437 when SS-104 times out. Output line 499 from AND gate 1343 is connected to switch SS-86 to its ON state. Output line 500 from AND gate 1418 is connected to switch SS-88a to its ON state. Output line 501 from AND gate 1429 is connected to switch SS-100 to its ON state. Output line 502 from AND gate 1414 is connected to switch SS-89 to its ON state. Output line 1439 from AND gate 1431 is connected to switch SS-85a to its ON state and output line 1441 from AND gate 1435 is connected to switch SS-105 to its ON state.

Output line 1434 from AND gate 1428 (FIG. 5E) is connected as the conditioning input to gate 1322, 1318, 55 and 1436 in gating circuit 484, as the second input to AND gate 1420, and as the increment-by-one input to number-of-syllable counter 1670 (FIG. 5M). Output line 1440 from AND gate 1420 is connected as the conditioning input to gates 1404 and as another input to OR gate 1202. Output lines 1442 from gates 1404 are connected as another set of inputs to OR gates 1206.

In addition to the inputs previously mentioned, lines 1444 and 1446 are also inputs to OR gate 1202 (FIG. 5D). Line 1444 is also the conditioning input to gates 1448. A signal appears on line 1444 when SS-23 is in its ON state, and a signal appears on line 1446 when SS-101 is in its ON state. Output line 1450 from OR gate 1202 is connected as the conditioning input to gates 1452 (FIG. 5E). The information input to gates 1452 is output lines 70 1454 from MAR 372. Output lines 1456 from gates 1452 are connected through delay-circuit 1458 and lines 1460 as the input to previous-address register (PAR) 390. Output lines 1462 from PAR 390 are connected as the information input to gates 1448. Output lines 1464 from gates 1448 are connected as another input to OR gates

1206. The final input to OR gates 1206 is output line 1466 from gates 1468 (FIG. 5T). The inputs to this gate will be described later. Output lines 1470 from OR gates 1206 are connected through delays 1472 and lines 1474 as the input to MAR 372.

In addition to being connected as the information input to gates 1452, output lines 1454 from MAR 372 are connected as the address input to core storage 364, as the information input to gates 1436 of gating circuit 484, and as the information input to gates 1476 (FIG. 5D). The conditioning input to these gates will be mentioned later. Output lines 1478 from gates 1476 are the other set of inputs to OR gates 1224.

The last field in MBR 368 is the used-bit field. Output line 1480 from gates 1482 (FIG. 5F) are the input to this field. The information inputs to gates 1482 are output lines 1484 from character-one generator 1486. The conditioning input to gates 1482 is line 1488. A signal appears on line 1488 when SS-103 is in its ON state.

Output line 1490 from the used-bit field of MBR 368 is connected as the input to decoder 470. When a zero is in the used-bit field, decoder 470 generates an output signal on line 1492, which line forms one input to AND gate 1494 of gating circuit 472. When a "1" is in the used-bit field, decoder 470 generates an output signal on line 1496. Line 1496 is one input to AND gate 1498 and is also one input to AND gate 1500 (FIG. 5D). The other input to AND gate 1500 is line 1502. A signal appears on line 1502 when SS-87a is in its ON state. Output line 1504 from AND gate 1500 is the conditioning input to gates 1476. The other input to gates 1494 (FIG. 5F) and 1498 is line 1506. A pulse appears on line 1506 when SS-87a switches from its ON to its OFF state. Output line 474 from AND gate 1494 is connected to switch SS-88 to its ON state, and output line 476 from AND gate 1498 is connected to switch SS-87b to its ON state.

Output lines 492 from gates 1436 of gating circuit 484 (FIG. 5E) are connected as the information inputs to gates 1510A-1510N (FIG. 5R) of word registers 488. It will be understood that while only three positions of this register are shown in FIG. 5R, this register would in fact contain as many positions as might be required. Output line 494 from gates 1318 are connected as the information input to gates 1512A-1512N. Output lines 496 from gates 1322 (FIG. 5E) are connected as the information inputs to gates 1521-152N (FIG. 5M).

Referring now to FIG. 5M, it is seen that column-select counter 508 is reset to a count of one by a signal applied to line 1530. A signal is applied to line 1530 when power is turned on to the circuit, at the end of each cycle of operation, and when either SS-85a or SS-89 is in its ON state. Column-select counter 508 is incremented one position by a signal applied to line 1532 and is decremented one position by a signal applied to line 1534. A signal is applied to line 1532 when either SS-88a or 94 is in its ON state. A signal is applied to line 1534 when SS-100 is in its ON state. Output lines 1536 from column-select counter 508 are connected as one input to compare-circuit 1538 and as the input to decoder 1540. Decoder 1540 generates an output signal on line 1542 when a count of zero is in column-select counter 508 and an output on line 1544 when a count other than zero is in this counter. Lines 1542 and 1544 are connected as inputs to AND gates 1546 and 1548 respectively of gating circuit 510. The other input to AND gates 1546 and 1548 is on line 1549. A pulse appears on line 1549 when SS-100 switches from its ON to its OFF state. Output line 516 from AND gate 1546 is connected to switch SS-107 to its ON state and output line 518 from AND gate 1548 is connected to switch SS-101 to its ON state.

Decoder 1540 generates an output signal on line 1551 when a count of one is in column-select counter 508, an output on line 1552 when there is a count of 2 in this counter, and an output on line 155N when a count of N is in the counter. Lines 1551-155N are connected as

the conditioning inputs to gates 1521-152N respectively and through cable 1550 as the conditioning inputs to (a) gates (1561A-1561N)-(156NA-156NN) (FIG. 5R) respectively; (b) gates (1571A-1571N)-(157NA-157NN) respectively; and (c) gates (1581A-1581N)-(158NA-158NN) (FIG. 5T) respectively.

Output lines 1591-159N from gates 1521-152N respectively are connected as the information input to frequency registers 1601-160N respectively of frequency register 490. Frequency registers 1601-160N are reset by a signal applied to line 1600. A signal is applied to line 1600 when power is turned on to the circuit and at the end of each cycle of operation. A signal is also applied to line 1600 when either SS-85 or 99 is in its ON state. Output lines 1611-161N from frequency registers 1601-160N respectively are connected as the information inputs to gates 1621-162N and 1631-163N respectively. The conditioning input to gate 1621-162N is line 1620. A signal appears on line 1620 when SS-89 is in its ON state. The conditioning input to gates 1631-163N is the previously described output lines 1551-155N from decoder 1540. Output lines 1641-164N from gates 1621-162N are connected as the inputs to adder 1640. Output lines 1651-165N from gates 1631-163N are connected as the inputs to OR gate 1650.

Output line 1660 from adder 1640 (FIG. 5M) is connected as the information input to gates 1662. The conditioning input to gates 1662 and gates 1664 is line 1666. A signal appears on line 1666 when SS-90 is in its ON state. The information input to gates 1664 is output lines 1668 from number-of-syllable counter 1670. Number-of-syllable counter 1670 is reset to a count of zero by a signal on line 1672. A signal is applied to line 1672 when power is turned on and at the end of each cycle of operation. A signal is also applied to line 1672 when SS-85a is in its ON state. Number-of-syllable counter 1670 is incremented by a signal applied to previously described line 1434.

In addition to being applied as an input to gates 1664, output lines 1668 from number-of-syllable counter 1670 are also applied as the second input to compare circuit 1538 and as the information input to gates 1678 and 1680. When the two inputs to compare circuit 1538 are equal, a signal appears on line 1682, which line is one input to AND gate 1684. When the two inputs to compare-circuit 1538 are not equal, a signal appears on line 1686, which line acts as one input to AND gate 1688. The other input to AND gates 1684 and 1688 is line 1690. A pulse appears on line 1690 when SS-93 switches from its ON to its OFF state. Output line 1692 from AND gate 1684 is connected to switch SS-95 to its ON state. Output line 1694 from AND gate 1688 is connected to switch SS-94 to its ON state.

Output lines 1696 and 1698 from gates 1662 (FIG. 5M) and 1664 respectively are connected as the inputs to divider 1700. Output lines 1702 from divider 1700 are connected as the information inputs to gates 1704 and gates 1706 (FIG. 5N). Output lines 1708 from OR gate 1650 is connected as the information input to gates 1710. The other input to gates 1704 and 1710 is line 1712. A signal appears on line 1712 when SS-91 is in its ON state. Output lines 1714 and 1716 from gates 1704 and 1710 respectively are connected as the inputs to subtractor 1718. Output line 1720 from subtractor 1718 is connected as the information input to gates 1722. The conditioning input to gates 1722 is line 1724. A signal is applied to line 1724 when SS-92 is in its ON state. Output lines 1726 from gates 1722 are connected as the input to squarer 1728 (FIG. 5N).

Output lines 1730 from squarer 1728 are connected as the information input to gates 1732. Output lines 1734 from intermediate-storage unit 1736 are connected as the information input to gates 1738. The conditioning input to gates 1732 and 1738 is in line 1740. A signal appears on line 1740 when SS-93 is in its ON state. Output lines

1742 and 1744 from gates 1732 and 1738 respectively are connected as the inputs to adder 1746. Output lines 1748 from adder 1746 are connected as the information inputs to gates 1750 and 1752. The conditioning input to gates 1750 is line 1754. A signal appears on line 1754 when SS-94 is in its ON state. Output lines 1756 from gates 1750 are connected as the information input to intermediate-store 1736. Intermediate-store 1736 is reset by a signal to line 1758. A signal is applied to line 1758 when power is applied to the circuit and at the end of each cycle of operation. A signal is also applied to line 1758 when SS-85a is in its ON state.

Line 1760 is connected as the conditioning input to gates 1680 and 1752. A signal is applied to line 1760 when SS-95 is in its ON state. Output lines 1762 and 1764 from gates 1680 and 1752 respectively are connected as the inputs to divider 1766. Output lines 1768 from divider 1766 are connected as the information input to gates 1770. The conditioning input to gates 1770 is line 1772. A signal is applied to line 1772 when SS-96 is in its ON state. Output lines 1774 from gates 1770 are connected as the inputs to square rooter 1776. Output lines 1778 from square rooter 1776 are connected as the inputs to gates 1780. The conditioning input to gates 1706 and 1780 is line 1782. A signal appears on line 1782 when SS-97 is in its ON state. Output lines 1784 and 1786 from gates 1706 and 1780 respectively are connected as the inputs to divider 1788. Output line 1790 from divider 1788 is connected as the information input to gates 1792. The conditioning inputs to gates 1792 is line 1794. A signal appears on line 1794 when SS-98 is in its ON state. Output lines 506 from gates 1792 are connected as the information inputs to gates 1796A-1796N (FIG. 5S) of word register 488.

Referring now to FIG. 5P, it is seen that word-select counter 528 is reset to a count of one by a signal applied to line 1798. A signal is applied to line 1798 when power is turned on to the circuit and at the end of each cycle of operation. A signal is also applied to line 1798 when SS-85 or SS-107 is in its ON state. Word-select counter 528 is incremented by a signal applied to line 1800. A signal is applied to line 1800 when SS-105 or SS-111 is in its ON state. There is an output line 1802 from word-select counter 528 for each word in word register 488. Lines 1802A-1802N are connected as the conditioning inputs to gates 1804A-1804N (FIG. 5Q) respectively (only 1804A and 1804B are shown in the figure) as the conditioning input to gates 1806A-1806N (FIG. 5R), as the conditioning input to gates 1510A-1510N, as the conditioning input to gates 1512A-1512N, as the conditioning input to gates 1796A-1796N (FIG. 5S), and as one input to AND gates (1581A-1581N)-(158NA-158NN) (FIG. 5T) respectively.

Output lines 1808A-18180N from gates 1510A-1510N are connected as the information inputs to gates 1571A-157NA, 1571B-157NB . . . 1571N-157NN. Output lines 1809A-1809N from gates 1512A-1512N respectively are connected as the information inputs to gates 1561A-156NA, 1561B-156NB . . . 1561N-156NN respectively. Output lines 1811A-1811N from gates 1561A-1561N are connected as the information input to first-syllable registers 1821A-1821N. Output lines 1812A-1812N from gates 1562A-1562N are connected as inputs to second-syllable registers 1822A-1822N. There are similar connections for the remaining syllable registers in each of the words of word registers 488 with output lines 181NA-181NN from gates 156NA-156NN being connected as the inputs to syllable N registers 182NA-182NN respectively. Similarly, output lines 1831A-1831N from gates 1571A-1571N are connected as the inputs to address registers 1841A-1841N. Output lines 1832A-1832N from gates 1572A-1572N are connected as the inputs to address registers 1842A-1842N respectively. Similar inputs are present for the remaining address registers in each of the words with output lines 183NA-183NN from gates

157NA-157NN being connected as the inputs to address registers 184NA-184NN.

Referring now to FIG. 5N, it is seen that the information input to gates 1678 is output lines 1668 from number-of-syllables counter 1670. The conditioning input to these gates is line 1850. A signal is applied to line 1850 when SS-98 is in its ON state. Output lines 1852 from these gates are connected as the information inputs to gates 1806A-1806N (FIG. 5R). Output lines 1854A-1854N from gates 1806A-1806N respectively are connected as the inputs to number-of-syllable registers 1856A-1856N. The final input to the word registers is output lines 1858A-1858N (FIG. 5S), from gates 1796A-1796N, which are connected as the inputs to ratio registers 1860A-1860N respectively. The reset input to the number of syllable, syllable, address, and ratio registers in word registers 488 is line 1861. A signal is applied to line 1861 when SS-85 is in its ON state.

Output lines 1862A-1862N from number-of-syllable registers 1854A-1854N (FIG. 5R) are connected as the information inputs to gates 1864A-1864N and 1866A-1866N (FIG. 5P). It should be noted that only the gates for the A and B words are shown for this portion of the circuit. However, this circuitry is exemplary of that which would appear for the other words and is shown as an example of the type of circuitry which would be employed. Output lines 1868A-1868N from gates 1864A-1864N are connected as the inputs to OR gate 1870 in compare-and-gating circuit 548. Output lines 1872A-1872N from gates 1866A-1866N are connected as the inputs to OR gate 1874. Output lines 1876 and 1878 from OR gates 1870 and 1874 respectively are connected as the inputs to compare circuit 1880. If the inputs applied to compare-circuit 1880 by OR gate 1874 (this would be the ratio at the address indicated by preferred-word register 544 during step 112), (FIG. 4) is greater than the ratio applied by OR gate 1870, compare-circuit 1880 generates an output signal on line 1882, which line is connected as one input to AND gate 1884. If the number of syllables in the two words being compared as equal, compare-circuit 1880 generates an output signal on line 1886, which is applied as one input to AND gate 1888. If the number of syllables applied by OR gate 1870 is greater than the number applied by OR gate 1874, compare-circuit 1880 generates an output signal on line 1890 which is applied as one input to AND gate 1892. Line 1894 is the other input to AND gates 1884, 1888, and 1892. A signal appears on line 1894 when SS-109 times out. An output signal on line 550 from AND gates 1892 causes SS-110 to be switched to its ON state. An output signal on line 554 from AND gate 1888 causes SS-112 to be switched to its ON state. An output signal on line 552 from AND gate 1884 causes SS-111 to be switched to its ON state.

Cables 1896A-1896N from syllable registers (1812A-1812NA)-(1821N-1822N) (FIGS. 5R-5S) respectively are connected as the information inputs to gates 1898A-1898N (FIG. 5Q) (only two of which are shown in the figure). Output lines 1900A-1900N are connected through OR gates 1902 and lines 1904 as the inputs to registers 1911-1911N of coded-word-hyphenation registers 564 (FIG. 5K).

Output lines 1921A-1921NA from address registers 1841A-184NA are connected as the information inputs to gates 1931A-193NA (FIG. 5T) respectively. Output lines 1921B-1921NB from address registers 1841B-184NB are connected as the information inputs to gates 1931B-193NB respectively. The outputs from the address registers of the other words in word registers 488 are similarly connected with output lines 1921N-1921NN from address registers 1841N-184NN being connected as the inputs to gates 1931N-193NN. Output lines 1941A-1941NA from AND gates 1581A-158NA (FIG. 5T) are connected as the conditioning inputs to gates 1931A-193NA. Output lines 1941B-1941NB from AND

gates 1581B-158NB are connected as the conditioning inputs to gates 1931B-193NB. There are similar connections for the remaining words in word register 488 with output lines 1941N-194NN from AND gates 1581N-158NN being connected as the conditioning inputs to gates 1931N-193NN. Output lines 1951A-195NA from gates 1931A-193NA are connected as the inputs to OR gate 1960A. Output line 1951B-195NB from gates 1931B-193NB are connected as the inputs to OR gate 1960B. There are similar connections for the remaining words in word register 488 with output lines 1951N-195NN from gates 1931N-193NN being connected as the inputs to OR gates 1960N. Output lines 1962A-1962N from OR gates 1960A-1960N are connected as the inputs to OR gate 1964. Output lines 1966 from OR gates 1964 are connected as the information inputs to previously mentioned gates 1468. Line 1968 is the conditioning input to gates 1468. A signal appears on lines 1968 when SS-101 is in its ON state. As indicated previously, output lines 1466 from gates 1468 is connected as an input to OR gate 1206 (FIG. 5E), which leads into MAR 372.

Output lines 1970A-1970N from ratio registers 1860A-1860N (FIG. 5S) of word registers 488 are connected as the information inputs to gates 1804A-1804N (FIG. 5Q), 1972A-1972N, and 1974A-1974N (only two of each of the gates are shown in the figures). Output lines 1976A-1976N from gates 1804A-1804N are connected as the inputs to OR gate 536 (FIG. 5P). Output lines 1978 from OR gates 536 are connected as the input to blank detector 530 and compare-to-one detector 532. When the ratio applied to blank detector 530 is not a blank, an output signal appears on line 1980, which line is connected as one input to AND gate 1982 of gating circuit 534. When the ratio field applied through OR gate 536 to blank detector 530 contains a blank, an output signal appears on line 1984, which line is connected as one input to AND gates 1986 and 1988. When the ratio in the field applied to compare-to-one circuit 532 is less than or equal to one, a signal appears on line 1990, which line is connected as a second input to AND gate 1982. When the ratio applied to compare-to-one detector 532 is greater than one, an output signal is derived on line 1992. Line 1992 is connected as one input to AND gates 1994 and 1996 in gating circuit 534. A second input to AND gate 1994 is output line 1998 from the OFF side of first-time-through flip-flop 535. Another input to AND gate 1996 is output line 2000 from the ON side of first-time-through flip-flop 535. Flip-flop 535 is reset to its OFF state by a signal applied to line 2002. A signal is applied to this line when power is applied to the circuit and at the end of each cycle of operation. A signal is also applied to this line when SS-110 is in its ON state. Flip-flop 535 is switched to its ON state by a signal applied to line 2004. A signal is applied to line 2004 when SS-107 is in its ON state. The final input to AND gates 1982, 1988, 1994, and 1996 is line 2006. A pulse is applied to line 2006 when SS-108 switches from its ON to its OFF state. Output line 538 from AND gate 1988 is connected to switch SS-120 to its ON state. Output line 540 from AND gate 1982 is connected to switch SS-111 to its ON state. Output line 546 from AND gate 1994 is connected to switch SS-109 to its ON state and output line 542 from AND gate 1996 is connected to switch SS-110 to its ON state.

As indicated previously one input to AND gate 1986 (FIG. 5P) is blank-output line 1984 from blank detector 530. The other input to this AND gate is line 2008. A signal is applied to line 2008 when SS-108 is in its ON state. Output line 2010 from AND gate 1986 is connected as one input to AND gates 2012A-2012N (only two of which are shown in FIG. 5P). The other input to AND gates 2012A-2012N are output lines 2014A-2014N respectively from preferred-word register 514. The input to preferred-word register 544 is output lines 2016 from gates 2108. The information inputs to gates 2018 are output lines

1802 from word-select counter 528. The conditioning input to gate 2018 is line 2020. A signal is applied to line 2020 when SS-110 is in its ON state. Preferred-word register 544 is reset to a count of one by a signal applied to line 2022. A signal is applied to line 2022 when power is applied to the circuit and at the end of each cycle of operation. A signal is also applied to line 2022 when SS-107 is in its ON state. Output lines 2024A-2024N from AND gates 2012A-2012N respectively are connected as the conditioning inputs to the aforementioned gates 1898A-1898N (only two of which are shown in FIG. 5Q).

In addition to the connections previously mentioned, output lines 1802A-1802N from word-select counter 528 (FIG. 5P) are connected as one input to AND gates 2026A-2026N and 2028A-2028N respectively (only two of which are shown in FIG. 5P). Similarly, output lines 2014A-2014N from preferred-word register 544 are connected as one input to AND gates 2030A-2030N and 2032A-2032N (only two of which are shown in FIG. 5P). The other input to AND gates 2026A-2026N and 2030A-2030N is line 2034. A signal is applied to line 2034 when SS-109 is in its ON state. The other input to AND gates 2028A-2028N and 2032A-2032N is line 2036. A signal appears on line 2036 when SS-112 is in its ON state. Output lines 2038A-2038N from AND gates 2026A-2026N are connected as the conditioning inputs to gates 1864A-1864N, and output lines 2040A-2040N from AND gates 2030A-2030N are connected as the conditioning inputs to gates 1866A-1866N (only two of each of these lines and gates being shown in FIG. 5P).

Output lines 2042A-2042N from AND gates 2028A-2028N are connected as the conditioning inputs to gates 1972A-1972N (FIG. 5Q) and output lines 2044A-2044N from AND gates 2032A-2032N are connected as the conditioning inputs to gates 1974A-1974N (only two of each of the lines and each of the gates being shown in FIG. 5Q). Output lines 2046A-2046N from gates 1972A-1972N are connected as the inputs to OR gate 2048 of gating-and-compare circuit 556. Output lines 2050A-2050N from gates 1974A-1974N are connected as the inputs to OR gate 2052. Output lines 2054 and 2056 from OR gates 2048 and 2052 respectively are connected as the inputs to compare-circuit 2058. If the ratio represented by the signal applied through OR gate 2048 to compare-circuit 2058 is greater than the ratio applied through OR gate 2052, compare-circuit 2058 generates an output signal on line 2060, which line forms one input to AND gate 2062. If the ratio represented by the signal applied to OR gate 2048 is equal to or less than that represented by the signal applied through OR gate 2052, compare circuit 2058 generates an output signal on line 2064 which is applied as one input to AND gate 2066. The other input to AND gates 2062 and 2066 is line 2068. A signal is applied to line 2068 when SS-112 switches from its ON to its OFF state. It will be remembered that gating-and-compare circuit 556 is involved in the performance of step 282 of FIG. 4. The significance of the inputs and outputs from this gate can be judged accordingly. Output line 558 from AND gate 2062 is connected to switch SS-110 to its ON state, and output line 560 from AND gate 2066 is connected to switch SS-111 to its ON state.

Referring now to FIG. 5K, it is seen that scan-control circuit 566 includes a group-control ring 2070 and a unit-control ring 2072. Signals on lines 2074 and 2076 reset group-control ring 2070 and unit-control ring 2072 respectively to their first position. A signal is applied to lines 2074 and 2076 when power is applied to the circuit, at the end of each cycle of the circuit, and when SS-120 is in its ON state. In addition, a signal is applied to line 2076 when either SS-126 or SS-128 is in its ON state. Group-control ring 2070 is incremented by a signal applied to line 2078, and unit-control ring 2072 is incremented by a signal applied to line 2080. A signal is applied to line 2078 when either SS-124 or SS-128 is in its ON state, and a signal is applied to line 2080 when SS-122 is in its ON state.

Output lines 2079A-2079N from group-control ring 2070 are connected as the inputs to AND gates (2081A-2086)-(2081N-2086N) respectively. Output lines 2091-2096 from unit-control ring 2072 form the other input to AND gates (2081A-2081N)-(2086A-2086N) respectively. Line 2091 is also connected as one input to AND gate 2100 (FIG. 5L) and through inverter 2102 and line 2104 as one input to AND gates 2106 and 2108. Output line 2096 from unit-control ring 2072 is also connected as one input to AND gate 2110 and through inverter 2112 and line 2114 as one input to AND gate 2116. Output lines 2121A-2126A from AND gates 2081A-2086A are connected as the scan control inputs to coded-word-hyphenation register 1911. Output lines 2121B-2126B from AND gates 2081B-2086B are connected as the scan-control inputs to coded-word-hyphenation register 1912. There are similar inputs to the remaining coded-word-hyphenation registers with output lines 2121N-2126N from AND gates 2081N-2086N being connected as the scan-control inputs to coded-word-hyphenation register 191N.

Output lines 2131-213N from coded-word-hyphenation registers 1911-191N respectively are connected as the inputs to OR gates 2140 (FIG. 5L) in control-and-gating-circuit 568. Output lines 2142 from OR gates 2140 are connected as the inputs to blank decoder 2144. When the position being scanned in the coded-word-hyphenation registers contains a blank, blank decoder 2144 generates an output signal on equals line 2146, which line is connected as a second input to AND gates 2100, 2106, and 2108. When the position in the coded-word-hyphenation registers being scanned contains some code character other than a blank, blank decoder 2144 generates an output signal on line 2148, which line is connected as an input to AND gates 2110, 2116, and 2150. The other input to AND gates 2100, 2106, 2110, and 2116 is line 2152. A pulse is applied to line 2152 when SS-121 switches from its ON to its OFF state. An output signal on line 2154 from AND gate 2116 causes SS-122 to be switched to its ON state. An output signal on line 2156 from AND gate 2110 causes SS-124 to be switched to its ON state. An output signal on line 2158 from AND gate 2100 causes SS-129 to be switched to its ON state, and an output signal on line 2160 from AND gate 2106 causes SS-128 to be switched to its ON state.

The other input to AND gates 2108 and 2150 is line 2162. A signal is applied to line 2162 when SS-121 is in its ON state. Output line 578 from AND gate 2108 is connected as one input to OR gate 2164 in gating circuit 570. The other input to this OR gate is line 580. A signal appears on line 580 when SS-125 is in its ON state. Output line 2166 from OR gate 2164 is connected as the conditioning input to gates 2168. The information input to gates 2168 are output lines 2170 from hyphen-generator 572. Output line 574 from AND gate 2150 is connected as the conditioning input to gates 634. As indicated previously, the information input to gates 634 are the lines 332 which contain characters from input-buffer register 302 (FIG. 5A). Output lines 2170 and 2172 from gates 634 and 2168 respectively are connected as two sets of inputs to OR gates 2174. The other set of inputs to these OR gates are output lines 2176 from gates 2178. The information input to gates 2178 are output lines 2180 from blank-code generator 2182. The conditioning input to gates 2178 is line 2184. A signal appears on line 2184 when SS-130 is in its ON state. Output line 576 from OR gate 2174 is connected as the information input to output register 346. Output lines 2186 from input-control-ring 2188 determine where in output register 346 data applied to lines 576 will be stored. Only one of the lines 2186 is conditioned in any given time. Input-control-ring 2188 is reset to its initial position by a signal applied to line 2190. A signal is applied to line 2190 when power is turned on, at the end of each operating cycle, and when SS-120 is in its ON state. Input-control-ring 2188 is incremented by a signal applied to line 2192 and is decremented by a signal applied to line 2194. A signal is ap-

plied to line 2192 when either SS-122, 124, 126, or 128 is in its ON state. A signal is applied to line 2194 when SS-129 is in its ON state. Characters are read out of output register, a character at a time on line 2196 under control of the printing device (not shown).

5

DETAILED OPERATION

The description of the operation of the circuit shown in FIGS. 5A-5T will generally be with reference to a specific example in which the proper hyphenation pattern for the word "Mercantile" is determined. Prior to the beginning of the operation to be described, a signal is applied to the reset input of each flip-flop, register, and counter in the circuit so that all of the circuit elements are in their reset condition at the beginning of the operating cycle. As indicated previously, these reset inputs are generated when power is applied to the circuit and at the end of each operating cycle. Once all of the registers have been reset, the following registers are set as indicated:

Line-size register 864 (FIG. 5C) in overflow-detection circuit 304 is set by signals applied to lines 862 to indicate the total number of spaces which the line is to contain. Next-character-address counter 420 (FIG. 5D) is set by signals applied to lines 1190 to the first-table address in core storage 364. Starting-point register 1208 is set by signals applied to lines 1212 to an address-one address position below that at which the table is to begin. Supplementary-starting-point register 1210 is set by signals applied to lines 1214 to the address at which the supplementary table in core storage 364 is to begin. Assuming that the table in core storage 364 is to begin at address 100 and the supplementary table at address 500, the address 100 is stored in next-character address counter 420, 30 the address 099 in starting-point register 1208, and the address 500 in supplementary-starting-point register 1210.

Steps 202 and 204

As a word is applied to the printing device (not shown), each character of the word is applied through lines 300 to input-buffer register 302 (FIG. 5A). Since input-control ring 608 is initially reset to its first position, the first character applied to input-buffer register 302 is stored in the first position of this register. A signal is applied by the external circuitry to line 614 after this character is applied to the circuit incrementing the input-control ring so that the second character applied to the input-buffer register is stored in its second position. Succeeding characters are stored in succeeding positions of the input-buffer register under control of the input-control ring. As each character is applied to the input-buffer register, a signal is applied to bit-line 310 (FIG. 5C) causing l/w counter 312 and character counter 848 to be incremented. When the end of a word (i.e., a space) is detected, a signal is applied to line 306. If, at this time, the count in character counter 848 is less than the count in line-size register 864, then overflow flip-flop 876 is still in its reset condition, generating an output signal on line 880 to partially condition AND gate 766. The signal on line 306 fully conditions AND gate 766, causing an output signal on line 308, which is applied through OR gate 611 (FIG. 5A) and line 605 to reset input-buffer register 302 and input-control ring 608. After a short delay in delay 760, the end-of-word signal on line 306 is also applied to reset l/w counter 312. This means that each word in a line is stored in the input-buffer register, and the number of characters in this word counted, but that this information is not used unless the permissible number of characters in the line is reached before the end of the word is reached.

When the count is counter 848 (FIG. 5C) becomes equal to the count in line-size register 864 while a word is being loaded into input-buffer register 302, compare circuit 870 generates an output signal on line 872, which partially conditions AND gate 854. The bit signal on line 75 310, which caused character counter 848 to increment

to the required count, is delayed in delay 850 and applied through line 852 to the other input of AND gate 854. AND gate 854 being fully conditioned at this time generates an output signal on line 874 which switches overflow flip-flop 876 to its ON state. Flip-flop 876 being in its ON state causes an output signal to appear on line 882, which signal partially conditions AND gate 314. If, at this time, decoder 780 generates an output signal on line 832 indicating that a count of one or two is in *l/w* counter 312, this means that the overflow occurred on the first or second character of the word, and that the word is therefore not to be hyphenated. The combined occurrence of signals on lines 832 and 882 fully conditions AND gate 314 to generate an output signal on line 888 which signal switches flip-flop 890 to its ON state. The sequence of operations just described effectively performs step 202 of the flow diagram of FIG. 1 (i.e., test to determine if the overflow occurred on the first or second character).

The circuit then continues to load characters into input-buffer register 302 until a signal on line 306 indicates that the end of the word has been reached. Since overflow flip-flop 876 is now in its ON state, AND gate 764 is fully conditioned by the end-of-word signal on line 306, causing an output signal on line 309 which is applied to stop the input-character-generating circuit. The signal on line 309 is also applied to partially condition AND gates 320, 322, and 886. If the overflow occurred on the first or second character, flip-flop 890 is generating an output signal on line 896 at this time to fully condition AND gate 886, causing an output signal on line 900 which is applied through OR gate 318 to do-not-hyphenate line 316. This completes step 202 (FIG. 1) of the operation. If, at this time, *l/w* counter 312 contains a count of 1, 2, 3, or 4, output line 830 from decoder 780 has a signal on it which fully conditions AND gate 320 to generate an output signal on line 898. The signal on line 898 is applied through OR gate 318 to do-not-hyphenate line 316. The above operation performs step 204 of the flow diagram of FIG. 1 by causing a do-not-hyphenate signal to be generated if the word at the end of the line contains four or less characters.

If the overflow did not occur on the first or second character, then flip-flop 890 is still in this reset condition, generating an output signal on line 894 which is applied to the second input to AND gate 322, and if the *l/w* counter 312 contains more than four letters, there is no signal on line 830, and inverter 834 applies the third input to AND gate 322, fully conditioning this AND gate to generate an output signal on line 324. The signal on line 324 switches SS-50 of clock circuit 326 to its ON state. This causes the test-for-number-of-vowels operation (step 206 of FIG. 1) to be initiated.

Test for number of vowels

The procedure for counting the number of vowel groups in a word is shown in FIG. 2. It will be remembered from previous discussion that each vowel or group of two vowels is counted as a single vowel group with the following exceptions: (1) An "i" followed by an "a" is counted as two vowels; (2) a "y" is counted as a vowel if it follows a consonant; (3) a final "e" is not counted as a vowel unless it is preceded by a stop character (b, d, g, j, k, p, t) followed by an "l"; (4) an "e" before a final "d" is counted only if the letter preceding the "e" is a "t" or a "d"; (5) and an "e" before a final "s" is counted only if the preceding letter is s, c, g, h, or x.

The CL-50 signal which occurs when SS-50 is in its ON state is applied through line 616 to reset output-control ring 612 (FIG. 5A) to its first position. This conditions input-buffer register 302 to apply the character contained in its first character position, for the example chosen an "m," through the appropriate lines 622 and OR gates 330 to lines 332. The signals on lines 332 are applied to decoder 632 (FIG. 5G) in vowel-count circuit 328. As may be seen from column 77 of the appendix

when SS-50 switches to its OFF state, it causes SS-52 to be switched to its ON state.

The resulting signal on line 1058 is applied as one conditioning input to AND gate 1014 (FIG. 5I) in vowel-count circuit 328. If the character applied to decoder 632 at this time is an "a," an "o," or a "u," OR gate 926 applies a second input to AND gate 1014 through line 1012 at this time. It will be remembered that these three vowels are always counted as a single vowel group, regardless of what character or characters may follow them. Therefore, output line 1068 from AND gate 1014 is connected through OR gate 1024 and line 1022 to increment number-of-vowel counter 1018.

When SS-52 switches from its ON to its OFF state, a signal is applied through line 1060 to one input of AND gates 986, 962, 1056, 1016, 960, 948 and 946. Assume first that the character applied to decoder 632 is an "a," an "o," or a "u," as previously stated. Then, there is a signal on line 1012 applying a second input to AND gate 1016. If a count of less than two is in number-of-vowel counter 1018, a third input to this AND gate is derived from line 1026. AND gate 1016 is therefore fully conditioned to generate an output signal on line 1082 which switches SS-51 to its ON state. Referring to the appendix, it is seen that when SS-51 is in its ON state, a signal is applied to line 620 (FIG. 5A) to increment output-control ring 612. This causes the character following the vowel just looked at to be applied to decoder 632. However, it will be remembered that according to the rules previously set out, even if this character is a vowel, it should not be counted. Therefore, there is no need to look at this character. To implement this, when SS-51 switches from its ON to its OFF state, it causes SS-51a to be switched to its ON state. SS-51a being in its ON state causes another signal to be applied to line 620 to increment output-control ring 612 one more position. When SS-51a switches from its ON to its OFF state, it causes SS-52 to be switched to its ON state. This causes the character, two characters advanced from the last character looked at, to be investigated to determine if it should be counted as a vowel group.

If the character applied to decoder 632 is an "a," "o," or "u," and the incrementing of counter 1018 during CL-52 time steps this counter to a count of two, there is no need to look for further vowels, since it has already been determined that the word is hyphenable. The resulting signal on line 1028 therefore conditions AND gate 1056 to generate an output signal on line 1070 during 52_r time, which signal is applied through OR gate 1072, line 1140 and OR gate 1142 to proceed-to-next step line 336.

Assume that the character now being applied to decoder 632 is not a vowel, is not a "y," and is not a blank. There will therefore be no output from OR gate 924 (FIG. 5G) and inverter 982 will therefore generate an output signal on line 984, which output is applied as one input to AND gate 986, the other input to this AND gate being the 52_r signal on line 1060. Output line 1062 from AND gate 986 is connected to switch SS-51a to its ON state. It will be remembered that when SS-51a is in its ON state, it causes a signal to be applied to line 620 to increment output-control ring 612 one position. This results in the next character being applied to decoder 632. As before, when single shot 51A switches to its OFF state, single-shot 52 is switched ON to cause a new character to be investigated.

Assume that the character now being applied to decoder 632 is a "y." It will be remembered that this character is counted as a vowel group if it is preceded by a consonant. The resulting signal out of decoder 632 on line 920 is applied as one input to AND gate 960. The other input to AND gate 960 is the 52_r line 1060. AND gate 960 being fully conditioned causes an output signal to appear on line 1084, which signal switches single-shot 78 to its ON state. From the appendix, it is

seen that when single-shot 78 is in its ON state, a signal is applied to line 618 to decrement output-control ring 612 one position. This causes the character preceding that previously looked at, in this case the character preceding the "y," to be applied to decoder 632. When single-shot 78 switches from its ON to its OFF state, it causes single-shot 79 to be switched to its ON state. When single-shot 79 is in its ON state, it causes a signal to be applied through line 1176 to one input of AND gate 988 (FIG. 5H). The other input to AND gate 988 is 10 the aforementioned line 984 from inverter 982, which line has a signal on it when the character applied to decoder 632 is not a vowel, a "y," or a blank, or in other words when the character applied to decoder 632 is a consonant. If AND gate 988 is fully conditioned, it generates an output signal on line 1178 which is applied through OR gate 1024 and line 1022 to increment number-of-vowel counter 1018. When SS-79 switches from its ON to its OFF state, a signal is applied through line 1180 to one input of AND gates 1038 and 1040. If, at this time, number-of-vowel counter 1018 is generating an output signal on line 1026 indicating that less than two vowel groups have been found, then the search for vowels must be continued, and AND gate 1038 is fully conditioned to generate an output signal on line 1182, causing single-shot 51 to be switched to its ON state. If two vowel groups have been found, then the resulting signal on line 1028 is applied to fully condition AND gate 1040. The resulting output signal on line 1184 is applied through OR gate 1140 to line 336. The signal on line 336 causes the circuit to proceed to the next step in the operation.

If the character applied to decoder 632 is an "i," a signal is applied through line 909 to one input of AND gate 948, the other input to this AND gate being the 52_r line 1060. AND gate 948 being fully conditioned generates an output signal on line 1086, which switches single-shot 75 to its ON state. It will be remembered that the character "i" is counted as one vowel group and that an additional vowel group is counted if the "i" is followed by an "a." When SS-75 is in its ON state, a signal is applied through line 1162, OR gate 1024, and line 1022 to increment number-of-vowel counter 1018. When SS-75 switches from its ON to its OFF state, a signal is applied to line 1164 to condition AND gates 1030 and 1042. If two vowel groups have already been counted, it does not make any difference whether the "i" is followed by an "a" or not. Therefore, if a signal appears on line 1028 at this time indicating that a count of two is in number-of-vowel counter 1018, AND gate 1042 is fully conditioned, generating an output signal on line 1168, which is passed through OR gate 1142 to line 336 to cause the circuit to proceed to the next step. If, however, there is a count of less than two in vowel-group counter 1018, the resulting signal on line 1026 is applied to fully condition AND gate 1030, resulting in an output signal on line 1166 which switches single-shot 76 to its ON state. Single-shot 76 being in its ON state causes a signal to be applied through line 620 to increment output-control ring 612 one position. This causes the character following the "i" to be applied to decoder 632. When single-shot 76 switches from its ON to its OFF state, single-shot 77 is switched to its ON state. No functions are performed during the period that single-shot 77 is in its ON state. However, when single-shot 77 switches from its ON to its OFF state, a signal is applied through line 1170 to one input of AND gates 932 and 934. If, at this time, the character applied to decoder 632 is not an "a," there is no signal on line 902 from decoder 632, and inverter 928 generates an output signal on line 930, which fully conditions AND gate 932. The resulting output signal on line 1172 causes single-shot 51a to be switched to its ON state, causing the search for additional vowel groups to be continued. If the character applied to decoder 632 at this time is an "a," a signal is applied through line

902 to fully condition AND gate 934. Since an "i" followed by an "a" is counted as two vowel groups, the required number of vowel groups has been found and the circuit may proceed on to the next step. Therefore, the output from AND gate 934 on line 1174 is applied through OR gate 1142 to line 336.

If the character applied to decoder 632 is an "e," the resulting output signal on line 906 from decoder 632 is applied as a conditioning input to AND gate 946. The other input to this AND gate is the 52_r line 1060. Output line 1088 from AND gate 646 causes single-shot 53 to be switched to its ON state. As may be seen from FIG. 2, the first step following the detection of an "e" being applied to decoder 632 is to look at the next character. Therefore, when SS-53 is in its ON state, a signal is applied to line 620 to increment output-control ring 612 one position. When SS-53 switches from its ON to its OFF state, a signal is generated which switches SS-54 to its ON state. SS-54 being in its ON state causes a signal to be applied through line 1090 to one input of AND gate 998 (FIG. 5G). The other input to AND gate 998 is output line 994 from inverter 992, which inverter generates an output signal when the character applied to decoder 632 is not a "d," an "s," or a blank. Referring to FIG. 2, it is seen that if the character following the "e" is not one of the three characters indicated above, the "e" should be counted as a vowel group. Therefore, output line 1092 from AND gate 998 is connected through OR gate 1024 and line 1022 to increment number-of-vowel counter 1018.

When SS-54 switches from its ON to its OFF state, a signal is applied through line 1094 to one input of AND gates 1054, 942, 958, 964 and 996. If inverter 992 is generating an output signal on line 994 at this time, a second input is applied to AND gate 996. A third unit to this AND gate is the not-equal-to-two output line 1026 from number-of-vowel counter 1018. Output line 1096 from AND gate 996 is connected to switch SS-51a to its ON state. This means that if the next character is not a "d," an "s," or a blank, so that the "e" is counted as a vowel group, but the vowel-group counter still contains a count less than two, the search is continued for additional vowel groups. If, at this time, the count in number-of-vowel group counter 1018 is equal to two, an output signal appears on line 1028 to fully condition AND gate 1054. This results in an output signal on line 1074 which is applied through OR gate 1072, line 1140 and OR gate 1142 to line 336 to cause the circuit to proceed to the next step in the operation.

If at this time the character applied to decoder 632 is a "d," a signal is applied through line 905 to a second input of AND gate 942, the third input to this AND gate being the not-equal-to-two line 1026. Output line 1102 from AND gate 942 is connected to switch SS-63 to its ON state. It will be remembered that an "e" before a final "d" is counted only if the letter preceding the "e" is a "t" or a "d." It is therefore necessary to look at the character following the "d" to determine if it is a blank and therefore whether the "d" is the final character of the word. During step 63 a signal is applied to line 620 to increment output-control ring 612. This causes the character following the "d" to be applied to decoder 632. When SS-63 times out (i.e. switches from its ON to its OFF state), SS-64 is switched to its ON state. When SS-64 is in its ON state, a signal is applied through line 1122 to one input of AND gate 976. If the character then being applied to decoder 632 is not a blank there is no signal on line 921 at this time, and inverter 968 therefore generates a signal on line 970 which is applied as the other input to AND gate 976. Output line 1124 from AND gate 976 is connected through OR gate 1024 and line 1022 to increment number-of-vowel counter 1018. The "e" is in this way counted as a vowel if the "d" following it is not the final letter of a word.

When SS-64 times out, a signal is applied through line

1126 to one input of AND gates 1048, 966 and 978. The other input to AND gate 1048 is equal to two line 1028 from number-of-vowel counter 1018. The output from AND gate 1048 is connected through OR gates 1072 and 1142 to line 336 to cause the circuit to proceed to the next step in the operation. If the character following the "d" is not a blank and the count in number-of-vowel counter 1018 is less than two, then all inputs to AND gate 978 are fully conditioned at this time, causing an output signal on line 1130 which switches SS-52 to its ON state. This causes a determination to be made as to whether the character following the "d" should be counted as a vowel group. Finally, if the character following the "d" is a blank, and there is a count of less than two in number-of-vowel counters 1018, all inputs to AND gate 966 are fully conditioned, causing an output signal on line 1128 which switches SS-65 to its ON state.

It is now desired to look at the character preceding the "e" to see whether it is in a "t" or a "d". Since the character presently being looked at is the character following the "d," it is necessary to look back three characters at this time. SS-65 being in its ON state causes a signal to be applied to line 618 to decrement output-control ring 612 one position. When SS-65 times out, it causes SS-66 to be switched to its ON state. SS-66 being in its ON state causes a second signal to be applied to line 618 to decrement output-control ring 612 the second position. When SS-66 times out, it causes SS-67 to be switched to its ON state. When SS-67 is in its ON state, a third signal is applied to line 618 to decrement output-control ring 612 to the desired position. When SS-67 times out, it switches SS-68 to its ON state. When SS-68 is in its ON state, a signal is applied through line 1132 to one input of AND gate 1006. The other input to AND gate 1006 is output line 1004 from OR gate 944. A signal appears on line 1004 if either a "d" or a "t" is applied to decoder 632 at this time. If AND gate 1006 is fully conditioned, a signal appears on line 1134, which signal is applied through OR gate 1024 and line 1022 to increment number-of-vowel counter 1018. It should be noted at this point that if the circuit has gone this far, it means that there is only a count of one in counter 1018 and, since the "d" was the final letter of the word, that there can be no further vowel groups in this word. Therefore, according to the criteria previously indicated, the word in question is not hyphenable. Therefore, when SS-68 times out, a signal is applied through line 1136 to AND gates 1036 and 1046. The other input to AND gate 1036 is not-equal-to-two line 1026. Output line 1144 from AND gate 1036 is connected through OR gate 1066 to not-hyphenable line 334. The other input to AND gate 1046 is equal-to-two line 1028. Output line 1138 from AND gate 1046 is connected through OR gates 1072 and 1142 to proceed-to-next-step line 336.

Returning now to the time at which SS-54 times out, if the character then applied to decoder 632 (i.e. the character following the "e") is an "s," all inputs to AND gate 958 (FIG. 5G) are present and an output signal is derived on line 1100 to switch SS-55 to its ON state. When SS-55 is in its ON state, a signal is applied to line 620 to increment output-control ring 612, causing the character following the "s" to be applied to decoder 632. It will be remembered that if this character is a blank, if the "s" is a final "s," the "e" is counted only if it is preceded by an "s," "c," "g," "h," or "x." When SS-55 times out, it switches SS-56 to its ON state. When SS-56 is in its ON state, a signal is applied through line 1104 to AND gate 972. The other input to AND gate 972 is the not-blank line 970 from inverted 968. If the "s" is not a final "s," the "e" should be counted as a vowel group. Therefore, output line 1106 from AND gate 972 is connected through OR gate 1024 and line 1022 to increment vowel counter 1018.

When SS-56 times out, a signal is applied through line 1108 to one input of AND gates 1052, 965 and 974. 75

If there is a count of two in number-of-vowel-group counter 1018 at this time, the resulting signal on line 1028 fully conditions AND gate 1052 to generate an output signal on line 1076, which is transmitted through OR gates 1072 and 1142 to proceed-to-next step line 336. If, at this time, there is a count of less than two in vowel-group counter 1018, line 1026 is applying a second input to AND gate 974. The third input to this AND gate is not blank line 970 from inverter 968, which line has a signal on it if the character following the "s" is not a blank (i.e. if the "s" is not the last letter of the word). When AND gate 974 is fully conditioned, it generates an output signal on line 1112 which causes SS-52 to be switched to its ON state. This results in a determination being made as to whether the character following the "s" should be counted as a vowel group. Finally, if the character following the "s" is a blank and there is a count of less than two in counter 1018, signals on lines 921 and 1026 fully condition AND gate 965 to generate an output signal on line 1110, which signal is applied to switch SS-57 to its ON state.

From FIG. 2 it is seen that if the "s" is the final letter of the word, it is necessary to look back three characters to see if the character preceding the "e" is an "s," "c," "g," "h," or "x." When SS-57 is in its ON state, a signal is applied to line 618 to decrement output-control ring 612 one position. When SS-57 times out, SS-58 is switched to its ON state. SS-58 being in its ON state causes a second signal to be applied to line 618 to decrement output-control ring 612 a second position. When SS-58 times out, it switches SS-59 to its ON state. SS-59 being in its ON state causes a third signal to be applied to line 618 to decrement output-control ring 612 to the desired position. When SS-59 times out, it causes SS-60 to be switched to its ON state. SS-60 being in its ON state causes a signal to be applied through line 1114 to one input of AND gate 1002. The other input to AND gate 1002 is output line 1000 from OR gate 938. The inputs to OR gate 938 are the "c," "g," "h," "s," and "x" output lines from decoder 632. If the character then applied to decoder 632 is one of these characters, AND gate 1002 generates an output signal on line 1116 which is applied through OR gate 1024 and line 1022 to increment number-of-vowel counter 1018. When SS-60 times out, a signal is applied through line 1118 to one input of AND gates 1034 and 1050. If counter 1018 has a count of two in it as this time, line 1028 applies a second input to AND gate 1050, causing an output signal on line 1078, which is applied through OR gates 1072 and 1142 to proceed-to-next-step output line 336. If, on the other hand, there is a count of less than two in counter 1018, the resulting signal on line 1026 fully conditions AND gate 1034. Since all characters in the word have been looked at at this time, if there is still a count of less than two in counter 1018, it means that the word is not hyphenable. Therefore, output line 1120 from AND gate 1034 is connected through OR gate 1066 to not-hyphenable-output line 334.

Returning now to the time when SS-54 times out, if the character following the "e" is a blank (i.e. if the "e" is the last letter of the word), a second conditioning signal is applied to AND gate 964 by line 921. If there is a count of less than two in counter 1018, a third conditioning input is applied to this AND gate by line 1026. AND gate 964 being fully conditioned causes an output signal on line 1098 which is applied to switch SS-71 to its ON state. Referring to FIG. 2, it is seen that when a blank follows the "e," the next step is to look back two characters to see if this character is an "I". When SS-71 is in its ON state, a signal is applied to line 618 to decrement output-control ring 612 one position. When SS-72 times out, SS-72 is switched to its ON state. When SS-72 is in its ON state, a second signal is applied to line 618 to cause output-control ring 612 to be decremented to the desired letter position. When SS-72 times out, a sig-

nal is applied through line 1146 to one input of AND gates 950 and 956. From FIG. 2 it is seen that if the character two positions preceding the "e" is not an "l," the "e" is not counted as a vowel group and, since this is the last letter of the word and there is a count of less than two in vowel-group counter 1018 at this time, the word is not hyphenable. Therefore, output line 1150 from AND gate 956, which gate is fully conditioned if the character being looked at is not an "l," is connected through OR gate 1066 to not-hyphenable line 334. If there is a signal on line 913 at this time indicating that the character being applied to decoder 632 is an "l," AND gate 950 is fully conditioned to generate an output signal on line 1148 which causes SS-73 to be switched to its ON state.

It is now desired to look at the character preceding the "l" to determine if it is a stop character. Therefore, when SS-73 is in its ON state, a signal is applied to line 618 to decrement output-control ring 612 one position. When SS-73 times out, it causes SS-74 to be switched to its ON state. When SS-74 is in its ON state, a signal is applied through line 1152 to one input of AND gate 1010 (FIG. 5J). The other input to AND gate 1010 is output line 1008 from OR gate 936, the inputs to this OR gate being the lines 903, 905, 907, 910, 912, 915 and 917 from decoder 632 for the stop characters "b," "d," "g," "j," "k," "p," and "t" respectively. Output line 1154 from AND gate 1010 is connected through OR gate 1024 and line 1022 to increment counter 1018 one position. When SS-74 times out, a signal is applied through line 1156 to AND gates 1032 and 1044, the other inputs to these AND gates being not-equal-to-two line 1026 and equal-to-two line 1028 respectively. For reasons previously indicated, output line 1158 from AND gate 1032 is connected through OR gate 1066 to not-hyphenable line 334, and output line 1160 from AND gate 1044 is connected through OR gate 1142 to proceed to next-step-output line 336.

Returning now to the time at which SS-52 times out, there is one possible condition which has yet not been discussed. Line 1060, to which a signal is applied at this time, is also connected as one input to AND gate 962 (FIG. 5G), the other inputs to this AND gate being blank line 921 from decoder 632 and not-equal-to-two line 1026 from counter 1018. If AND gate 962 is fully conditioned, it means that the end of the word has been reached without having found two vowel groups. Therefore, according to criteria previously specified, the word is not hyphenable. Output line 1064 from AND gate 962 is therefore connected through OR gate 1066 to not-hyphenable line 334.

STEP 210 TO DETERMINE IF WORD IS IN TABLE OF MOST FREQUENT ERRORS

Since the word "Mercantile," which is being investigated for this example, has three vowel groups according to the criteria previously stated, an output signal will ultimately be derived on line 336 to cause the circuit to switch SS-115 to its ON state. When SS-115 is in its ON state, a signal is applied to line 668 (FIG. 5A) to (a) condition gates 660 to apply the word stored in input-buffer register 302 to argument register 340; (b) reset the match indicators in the control portion of associative memory 338 to the match side; and (c) set flip-flop 670 to its OFF state. As indicated previously, the argument portion 341 of associative memory 338 contains the words which would be improperly hyphenated if it were attempted to hyphenate them in accordance with the probability scheme of this invention, and function portion 342 of this memory contains the proper hyphenation patterns for these words.

When SS-115 times out, a signal is applied to switch SS-116 to its ON state. When SS-116 is in its ON state, a signal is applied to line 666 to cause the word stored in argument register 340 to be associated with the words

stored in argument portion 341 of associative memory 338. As mismatches are detected during this associate operation, the match indicators for these entries are reset to their mismatch side. The match indicator for a matched entry is left on its match side. When SS-116 times out, it applies a signal to switch SS-117 to its ON state.

When SS-117 is in its ON state, a test signal is applied to line 672. If a match has been had during the associate operation, this signal causes the appropriate entry in function portion 342 to be read out through lines 344 into output register 346 (FIG. 5L). If no match was found during the associate operation, the signal applied to line 672 passes through the control circuit to line 674 to switch flip-flop 670 to its ON side. When SS-117 times out, a signal is applied through line 680 to one input of AND gates 350 and 354. If a match was found during the associate operation, flip-flop 670 is still in its OFF state, causing an output signal to appear on line 676, which fully conditions AND gates 350 to generate an output signal on line 348. An output signal on line 348 means that the desired hyphenation pattern has been found and that the circuit has reached the end of its operation. If no match was found during the associate operation, flip-flop 670 is switched to its ON state and an output signal appears on line 678. AND gate 354 is therefore fully conditioned at this time to generate an output signal on line 352 which switches SS-0 to its ON state. The switching of SS-0 to its ON state causes the circuit to start performing step 212 (FIG. 1) of the operation.

30 FORM SYLLABLE PATTERNS (STEP 212, FIG. 1)

Since the word "Mercantile" is hyphenable in accordance with the teachings of this invention, it is not found in associative memory 338, and the circuit proceeds to step 212 (FIG. 1) to form syllable patterns. When SS-0 is in its ON state, a signal is applied to line 750 to reset next-character-number counter 748 (FIG. 5D) to a count of one, a signal is applied to line 768 to reset *l/w* counter 312 (FIG. 5C) to a count of one, a signal is applied to line 616 to reset output-control ring 612 (FIG. 5A) to its first position, a signal is applied to line 706 to reset argument-input-control ring 704 (FIG. 5B) to its first position, a signal is applied to line 1220 to condition gates 1218 (FIG. 5D) to transfer the address stored in starting-point register 1208 into table-address counter (TAC) 386, and a signal is applied to line 1260 to condition gates 1258 to transfer the address in supplementary-starting-point register 1210 into supplementary-address counter 392.

When SS-0 times out, a signal is applied to switch SS-0a to its ON state. Since some syllables may only begin a word and other syllables may only end a word, it is necessary that there be some indication as to the beginning and the end of the word in argument register 360. For this reason, an asterisk (*) is inserted in the argument register at the beginning of the word and at the end of the word. Therefore, when SS-0a is in its ON state, a signal is applied to line 696 (FIG. 5B) to condition gates 690 to pass the code representing an asterisk (*) through OR gates 686 and coder 358 to the position in argument register 360 indicated by input-control ring 704. Since input-control ring 704 was just set to its first position, this is the position in which the asterisk is stored. When SS-0a times out, a signal is applied to switch SS-0b to its ON state. Since a character has been stored in the first position of argument register 360, it is now necessary to step input-control ring 704 so that the first character of the word applied to the argument register will be stored in the next position. This is accomplished by applying a signal to increment-line 708 when SS-0b is in its ON state. When SS-0b times out, a signal is applied to switch SS-1 to its ON state.

Having performed the preliminary steps indicated above, the circuit is now ready to perform step 220 indicated in FIG. 3A. When SS-1 is in its ON state, a signal is applied to line 682 (FIG. 5B) to gate the character in input-buffer register 302, indicated by output control ring

612, in this case the first character of the word, through gates 630, lines 684, OR gates 686, line 698, coder 358, and lines 700 into the position in argument register 360 indicated by input-control ring 704. For the first letter of the word "Mercantile," it is seen from FIG. 8 that the coder would cause the character "N" to be stored in the second position in argument register 360. When SS-1 is in its ON state, the following operations are also performed: (a) a signal is applied to line 714 (FIG. 5B) to set all the match indicators in associative memory 362 to their match state and to reset match-flip-flop 716 to its OFF state. (b) A signal is applied to line 752 to step next-character-number counter 748 (FIG. 5D) plus 1. (c) A signal is applied to line 860 which signal is passed through OR gates 856 and line 858 to increment l/w counter 312 (FIG. 5C) by one. The last two operations stated above have the effect of causing next-character counter 748 to contain the number of the character following the last character applied to argument register 360 and of causing l/w counter 312 to indicate a number of characters one greater than that applied to argument register 360. The significance of these two facts will become apparent later. When SS-1 times out, it causes SS-1a to be switched to its ON state.

Referring to FIG. 8, it is seen that the coded character "V" is used for an "e," and the coded character "T" for a "g," except when these characters appear at the end of a word. When these characters appear at the end of a word, an "e" is recorded as an "E" and a "g" as a "G." Since, when a character is applied to coder 358, there is no way of determining whether it is a final character or not, the operations to be described now are required to be sure that the proper entry is made for an "e" or a "g" in a word. When SS-1a is in its ON state, a signal is applied to line 620 to increment output-control ring 612 (FIG. 5A) one position. The resulting output on a line 622 is applied through OR gate 330 and lines 332 to blank decoder 628 (FIG. 5B). If the character is a blank, indicating that the preceding character is the end of the word, blank decoder 628 generates an output signal on line 636 which is converted into a pulse by capacitor 638 to flip end-of-word flip-flop 640 to its ON state. When SS-1a times out, a signal is applied through line 658 to one input of AND gates 648 and 656. If the character just looked at is not a blank, as would be the case after the first letter of the word "Mercantile" is transferred into argument register 360, end-of-word flip-flop 640 is still in its OFF state at this time, causing a signal to be applied through line 652 to the other input of AND gate 656. The resulting output signal on line 661 is applied to switch SS-2 to its ON state. This will cause an associate operation to be performed in a manner to be described presently.

However, in order to complete the description of the loading phase of the operation at this point, assume that the operation has reached a point where the final "e" of the word "Mercantile" has been transferred into argument register 360. Since it has not yet been determined that this is the last letter of the word, this "e" is stored in argument register 360 as the coded character "V." Now, during CL-1a a blank character is applied to blank decoder 628, and end-of-word flip-flop 640 is switched to its ON state. Therefore, when SS-1a times out, flip-flop 640 is applying a signal to line 644 to fully condition AND gate 648. The resulting output signal on line 659 causes SS-1b to be switched to its ON state.

When SS-1b is in its ON state, a signal is applied to line 618 to decrement output-control ring 612 to the position of the last letter in the word, in this case the "e." When SS-1b times out, a signal is applied to switch SS-1c to its ON state. When SS-1c is in its ON state, a signal is again applied to line 682 to condition gates 630 to apply this last character through OR gate 686 and coder 358 to the appropriate position in argument register 360. However, at this time, end-of-word flip-flop 640 is still

in its ON state, causing a signal to be applied through line 644 to coder 358. The coder is therefore advised of the fact that this is the final "e" of a word and stores the coded character "E" rather than the coded character "V" in argument register 360. If the final letter of the word is a character other than "e" or a "g," the signal on line 644 has no effect on the coder, and the same character is stored in the argument register as would otherwise be stored. When SS-1c times out, a signal is applied to switch SS-1d to its ON state. When SS-1d is in its ON state, a signal is applied to increment input-control ring 704 for argument register 360 to condition the position following that in which the last character for the word is stored. When SS-1d times out, a signal is applied to switch SS-1e to its ON state. When SS-1e is in its ON state, a signal is applied to line 696 to condition gates 690 to pass the code for the asterisk (*) from code generator 694 through lines 688, OR gates 686, lines 698, coder 358, and lines 700 to the position in argument register 360 indicated by input-control ring 704, in this case to the position following that in which the last letter of the word is stored. In this way, the required asterisk (*) is stored at the end of the word. When SS-1e times out, a signal is applied to switch SS-2 to its ON state.

When SS-2 is switched to its ON state, either by a signal on line 661 when the last character read into argument register 360 is not the last letter of the word, or by SS-1e timing out when the last character read into argument register 360 is the last character of a word, a signal is applied to line 712 (FIG. 5B) to cause an association to be made between the syllable stored in argument register 360 and the acceptable syllables stored in associative memory 362. If no acceptable syllable is found, then all of the match indicators in the control portion of associative memory 362 are reset. If a match is found, the match indicator for that entry is left set. When SS-2 times out, a signal is applied to switch SS-3 to its ON state.

When SS-3 is in its ON state, a signal is applied to line 718 to test the match indicators in the control portion of associative memory 362. If there has been a failure to achieve a match, as would be the case, for example, when only the asterisk (*) and the "N" for the word "Mercantile" are in argument register 360, the signal applied to line 718 passes through the control circuit to line 720 to set match flip-flop 716 to its ON state. When this occurs, a signal is applied to output line 726 which partially conditions AND gates 650, 728 and 730. When SS-3 times out, a signal is applied through line 732 to a second input of these AND gates. When only the asterisk (*) and the "N" are in argument register 360, l/w counter 312 has a count of only two therein, and decoder 780 is therefore generating an output signal on not-equal-to-seven line 790, which fully conditions AND gate 730 to generate an output signal on line 404, which switches SS-0b to its ON state. From previous discussion, it will be remembered (referring to the chart in the appendix) that when SS-0b is in its ON state, the operation of reading a new character into argument register 360 is commenced. It can be seen that during succeeding time intervals, the l/w counter and the next-character-number counter are each incremented, and an association is performed to see if the letters now in argument register 360 form a possible syllable.

From FIG. 6, it is seen that "NV" (i.e. the reduced character set for the first two letters of the word "Mercantile") is a possible syllable. Therefore, during clock-time two (CL-2) when an association is made on this possible syllable, a match is indicated, and a match circuit in associative memory 362 is left in its match state. During CL-3 when a test signal is applied to line 718, a match condition is now found, causing the syllable and its associated frequency to be read out of associative memory 362 through lines 370 into the syllable and frequency fields of memory-buffer register (MBR) 368 (FIG. 5F). The detection of a match also causes a signal to be applied

through line 742 to AND gate 657. Since end-of-word-flip-flop 640 is in its OFF state at this time, there is a signal on line 652 which fully conditions AND gate 657 to generate a signal on line 743 which conditions gates 744 to apply the next-character number now stored in next-character-number counter 748 (FIG. 5D) through gates 744 and lines 754, OR gates 756 (FIG. 5F), and lines 758 to the next-character-number field of MBR 368. Since counter 748 is always incremented to contain the number of the character following the last character which was applied to argument register 360, the number 3 is read at this time into the next-character-number field. When SS-3 times out, the signal applied to line 732 now finds AND gate 724 (FIG. 5B) conditioned by a signal applied to output line 722 from the OFF side of match flip-flop 716. The resulting output signal on line 734 is applied to switch SS-20 to its ON state. As will be seen presently, SS-20 being in its ON state causes the entry which was just made into MBR 368 to be stored in the table in core storage 364. However, before describing this particular operation, the other possible conditions which may exist when SS-3 times out will be investigated.

As was indicated previously, *l/w* counter 312 (FIG. 5C) always contains a count one greater than the number of characters in argument register 360. Therefore, when a six-letter syllable has been stored in argument register 360, it having previously been decided that syllables in excess of six letters will not be considered, *l/w* counter 312 has a count of seven in it. When there is a count of seven in *l/w* counter 312, decoder 780 generates an output signal on equal-to-seven line 782. This line is connected as one of the conditioning inputs to AND gate 728 (FIG. 5B), the other conditioning inputs to this AND gate being 3_T line 732 and no-match line 726 from flip-flop 716. This means that when there is no match but a six-letter syllable is in argument register 360, AND gate 728 generates an output signal on line 738 which is applied through OR gate 740 to line 406 to switch SS-4 to its ON state. A similar situation exists when there is a no-match indication on line 726 from flip-flop 716 and an end-of-word indication on output line 644 from end-of-word-flip-flop 640. Under these conditions, AND gate 650 is fully conditioned when a signal is applied to 3_T line 732, causing an output signal on line 736 which is applied through OR gate 740 to line 406 to switch SS-4 to its ON state. It will be remembered from previous discussion and by reference to the flow chart of FIG. 3A that under either of the conditions indicated above, a sequence of operations is commenced to find a new letter at which to start looking for possible syllables. The functions which are performed when SS-4 is switched to its ON state will be described later.

As indicated previously, when an acceptable syllable pattern is found in associative memory 362, the syllable, its relative frequency, and the appropriate next-character number from next-character-number counter 748 are stored in the proper fields in memory-buffer register 368 (FIG. 5F). AND gate 724 (FIG. 5B) is then caused to generate an output signal on line 734 which switches SS-20 to its ON state. The switching of SS-20 to its ON state causes step 222, the create table-entry step, of FIG. 3A to commence. When SS-20 is in its ON state, a signal is applied to line 1228 (FIG. 5D) to increment table-address counter 386 by one. Since the number originally stored in starting-point register 1208 and previously transferred to TAC 386 is one less than the first address position of the table in core storage 364, the incrementing of TAC during CL-20 brings the first address in the table into TAC. When CL-20 is in its ON state, a signal is also applied through line 1338 (FIG. 5E) to one input of AND gates 651 and 786. If end-of-word-flip-flop 640 is in its ON state, the resulting signal on line 644 is applied to fully condition AND gate 651. If the count in *l/w* counter 312 is equal to seven, a signal is applied through line 782 to condition the other input to AND gate 786. It

can be seen that when either of these conditions occur, this will be the last entry in the table starting with the particular letter in question. Therefore, output lines 1334 and 1332 from AND gates 651 and 786 respectively are connected through OR gate 1328 to condition gates 378 to store a one from character generator 380 in the level-termination field of MBR 368.

When SS-20 times out, a signal is applied to switch SS-21 to its ON state. When SS-21 is in its ON state, a signal is applied to line 1236 (FIG. 5D) to condition gates 1232 to apply the address in TAC 386 to MAR 372, and to condition gates 1452 to pass the address in MAR into previous address register (PAR) 390. Delay 1472 prevents the new address from being read from TAC into MAR while the previous address in MAR is being read into PAR. When SS-21 is in its ON state, a signal is also applied to line 1306 (FIG. 5F) to switch memory-status-flip-flop 1304 to its OFF or write state. When CL-21 switches from its ON to its OFF state, a signal is applied to switch SS-22 to its ON state. When SS-22 is in its ON state, a signal is applied to line 1302 to cause a memory cycle of core storage 364. Since memory-status-flip-flop 1304 is in its write state, this causes the syllable, frequency and next-character-number information stored in MBR 368 to be recorded in core storage 364 at the address indicated in MAR 372. For the first syllable of the word, this storage is made at the address 100. Also, at this time, a signal is applied to line 826 (FIG. 5A) to cause table-entered-flip-flop 408 to be switched to its ON state. This means that a table entry has been made starting with the first letter contained in argument register 360.

As indicated previously, used-flip-flop 374 (FIG. 5B) is switched to its ON state when a complete set of entries has been made starting with a particular letter and the circuit is seeking a new letter to start looking for possible syllables at. Therefore, when only the first syllable has been entered into the table in core storage 364, used flip-flop 374 is in its reset or OFF state. At this time, there is also a signal on line 790 indicating that the count in *l/w* counter 312 (FIG. 5C) is less than seven. Therefore, when a signal is applied to line 814 (FIG. 5B) when SS-22 times out, it finds AND gate 792 of gating circuit 376 fully conditioned, causing an output signal on line 382 which switches SS-0b to its ON state. From the appendix and from the flow diagram of FIG. 3A, it will be seen that the switching of SS-0b to its ON state causes the circuit to apply an additional character to argument register 360 in an attempt to find additional possible syllables starting with the first letter of the word.

Referring to FIG. 6, a table entry is made at address 100 for the syllable "NV," and an entry is made at address 101 for the syllable "NVL." Attempts to find additional possible syllables starting with the first letter of the word are unsuccessful. When six characters have been entered into argument register 360 and a mismatch indication occurs; line 782 from decoder 780 is supplying a conditioning input to AND gate 728 (FIG. 5B), and match flip-flop 716 is applying a second conditioning input to this AND gate through line 726. Therefore, when SS-3 times out applying a signal to line 732, AND gate 728 generates an output signal on line 738 which is applied through OR gate 740 to switch SS-4 to its ON state.

When SS-4 is in its ON state, a signal is applied through line 1340 (FIG. 5E) to one input of AND gate 822. Since table-entered-flip-flop 408 is in its ON state (this flip-flop was switched to its ON state when the table entry was made for the possible syllable "NV"), a signal appears on on-side-output line 818 to fully condition AND gate 822, causing an output signal on line 1336 which is applied through OR gate 1328 to condition gates 378 to apply a numeral one from generator 386 to the level-termination-mark field of MBR 368. When SS-4 times out, a signal is applied through line 828 (FIG. 5A) to one input of AND gates 812 and 820 in gating-circuit 410. Since the table-entered-flip-flop is in its ON state, a signal is applied

through line 818 to fully condition AND gate 820, causing an output signal on line 412 which switches SS-31 to its ON state. When SS-31 is in its ON state, a signal is applied to line 1302 to cause a memory cycle to be performed. It will be remembered that memory-status-flip-flop 1304 was switched to its write state when the table entry was made. There has been no signal since then to switch it to its read state. Therefore, the memory cycle during CL-31 time is a write cycle causing the level-termination mark which was read into the level-termination field of MBR 368 during CL-4 time to be stored in the appropriate field position of the last table entry, in this case the table entry for the possible syllable "NVL" at address 101 (see FIG. 6). When SS-31 times out, a signal is applied through line 794 (FIG. 5B) to the AND gates in gating-circuit 396. Since a count of seven is in *l/w* counter 312 at this time, decoder 780 generates an output signal on line 782 which fully conditions AND gate 788 to generate an output signal on line 798 which is applied through OR gate 800 to line 398 to switch SS-32 to its ON state.

From FIG. 3A, it is seen that it is now desired to find the next letter with which possible syllables may begin. As a first step in this operation, when SS-32 is in its ON state, a signal is applied to line 1308 (FIG. 5F) to set memory-status flip-flop 1304 to its OFF or read state. A signal is also applied to line 1290 (FIG. 5D) to condition gates 1196 to pass the address in next-character-address counter 420 through OR gates 1206 and delay 1472 to MAR 372. It will be remembered that the address of the first position in the table of FIG. 6, in this case the address 100, was initially stored in address counter 420. Therefore, this is the address which is now applied to MAR. It is noted that the signal on line 1200 also causes the address which was in MAR to be read into PAR 390. When SS-32 times out, a signal is applied to switch SS-33 to its ON state. When SS-33 is in its ON state, a signal is applied to line 1302 to cause a memory cycle, in this case to cause the entry at the first position in the table of FIG. 6 to be read into MBR 368. When SS-33 times out, it causes SS-33a to be switched to its ON state. Nothing occurs, during the time that SS-33a is in its ON state. However, when 33a times out, a signal is applied through line 1380 (FIG. 5F) to one input of AND gates 1374 and 1378. It will be remembered that if the next-character-number field of an entry is blank, this means that this entry contains a possible last syllable for the word. At the present stage of the operation, however, entry 100 is the one which is in MBR 368, and the next-character-number field of this entry contains the character 3. Therefore, blank decoder 422 finds the contents of the next-character-number field not equal to a blank and generates an output signal on line 1376 which fully conditions AND gate 1378 to generate an output signal on line 430, which is applied to switch SS-33c to its ON state.

When SS-33c is in its ON state, a signal is applied to line 1350 (FIG. 5F) to condition gates 1348 to apply the character in next-character-number field of MBR 368 to next-character-number register 394. When SS-33c times out, a signal is applied to switch SS-33d to its ON state. When SS-33d is in its ON state, a signal is applied to line 1276 (FIG. 5D) to condition gates 1274 to apply the contents of supplementary-address counter 392 to register 446. When SS-33d times out, a signal is applied to switch SS-33e to its ON state. When SS-33e is in its ON state, a signal is applied to line 1260 to condition gates 1258 to pass the contents of supplementary-starting-point register 1210 into supplementary-address counter 392. When SS-33e times out, a signal is applied to switch SS-33f to its ON state. When SS-33f is in its ON state, a signal is applied to line 1298 to condition gates 1272 to apply the address in supplementary-address counter 92 to MAR 372 and to condition gates 1452 to apply the address which was in MAR to PAR 390. A signal is also applied to line 1308 (FIG. 5F) at this time to switch

memory-status-flip-flop 1304 to its OFF or read state. When SS-33f times out, a signal is applied to switch SS-33g to its ON state. When SS-33g is in its ON state, a signal is applied to line 1302 to cause a memory cycle to be performed, in this case to cause the contents of the first address in the supplementary table to be read out into MBR 368. When SS-33g times out, a signal is applied to switch SS-33h to its ON state. Nothing occurs during CL-33h time. However, when SS-33h times out, a signal is applied through line 1370 (FIG. 5F) to condition AND gates 1364 and 1368. The other inputs to these AND gates are the outputs from compare-circuit 442 which circuit is comparing the next-character-number which was stored in next-character-number register 394 with the next-character number in the next-character-number field of memory buffer register 368, this number being the next-character number in the first entry of the supplementary table. The purpose of this operation is to determine whether a search has previously been made starting with the character represented by this next-character number. It will be remembered that if such a search has been made, then there is no need to repeat it, and the proper chain address may be read into the table entry which gave rise to this next-character number. However, in this case, there has been no entry into the supplementary table so that compare-circuit 442 generates an output signal on not-equal line 1366, fully conditioning AND gate 1368 to generate an output signal on line 454. A signal on line 454 is applied to switch SS-33o to its ON state.

Nothing occurs in the circuit during CL-33o time. However, when SS-33o times out, a signal is applied through line 1296 (FIG. 5D) to one input of AND gates 1290 and 1294. The other inputs to AND gates 1290 and 1294 are the outputs from compare-circuit 448, which circuit is comparing the address which was in SAC (i.e. the address at which the last entry was made in the supplementary table) with the address presently in SAC. Since, at the present stage of the operation, both of these registers contain the address 500, compare-circuit 448 generates an output signal on equal line 1288, fully conditioning AND gate 1290 to generate an output signal on line 458, which signal is applied to switch SS-33q to its ON state.

The circuit is now ready to determine the starting point for the next syllable string, to perform step 242 of FIG. 3A. When SS-33q is in its ON state, a signal is again applied to line 1290 (FIG. 5D) to condition gates 1196 to apply the address in next-character-address counter 420 to MAR 372. The address 100 is therefore stored in MAR 372. When SS-33q times out, a signal is applied to switch SS-33r to its ON state. When SS-33r is in its ON state, a signal is applied to line 1192 to increment next-character-address counter 420 one position. During CL-33r time a signal is also applied to line 1308 (FIG. 5F) to switch memory-status flip-flop 1304 to its read state. When SS-33r times out, a signal is applied to switch SS-33s to its ON state. When SS-33s is in its ON state, a signal is applied to line 1302 to cause a memory cycle during which the entry at address 100 is read into MBR 368. When SS-33s times out, a signal is applied to switch SS-33t to its ON state. When SS-33t is in its ON state, a signal is applied to line 824 (FIG. 5A) to reset table entered flip-flop 408 to its OFF state, a signal is applied to line 806 (FIG. 5B) to set used flip-flop 374 to its ON state, a signal is applied to line 642 to set used flip-flop state, a signal is applied to line 642 to reset end-of-word flip-flop 640 to its OFF state (in this example it still is in its OFF state and this acts as a mere perfunctory one) and a signal is applied to line 774 (FIG. 5F) to condition gates 772 to apply the contents of the next-character-number field in MBR 368 through lines 770 to *l/w* counter 312 (FIG. 5C). It should be noted that in this instance the *l/w* counter is merely being used as a register and not as a *l/w* counter. When SS-33t times

out, a signal is applied to switch SS-33w to its ON state. When SS-33w is in its ON state, a signal is applied to line 616 to reset output-control ring 612 to its first position, and a signal is applied to line 750 (FIG. 5D) to reset next-character-number counter 748 to a count of one. These are preliminary steps to the setting of the output-control ring to the position indicated by the next-character number which is now stored in l/w counter 312.

When SS-33w times out, a signal is applied to switch SS-33x to its ON state. When SS-33x is in its ON state, a signal is applied to line 752 (FIG. 5D) to increment next-character-number counter 748, and a signal is applied to line 620 (FIG. 5A) to increment output-control ring 612 one position. When SS-33x times out, a signal is applied to switch SS-33x to its ON state. When SS-33y is in its ON state, a signal is applied to line 776 to decrement l/w counter 312 one position. When SS-33y times out, a signal is applied through line 842 (FIG. 5C) to AND gates 836 and 840. Since the count originally in l/w counter 312 was 3, decrementing it a single time drops this count to only 2. Therefore, there is no signal on line 833 from decoder 780 at this time, and inverter 838 applies a signal to AND gate 840 to fully condition this AND gate, causing an output signal on line 846 which switches SS-33x to its ON state.

The incrementing of the output-control ring and the next-character-number counter, and the decrementing of the l/w counter continue until the l/w counter has been decremented to a count of one. When this occurs, the output-control ring and the next-character-number counter will have been incremented to the desired position. At this time, when SS-33y times out, there is a signal on line 833 fully conditioning AND gate 836 to generate an output signal on line 844 which switches SS-33z to its ON state. When SS-33z is in its ON state, a signal is applied to line 710 (FIG. 5B) to reset argument register 360, and a signal is applied to line 706 to reset argument-input-control ring 704 to its first position. When SS-33z times out, a signal is applied to switch SS-1 to its ON state. The circuit is now ready to look for possible syllables starting with the third character of the word, in this case the reduced character set letter "L."

As may be seen from FIG. 6, there are no possible syllables beginning with this letter. Therefore, successive letters are applied to argument register 360 and successive attempts made to match until six characters have been read into argument register 360. When SS-2 times out at this time, the signal applied to line 732 again finds AND gate 728 (FIG. 5B) fully conditioned causing an output signal on line 406 which switches SS-4 to its ON state. Since no table entry was made starting with this letter, table-entered flip-flop 408 is still in its reset condition, and AND gate 822 (5E) is therefore not conditioned. No operations are therefore performed during CL-4 time. When SS-4 times out, the signal applied to line 828 (FIG. 5A) now finds AND gate 812 fully conditioned, causing an output signal on line 414 which switches SS-5 to its ON state. It should be noted that output line 808 from the ON side of used flip-flop 374 is also a conditioning input to AND gate 812. However, if the table-entered flip-flop is in its OFF state, the used flip-flop should always be on its ON state. The reason for this is that the only situation when the used flip-flop is in its OFF state during CL-4 time is when possible first syllables of the word are being looked for, and, if the word is to be hyphenable at all, it must have at least one possible first syllable, and the tabel-entered flip-flop will be in its ON state.

At this point, the circuit is performing step 232 of FIG. 3A. When SS-5 is in its ON state, a signal is applied to line 1394 (FIG. 5E) to condition gates 418 to route the zero signal from generator 416 into the chain-address field of MBR 368. A signal is also applied to line 1306 (FIG. 5F) to switch memory-status-flip-flop 1304

to its write mode. When SS-5 times out, a signal is applied to switch SS-6 to its ON state. When SS-6 is in its ON state, a signal is applied to line 1302 to cause a memory cycle to be performed. In this instance during the memory cycle, the "O" stored in the chain-address field of MBR is written into the entry whose address is in MAR 372 at that time. In this case, this is the entry 100. When SS-6 times out, a signal is applied to switch SS-7 to its ON state.

At this time, the operation of making the appropriate supplementary-table entry is commenced. When SS-7 is in its ON state, a signal is applied to line 1314 (FIG. 5F) to reset MBR 368. When SS-7 times out, a signal is applied to switch SS-8 to its ON state. When SS-8 is in its ON state, a signal is again applied to line 1394 to condition gates 418 to apply to the "0" code to the chain address field of MBR 368. When SS-8 times out, a signal is applied to switch SS-29 to its ON state. When SS-29 is in its ON state, a signal is applied to line 1358 (FIG. 5F) to apply the next-character number stored in next-character-number register 394 to the next-character-number field of MBR 368. When SS-29 times out, a signal is applied to switch SS-30 to its ON state. When SS-30 is in its ON state, a signal is applied to line 1298 (FIG. 5D) to condition gates 1272 to apply the address in supplementary-address counter 392 to MAR. The address in MAR is also stored in PAR during this time. The address at which the next supplementary-table entry is to be made, in this case the address 500, is in this way read into MAR. When SS-30 times out, a signal is applied to switch SS-30a to its ON state. When SS-30a is in its ON state, a signal is applied to line 1268 to increment supplementary-address counter 392 by one. When SS-30a times out, a signal is applied to switch SS-31 to its ON state. When SS-31 is in its ON state, a signal is applied to line 1302 to cause a memory cycle, in this case to cause the supplementary-table entry which is stored in the next-character number and the chain-address fields of MBR 368 to be entered into the proper position in the supplementary table. When SS-31 times out, a signal is applied to line 794 (FIG. 5B), which, since there is a count of seven in l/w counter 312 at this time, finds AND gate 788 fully conditioned by the signal on line 782 to generate an output signal on line 798 which is applied through OR-gate 800 to line 398 to cause SS-32 to switch to its ON state. When SS-32 is switched to its ON state, the circuit proceeds to find the next character at which it may begin looking for possible syllables, in this case the fourth character which is contained in the next-character-number field of entry 101. As before, an unsuccessful check is made to see if this character is contained in the supplementary table before the circuit proceeds to find syllables starting with this letter.

Assume now that a match has been had on the syllable containing the reduced character set letters "CV" and that this syllable with its relative frequency and its next-character number have been stored in memory position 102 (see FIG. 6) of core storage 364 in a manner previously described. Under these conditions, when SS-22 times out, causing a signal to be applied to line 814 (FIG. 5B), used flip-flop 374 is in its ON state (having been set to its ON state during a preceding 33t time when a search was being made for a new character at which to begin looking for possible syllables) and AND gate 810 is therefore fully conditioned, causing an output signal on line 385 which switches SS-23 to its ON state. The step now being performed is step 224 in FIG. 3A, namely the writing of a chain address. Looking at CL-21 time in the appendix section, it is noted that when TAC was transferred to MAR in order to put the proper address in MAR at which to store the new table entry, the address which was in MAR, the address from which the next-character number which gave rise to the present search was derived, was transferred into PAR 390

(FIG. 5E). When SS-23 is in its ON state, a signal is applied through lines 1444 to gates 1448 to cause the address in PAR to be transferred into MAR 372. The signal on line 1444 also causes the address in MAR to be transferred to PAR. The effect of this is to restore the address from which the next-character number was derived to MAR. During CL-23 time, a signal is also applied to line 804 (FIG. 5B) to reset used-flip-flop 374 to its OFF state, and a signal is applied to line 1308 (FIG. 5F) to set memory-status-flip-flop 1304 to its OFF or read state. When SS-23 times out, a signal is applied to switch SS-24 to its ON state. When SS-24 is in its ON state, a signal is applied to line 1302 to cause a memory cycle to be performed, in this case to cause the entry at the address indicated by MAR, the entry at address 101, to be read into MBR 368. When SS-24 times out, a signal is applied to switch SS-25 to its ON state. When SS-25 is in its ON state, a signal is applied to line 1350 (FIG. 5F) to condition gates 1348 to read the next-character number in the next-character-number field of this entry into next-character-number register 394. As will be seen presently, this register will be used in forming the next supplementary-table-address entry to be made. During CL-25, a signal is also applied to line 1238 (FIG. 5D) to condition gates 1234 to apply the address in TAC 386 to the chain-address field of MBR 368. This address is the address at which the last entry was made in the table, in this case the address 102. Finally, during CL-25 time, a signal is applied to line 1306 to switch memory-status-flip-flop 1304 to its ON or write state. When SS-25 times out, a signal is applied to switch SS-26 to its ON state. When SS-26 is in its ON state, a signal is applied to line 1302 to cause a memory cycle to be performed, in this case to cause the entry at address 101 to be re-entered with the chain-address field now containing the address 102. When SS-26 times out, a signal is applied to switch SS-27 to its ON state.

The circuit is now ready to perform step 226 to make an appropriate supplementary table entry. When SS-27 is in its ON state, a signal is applied to line 1314 (FIG. 5F) to reset MBR 368 to a blank. When SS-27 times out, a signal is applied to switch SS-28 to its ON state. When SS-28 is in its ON state, a signal is again applied to line 1238 (FIG. 5D) to condition gates 1234 to apply the address in TAC 386, in this case the address 102, to the chain-address field of MBR. When SS-28 times out, a signal is applied to switch SS-29 to its ON state. When SS-29 is in its ON state, a signal is applied to line 1358 (FIG. 5F) to condition gates 1356 to pass the next-character number stored in next-character-number register 394 into the next-character-number field of MBR. The two entries thus made in MBR 368 combine to form the second entry in the supplementary table shown in FIG. 7. When SS-29 times out, a signal is applied to switch SS-30 to its ON state. When SS-30 is in its ON state, a signal is applied to line 1298 (FIG. 5D) to condition gates 1272 to apply the address in supplementary-address counter 392 to MAR 372 (and also to transfer the address in MAR to PAR). When SS-30 times out, a signal is applied to switch SS-30a to its ON state. When SS-30a is in its ON state, a signal is applied to line 1268 to step supplementary-address counter 392 by one. When SS-30a times out, a signal is applied to switch SS-31 to its ON state. When SS-31 is in its ON state, a signal is applied to line 1302 to cause a memory cycle during which the supplementary entry is stored in the supplementary table. When SS-31 times out, a signal is applied to line 794 (FIG. 5B). Since end-of-word flip-flop 640 is not in its ON state at this time and there is a count of less than seven in *l/w* counter 312, AND gate 654 of gating circuit 396 is fully conditioned at this time to generate an output signal on line 400, which is applied to switch SS-0b to its ON state. This causes additional

characters to be read into argument register 360 and additional possible syllables starting with the reduced character set letter "C" to be found in a manner previously described.

The circuit proceeds to store entries in the manner indicated above until the syllable having the reduced character set "TVLE" is applied to argument register 360. Since the "E" in this syllable is the final "E" of the word, during CL-1 time, end-of-word-flip-flop 640 is switched to its ON state in a manner previously described. Therefore, during CL-3 time when a test signal is applied to line 718 (FIG. 5B) the syllable and its frequency are applied through line 370 to the syllable and frequency fields in MBR 368, but the signal applied to line 742 finds AND-gate 657 deconditioned, there being no signal applied to line 652 by end-of-word-flip-flop 640, and the next-character-number field of MBR is therefore left blank. As indicated previously, a blank next-character-number field is interpreted to mean that the entry containing it is for the last syllable of a word. From this point on, the operations for this entry are the same as those previously described.

The circuit then proceeds to store the remaining entries in the table of FIG. 6 in a manner similar to that previously described.

After having written the entry at address 111 for the possible syllable "LE" and having found no further syllables starting with the letter "I," the circuits looks at the next-character-address field of entry 106 and seeks to find the possible syllables beginning with the character "e." The first attempt to do this during CL-3 time results in a mismatch and, since end-of-word-flip-flop 640 is in its ON state, when SS-3 times out, AND gate 650 (FIG. 5B) is fully conditioned, causing an output signal which switches SS-4 to its ON state. The circuit then proceeds to write a chain address of "0" at table 106 in a manner previously described to make a supplementary table entry for the next-character number 10, and to proceed to step 234 (FIG. 3A) to attempt to find a new next-character number. At this time, next-character-address counter 420 (FIG. 5D) contains the address 107, and during CL-32 and 33 time, the table entry at this address is read out into MBR 368 in a manner previously described. When SS-33 times out, a signal is applied to switch SS-33a to its ON state. When SS-33a times out, a signal is applied to line 1380 (FIG. 5F) to condition AND gates 1374 and 1378 of gating-circuit 426. Since the syllable at address 107 is the last syllable of a word, the next-character field of this entry is a blank, and blank decoder 422 therefore generates an output signal on line 1372 to fully condition AND gate 1374 to generate an output signal on line 428 which switches SS-33u to its ON state.

The circuit is now ready to perform step 238 of FIG. 3A. When SS-33u is in its ON state, a signal is applied through line 1388 (FIG. 5E) to condition gates 343 to store the code for the character 2 contained in generator 432 in the chain-address field of MBR 368. A signal is also applied to line 1306 to switch memory-status-flip-flop 1304 to its ON or write mode. When SS-33u times out, a signal is applied to switch SS-33u to its ON state. When SS-33v is in its ON state, a signal is applied to line 1302 to cause a memory cycle which stores the chain address of 2 at the address indicated in MAR, in this case at the address 107. At this time, TAC 386 contains the address at which the last table entry was made, in this case the address 111, and next-character-address counter 420 contains the address of the entry, the next-character-address field of which was just looked at. When these two registers contain the same count, the next-character-number field of all entries has been looked at and the circuit is ready to form syllable patterns. The contents of these two registers are applied to compare-circuit 1198 (FIG. 5D). Since they are not equal at this time, com-

pare-circuit 1198 generates an output signal on line 1250 which is applied as one input to AND gate 1252. When SS-33v times out, a signal is applied through line 1254 as the other input to AND gate 1252, causing an output signal on line 440, which switches SS-33b to its ON state. When SS-33b is in its ON state, a signal is applied to line 1192 to step next-character-address counter 420. This counter now contains the address 108. When SS-33b times out, a signal is applied to switch SS-32 to its ON state.

During clock times 32 and 33, the table entry stored at address 108 is read out into MBR 368. Since this entry contains the next-character number 9, when SS-33a times out, blank decoder 422 (FIG. 5F) is generating an output signal on line 1376 which conditions AND gate 1378 to generate an output signal on line 430 to switch SS-33c to its ON state. During CL-33c, 33d, 33e, 33f, and 33g, the next-character number 9 is stored in next-character-number register 394, and the first entry in the supplementary table is read into MBR 368, all in a manner previously described. Since the first entry in the supplementary table does not contain the next-character number 9, compare-circuit 442 (FIG. 5F) is generating an output signal on line 1366 when a signal is applied to line 1370 when SS-33h times out, causing AND gate 1368 to generate an output signal on line 454 which switches SS-33o to its ON state. As described previously, this causes the next entry in the supplementary table to be applied to MBR 368. The above operations are repeated until the sixth entry in the supplementary table is applied to MBR 368. The next-character-number field of this entry contains a 9, and compare-circuit 442 therefore generates an output signal on equal-line 1362 when SS-33h times out, causing AND gate 1364 to be fully conditioned to generate an output signal on line 452, which switches SS-33i to its ON state.

The circuit is now ready to perform the write-chain-address-incurrent-table-entry step 244 of FIG. 3A. When SS-33i is in its ON state, a signal is applied to line 1406 (FIG. 5E) to condition gates 1402 to pass the chain address then stored in MBR 368, in this case the chain address 111, into chain-address register 460. When SS-33i times out, a signal is applied to switch SS-33j to its ON state. When SS-33j is in its ON state, a signal is applied through line 1200 (FIG. 5D) to condition gates 1196 to apply the address in next-character-address counter 420, in this case the address 108, to MAR. When SS-33i times out, a signal is applied to switch SS-33j to its ON state. When SS-33k is in its ON state, a signal is applied to line 1302 to cause a memory cycle which results in the entry at the address indicated in MAR, the entry at address 108, to be read into MBR 368. When SS-33k times out, a signal is applied to switch SS-33l to its ON state. When SS-33l is in its ON state, a signal is applied through line 1400 (FIG. 5E) to condition gates 1396 to apply the chain address which was stored in chain-address register 460 to the chain-address field of MBR 368. During CL-33l time, a signal is also applied to line 1306 to switch memory-status-flip-flop 1304 to its ON or write mode. When SS-33l out, a signal is applied to switch SS-33m to its ON state. When SS-33m is in its ON state, a signal is again applied to line 1302 to cause a memory cycle which results in the entry in MBR, this entry including the chain address which was derived from the supplementary table, being read into address 108 in core storage 364. When SS-33m times out, a signal is applied to switch SS-33n to its ON state. When SS-33n is in its ON state, a signal is applied through line 1284 (FIG. 5D) to condition gates 1282 to apply the address in register 446 to supplementary-address counter 392. This step is necessary to restore SAC to the address of the last entry which was made in the supplementary table so that any additional entry in this table which may be required will be made in the proper position. When SS-33n times out, a signal is applied to switch SS-33b

to its ON state. As indicated previously, this causes a signal to be applied to line 1192 to increment next-character-address counter 420, in this case incrementing it to the address 109. When SS-33b times out, a signal is applied to switch SS-32 to its ON state, causing a new search to commence for a character at which new syllables may be formed.

Operations similar to those described above are performed when the next-character fields of entries 109 and 110 are looked at. When the next-character-number field of entry 111 is looked at, it is found to be blank, and SS-33u is switched to its ON state in a manner previously described. When SS-33u is in its ON state, a 2 is stored in the chain-address field of this entry in a manner previously described, and the circuit to proceed to clock time 33v. When SS-33v times out, a signal is applied through line 1254 (FIG. 5D) to AND gates 1248 and 1252. Since the next-character-number field of the last entry in the table is being looked at at this time, both next-character-address counter 420 and table-address counter 386 contain the same address, in this case the address 111, and compare circuit 1198 in compare-and-gating circuit 436 therefore generates an output signal on equals-line 1246 which fully conditions AND gate 1248 to generate an output signal on line 438, which causes SS-85 to be switched to its ON state.

The circuit has now completed the storing of possible syllables in the table in core storage 364 and is ready to form possible syllable patterns. When SS-85 is in its ON state, a signal is applied to line 1861 (FIG. 5R) to reset all of the number of syllable, syllable address, and ratio registers in word registers 488. A signal is also applied to line 1600 (FIG. 5M) to reset all the frequency registers 1601-160N in frequency registers 490, and to line 1798 (FIG. 5P) to reset word-select counter 528 to its first position. When SS-85 times out, a signal is applied to switch SS-85a to its ON state. When SS-85a is in its ON state, a signal is applied to line 1220 (FIG. 5D) to condition gates 1218 to apply the address in starting-point register 1208 to TAC 386, a signal is applied to line 1424 (FIG. 5E) to switch flip-flop 487 to its OFF state, a signal is applied to line 1530 (FIG. 5M) to reset column-select counter 508 to its first position, a signal is applied to line 1672 to reset number-of-syllables counter 1670 to a count of one, and a signal is applied to line 1758 to reset intermediate-store register 1736. When SS-85a times out, a signal is applied to switch SS-85b to its ON state. When SS-85b is in its ON state, a signal is applied to line 1228 (FIG. 5D) to step TAC 386 by one. This effectively puts the address of the first entry in the table of FIG. 6, the address 100, in TAC. When SS-85b times out, a signal is applied to switch SS-86 to its ON state. When SS-86 is in its ON state, a signal is applied to line 1236 to condition gates 1232 to transfer the address in TAC 386 to MAR 372. As with all other similar transfers, the address in MAR is transferred into PAR. This effectively sets the address 100 into MAR. During CL-86, a signal is also applied to line 1308 (FIG. 5F) to switch memory-status flip-flop 1304 to its OFF or read state. When SS-86 times out, a signal is applied to switch SS-87 to its ON state. When SS-87 is in its ON state, a signal is applied to memory-cycle line 1302 to cause the contents of the entry at the address indicated in MAR, in this case the entry at address 100, to be read into MBR 368. When SS-87 times out, a signal is applied to switch SS-87a to its ON state. When SS-87a is in its ON state, a signal is applied through line 1502 (FIG. 5D) to AND gate 1500. However, since there is no used-bit in the entry in MBR at this time, AND gate 1500 is not fully conditioned and no operations are performed during this clock time. When SS-87a times out, a signal is applied through line 1506 (FIG. 5F) to AND gates 1494 and 1498. Since the used-bit in MBR at this time is a 0, decoder 470 generates an output signal on line 1492, which fully conditions AND gate 1494 to generate an output signal on line 474, which switches

SS-88 to its ON state. The purpose of the operation just described is to determine if the entry being investigated has been used to form previous syllable patterns.

Referring to FIG. 3B, it is seen that a determination must now be made as to whether the entry has a chain address of 0 or not. If the entry has a chain address of 0, this means that there are no acceptable syllables which may start with the letter following its last letter and therefore that it itself is not an acceptable syllable for the word in question. When SS-88 is in its ON state, a signal is applied to line 1228 (FIG. 3D) to step TAC 386 by one. A signal is also applied through line 1432 (FIG. 5E) to one input of AND gates 485 and 1428. Since the entry at address 100 contains no level termination mark, there is no signal on line 1342 from zero-detector 512, and flip-flop 487 remains in its OFF state. The chain address of 0 in the entry at address 100 means that the other input to AND gate 1428 on line 1426 from zero-detector 480 is not present. Nothing further happens during CL-88 time. When SS-88 times out, a signal is applied through line 1430 (FIG. 5E) to one input of AND gate 1343. The other inputs to this AND gate are conditioned by output line 1422 from the equals side of zero-detector 480, output line 1345 from the equals output of detector 512 and output line 1433 from the OFF side of flip-flop 487. Output line 499 from AND gate 1343 is connected to switch SS-86 to its ON state. It will be remembered that TAC was incremented by one during CL-88 time so that it now contains the address 101. Therefore, during CL-86 time, the entry at this address is read into MBR and the circuit proceeds through the steps just described until CL-88 time is again arrived at.

At CL-88 time, TAC 386 is again incremented by a signal applied to line 1228, and a signal is again applied through line 1432 to condition AND gates 1428 and 485. However, since the chain-address field of entry 101 is not blank, it contains the address 102, zero-detector 480 is generating an output signal on not-equal-to-zero line 1426 at this time, fully conditioning AND gate 1428 to generate an output signal on line 1434, which is applied to condition AND gates 1318, 1322, and 1436. The absence of a signal on equal-to-zero line 1422 prevents AND gate 485 from being fully conditioned and flip-flop 487 remains in its OFF state. Gates 1318 being conditioned allow the syllable contained in MBR 368, in this case the syllable "NVL," to be applied through line 494 to gates 1512A (FIG. 5R). Since word-select counter 528 (FIG. 5P) is in its first position, there is an output signal on lines 1802A which conditions gates 1512A to pass the syllable through lines 1809A to gates 1561A. Since column-select counter 508 (FIG. 5M) is also in its first position at this time, decoder 1540 is generating an output signal on line 1551, which is applied through cable 1550 to condition gates 1561A (FIG. 5R) to store the syllable in syllable register 1821A. Similarly, gates 1436 being conditioned allow the address in MAR 372, the address 101, to be applied through lines 492, condition gates 1510A (FIG. 5R), lines 1808A conditioned gates 1571A, and lines 1831A to address register 1841A. The first syllable and its address are in this manner stored in the first-syllable and address registers of word registers 488. Gates 1322 being conditioned permit the frequency for this syllable contained in MBR 368 to be applied through lines 496, conditioned gates 1521 (FIG. 5M) and lines 1591 to the first-frequency register 1601. The output signal on line 1434 is also applied to increment number-of-syllables counter 1670 (FIG. 5M) to a count of one. Finally, the signal on line 1434 is applied as one input to AND gate 1420 (FIG. 5E) the other input to this AND gate being the output on not-equal-line 1416 from two-detector 482. Since the chain address in the chain-address field of entry 101 is not a 2, AND gate 1420 is fully conditioned at this time to generate an output signal on line 1440, which is applied to condition gates 1404 to pass the address in the chain-address field of MBR 368 into MAR 372. As always, the

address in MAR is also read into PAR. The effect of the above operations is to store the first syllable with its frequency and address in appropriate positions in the word registers and frequency registers and to set the circuit to continue forming the syllable pattern at a syllable which may follow the first syllable. When SS-88 times out, a signal is applied through line 1430 to one input of AND gate 1418. Since the chain-address field of MBR 368 contains neither a 0 nor a 2, detectors 480 and 482 apply the other required inputs to this AND gate, causing an output signal to be generated on line 500, which switches SS-88a to its ON state. When SS-88a is in its ON state, a signal is applied to line 1532 (FIG. 5M) to increment column-select counter 508 to its second position. When SS-88a times out, a signal is applied to switch SS-87 to its ON state.

Since the address 102 is now in MAR 372, the return to CL-87 causes this entry to be read into MBR 368 and causes the succeeding operations indicated by step 87a and 87b to be performed on this entry. TAC is stepped during CL-88 time and, since the chain address of this entry is 0, no entry is made and the circuit returns to CL-86 time.

From the appendix and previous discussion, it is seen that since TAC now contains the address 103, the entry at this address is now investigated and, since it has a chain address other than 0 or 2, the syllable, "CVN," is stored in syllable register 1822A, the address 103 is stored in address register 1922A, and the frequency is stored in frequency register 1602. The chain address 105 is read into MAR, and the number-of-syllables counter and column-select counter are each incremented by one. The circuit then returns to CL-87 time to complete the forming of the syllable pattern.

The entry at address 105, the syllable "TV," chain addresses to the entry at 111, the syllable "LE." Therefore, as may be seen from FIG. 9 which shows the entries which are made in the word registers, the fourth time that CL-88 time comes up, the syllables at addresses 101, 102, and 105 have already been stored in the appropriate positions in the word register and the frequency register, and MBR 368 contains the entry stored at address 111. Since this entry has a chain address of 2, AND gate 1428 is still conditioned at CL-88 time causing gates 1318, 1322, and 1436 to be conditioned to store the syllable, its frequency, and its address in appropriate positions of the word and frequency registers, and a signal is applied through line 1434 to step number-of-syllables counter 1670 to a count of four. However, 2-detector 482 is now generating an output signal on line 1412, and AND gate 1420 is therefore not conditioned to store the chain address 2 in MAR. When SS-88 times out, the signal applied to line 1430 finds AND gate 1414 conditioned by the output signal on line 1412 from detector 482 and generates an output signal on line 502 which is applied to switch SS-89 to its ON state.

Referring to FIG. 3B, it is seen that the operation now to be performed is that of calculating the ratio of the average frequency for the syllables of the first possible syllable pattern to the square root of the sum of the squares of the standard deviation of these frequencies from the average. Calculate-circuit 504 of FIGS. 5M-5N operates to perform this function. When SS-89 is in its ON state, a signal is applied to line 1530 (FIG. 5M) to reset column-select counter 508 to its first position, and a signal is applied to line 1620 to condition gates 1621-162N to pass the frequencies stored in frequency registers 1601-160N (note that only the first four of the registers actually contain information at this time) through lines 1641-164N to adder 1640. When SS-89 times out, a signal is applied to switch SS-90 to its ON state. When SS-90 is in its ON state, a signal is applied through lines 1666 to condition gates 1662 to pass the sum of the frequencies as arrived at by adder 1640 through lines 1696 to the dividend input of divider 1700 and to condition gates 1664 to pass the number-of-syllables count, in this

case 4, from counter 1670 through lines 1698 to the divisor input of divider 1700. The average frequency is therefore computed in divider 1700. When SS-90 times out, a signal is applied to switch SS-91 to its ON state. When SS-91 is in its ON state, a signal is applied to line 1712 to condition gates 1704 to pass the average frequency through lines 1714 to one input of subtractor 1718 and to condition gates 1710 to pass the frequency contained in frequency register 1601 (gates 1631 are now conditioned by the output signal on line 1551 since column-selector counter was reset to its first position at CL-89 time) through lines 1716 to the other input of subtractor 1718. Subtractor 1718 computes the deviation of the first frequency in register 1601 from the average frequency. When SS-91 times out, a signal is applied to switch SS-92 to its ON state. When SS-92 is in its ON state, a signal is applied through line 1740 to condition gates 1732 to pass the deviation computed in subtractor 1718 through lines 1726 to squarer 1728 (FIG. 5N). The square of the deviation for the first frequency is in this way computed. When SS-92 times out, a signal is applied to switch SS-93 to its ON state. When SS-93 is in its ON state, a signal is applied through line 1740 to condition gates 1732 to pass the square of the deviation just computed in squarer 1728 through lines 1742 to one input of adder 1746 and to condition gates 1738 to pass the contents of intermediate store 1736 through lines 1744 to the other input of adder 1746. Since, at this time, intermediate store 1736 is blank, the effect of this operation is to store the square computed in squarer 1728 in adder 1746.

When SS-93 times out, a signal is applied through line 1690 (FIG. 5M) to one input of AND gates 1684 and 1688. Since number-of-syllables counter 1670 contains a count of 4 at this time and column-select counter 508 is set to its first position at this time, the two inputs to compare-circuit 1538 are not equal, and compare-circuit 1538 therefore generates an output signal on line 1686 which fully conditions AND gate 1688 to generate an output signal on line 1694, which signal switches SS-94 to its ON state.

When SS-94 times out, a signal is applied to switch through line 1532 to increment column-select counter 508 to its second position, and a signal is applied through lines 1754 (FIG. 5N) to condition gates 1750 to pass the contents of adder 1746, in this case the square of the standard deviation of the first frequency from the average, into intermediate store 1736.

When SS-94 times out, a signal is applied to switch SS-91 to its ON state. Since the column-select counter is now in its second position, during CL-91 and CL-92 time, the square of the deviation of the frequency of the second syllable from the average is computed and stored in quarter 1728. During CL-93 time, this square deviation is applied to one input of adder 1746, and the previously computed square deviation stored in intermediate store 1736 is applied to the other input of this adder. The resulting sum in this adder is the sum of the squares of these two frequencies. Since the count in the column-select counter and the number-of-syllables counter is still not equal, this sum is stored in intermediate store 1736, and the circuit proceeds to compute the square of the deviation of the frequency of the third syllable from the average, to add this to the previously computed sum, and to compute the square of the deviation of the frequency of the fourth syllable from the average and to add this to the previously computed sum. When CL-93 times out at this time, adder 1746 contains the sum of the square of the standard deviations of all the frequencies from the average, and both column-select counter 508 and number-of-syllables counter 1670 contain a count of 4. Therefore, compare circuit 1538 generates an output signal on line 1682, which fully conditions AND gate 1684 to generate an output signal on line 1692, which signal switches SS-95 to its ON state.

When SS-95 is in its ON state, a signal is applied through line 1760 (FIG. 5N) to condition gates 1752 to

apply the sum of the squares of the standard deviations contained in adder 1746 through lines 1764 to the dividend input of divider 1766 and to condition gates 1680 to apply the number of syllables contained in number-of-syllables counter 1670 through lines 1762 to the divisor input of this divider. The result of this operation is to compute the average square deviation. When SS-95 times out, a signal is applied to switch SS-96 to its ON state. When SS-96 is in its ON state, a signal is applied through line 1772 to condition gates 1770 to apply the average square deviation through lines 1774 to square-rooter 1776. The square root of the sum of the squares of the average deviation is computed in square-rooter 1776. When SS-96 times out, a signal is applied to switch SS-97 to its ON state. When SS-97 is in its ON state, a signal is applied to line 1782 to condition gates 1706 to apply the average frequency contained in divider 1700 through lines 1702 and lines 1784 to the dividend input of divider 1788 and to condition gates 1780 to pass the square root of the sum of the squares of the average deviation through lines 1786 to the divisor input of this divider. When SS-97 times out, a signal is applied to switch SS-98 to its ON state.

When SS-98 is in its ON state, a signal is applied through line 1794 to condition gates 1792 to apply the computed ratio through lines 506 and conditioned gates 1796A (FIG. 5S) (word-select counter 528 is still in its first position) to ratio register 1860A. A signal is also applied through lines 1850 (FIG. 5N) to condition gates 1678 to apply the number of syllables contained in number-of-syllable register 1670 through lines 1852 and conditioned gates 1806A (FIG. 5R) to number-of-syllables register 1856A. All of the desired information with reference to the first possible syllable pattern is therefore stored in the word-one position of word register 488. When SS-98 times out, a signal is applied to switch SS-99 to its ON state. When SS-99 is in its ON state, a signal is applied to line 1600 (FIG. 5M) to reset frequency registers 1601-160N. When SS-99 times out, a signal is applied to switch SS-100 to its ON state.

The circuit is now ready to perform step 264 of the operation, namely to determine whether all possible syllable patterns have been formed or whether there are additional possible syllable patterns. When SS-100 is in its ON state, a signal is applied to line 1534 (FIG. 5M) to decrement column-select counter 508 by one position. At this time, the column-select counter is set to 4. Therefore, when it is decremented, it has a count of 3 therein. When SS-100 times out, a signal is applied through line 1549 to one input of AND gate 1548. Since column-select counter 508 has a count of 3 in it (i.e. a count other than 0), line 1544 from decoder 1540 has a signal on it at this time which fully conditions AND gate 1548 to generate an output signal on line 518 which switches SS-101 to its ON state. As will be seen later, if column-select counter has a count of 0 in it at this time, then all possible syllable patterns have been formed and the circuit is ready to select the preferred pattern.

During clock times 101 through 105, the circuit is seeking a new table entry at which to begin forming syllable patterns. When SS-101 is in its ON state, a signal is applied through line 1968 (FIG. 5T) to condition gates 1468. Since word-select counter 528 is still in its first position and column-select counter 508 is in its third position, AND gate 1583A (not shown) of the gates 1581A-158NA (FIG. 5T), is conditioned, generating an output signal on line 1943A which conditions gate 1933A to pass the address of the third syllable of the syllable pattern which was formed in word 1 through line 1953, OR gate 1960A, line 1962A, OR gate 1964, and line 1966 to the information input of gates 1468. This address is applied through gates 1468 and lines 1466 to MAR 372. The address 105 is in this manner read into MAR. When SS-101 is in its ON state, a signal is also applied to line 1308 (FIG. 5F) to switch memory-status-flip-flop 1304 to its OFF or read state. When SS-101 times out, a signal

is applied to switch SS-102 to its ON state. When SS-102 is in its ON state, a signal is applied to line 1302 to cause the entry at address 105 to be read into MBR 368. When SS-102 times out, a signal is applied to switch SS-103 to its ON state. When SS-103 is in its ON state, a signal is applied to line 1306 to switch memory-status-flip-flop 1304 to its ON or write state, and a signal is applied through line 1488 to condition gates 1482 to apply a one from generator 1486 through lines 1480 to the used-bit field of MBR 368. When SS-103 times out, a signal is applied through line 1347 to one input of AND gates 1344 and 1346. Since there is no level termination mark in the level-termination field of entry 105, zero-detector 512 generates an output signal on line 1345 which fully conditions AND gate 1346 to generate an output signal on line 524 which switches SS-104 to its ON state. When SS-104 is in its ON state, a signal is applied to line 1302 to cause the entry at address 105 to be read back in with a used bit in its used-bit field. When SS-104 times out, a signal is applied through line 1437 (FIG. 5E) to one input of AND gate 1435. Since flip-flop 487 is in its OFF state at this time, a second input is being applied to AND gate 1435 through line 1433. Output line 1441 from AND gate 1435 is connected to switch SS-105 to its ON state. When SS-105 is in its ON state, a signal is applied to line 1800 (FIG. 5P) to increment word-select counter 528 to its second position. When SS-105 times out, a signal is applied to switch SS-85a to its ON state.

The circuit now proceeds to store the syllables "NVL" and "CVN" in the first two syllable positions of the second word in word register 488 and to store the relative frequencies of these two syllables in frequency registers 1601 and 1602 in a manner identical to that previously described. The address 105 is again stored in MAR after these operations and after CL-87 time when this entry is read into MBR 368, the circuit proceeds to CL-87a time. During CL-87a time, a signal is applied to line 1502 (FIG. 5D) to condition AND gate 1500. Since there is now a used bit of 1 in the used-bit field of the entry at address 105, decoder 470 generates an output signal on line 1496 which is applied to fully condition AND gate 1500 to generate an output signal on line 1504 which conditions gates 1476 to apply the address in MAR, the address 105, through lines 1478 and OR gate 1224 to TAC 386. When SS-87a times out, the signal applied to line 1506 (FIG. 5F) finds AND gate 1498 fully conditioned by the signal on line 1496 from decoder 470 and generates an output signal on line 476 which switches SS-87b to its ON state. When SS-87b is in its ON state, a signal is applied to line 1228 to step TAC 386 by one, to increment this counter to the address 106. When SS-87b times out, a signal is applied to switch SS-86 to its ON state.

The circuit now attempts to determine if the entry at address 106, the syllable "TVL," is a possible syllable which may be used with the two syllables already stored. Since this syllable has a chain address of 0, it is not an acceptable syllable, and the circuit proceeds to determine if the syllable stored at address 107 is an acceptable syllable. As is seen from FIG. 9, this is an acceptable syllable in the pattern, and the circuit proceeds to store the second possible syllable pattern and to compute the desired ratio therefore in a manner previously described.

When the column-select counter is now decremented by one, it is the second syllable, the syllable "CVN" stored at address 103, which has a used bit inserted in its used-bit field, and the circuit proceeds to form the remaining two syllable patterns shown in FIG. 9 in a manner substantially the same as that already described. In the process, a used bit is also inserted in the used-bit field of the syllable "V" stored at address 108.

When the last syllable pattern has been stored, the circuit, as always, proceeds to CL-100 time. During this time, column-select counter 508 (FIG. 5M) is decremented to a count of 2 (i.e. the last possible syllable pattern has 3 syllables). Since the column-select counter does

not have a count of 0 in it, the circuit proceeds to switch SS-101 to its ON state. During CL-101 time, the address 104, the address of the second syllable in the last possible syllable pattern, is read into MAR and the memory is set to its read status. During SS-102 time, this entry is read into MBR 368. During CL-103 time, a one bit is inserted in the used field of MBR, and the memory is set to its write status. When SS-103 times out, the signal applied to line 1347 (FIG. 5F) finds AND gate 1344 fully conditioned by the output signal on not-equal-to-zero line 1342 from detector 512, this being true since there is a level-termination mark in the level-termination field of entry 104. AND gate 1344 therefore generates an output signal on line 522 to switch SS-100 to its ON state. This results in column-select counter 508 being decremented to a count of 1. Since there is still not a count of 0 in this counter, the circuit again proceeds through CL-101 to 103 time, this time reading the entry at address 101, the entry for the syllable "NVL," into MBR 368. Since this entry also has a mark in its level-termination field, AND gate 1344 is again caused to generate an output signal on line 522, which again switches SS-100 to its ON state. This time when column-select counter 508 (FIG. 5M) is decremented, it is decremented to a count of 0. Therefore, when SS-100 times out, decoder 1540 is generating an output signal on line 1542, and AND gate 1546 is fully conditioned to generate an output signal on line 516 which switches SS-107 to its ON state. As has been indicated previously, this means that the circuit has formed all possible syllable patterns and is now ready to select the preferred pattern.

Before describing the select-preferred-pattern step of the operation, one additional condition should be considered. In the word "Mercantile" there is no possible syllable having both a level termination mark in its LTM field and a chain address of zero. When an entry having both a level termination mark and a chain address of zero is encountered, the signal is applied to line 1432 (FIG. 5E) during CL-88 time fully conditions AND gate 485 to generate an output signal on line 498 which signal switches flip-flop 487 to its ON state. When SS-88 times out, the signal applied to line 1430 finds AND gate 1429 in gating circuit 486 conditioned by the output signal on ON-side output line 1427 from flip-flop 487 causing an output signal on line 501 which switches SS-100 to its ON state. This effectively performs step 255 (FIG. 3B) of the operation. The effect of this operation is to indicate that the syllable pattern being formed cannot be completed and that a ratio should not be computed for this pattern.

The circuit proceeds through clock times 100-103 in a manner identical to that previously described with column-select counter 508 (FIG. 5M) being decremented by one and a used bit being written into the used-bit field of the last syllable stored in the word register. If the syllable which has the zero chain address and the level termination mark is a possible first syllable for the word, then no further syllable patterns can be formed, and, when SS-100 times out, the circuit proceeds to the select-preferred-pattern step in the manner indicated above (also see appendix).

If the syllable is not a possible first syllable for the word, then, when SS-103 times out, the circuit either returns to CL-100 time or goes on to CL-104 time, depending on whether the preceding syllable has a level termination mark or not (see appendix). If the circuit proceeds to CL-104 time, when SS-104 times out a signal is applied through line 1437 (FIG. 5E) to one input of AND gate 1431. Since flip-flop 487 was previously set to its ON state, this AND gate is fully conditioned by the output signal on ON-side output line 1427 from flip-flop 487 causing an output signal on line 1439 which switches SS-85a to its ON state. It will be noted that since the operation performed during CL-105 time was not performed, the word-select counter is not incremented and is therefore still set at the same position it was set at when the unsuc-

cessful effort to form a syllable pattern was attempted. The new syllable pattern which is formed when SS-85a is switched to its ON state is therefore stored in this word position.

Select preferred pattern

Since all the ratios are now stored in the registers 1860A-1860D (FIG. 5S) of word register 488, the circuit is now ready to select the preferred pattern, i.e. the circuit is ready to perform step 270 of (FIG. 1). As indicated previously, at the beginning of this step, SS-107 is switched to its ON state. When SS-107 is in its ON state, a signal is applied to line 1798 (FIG. 5P) to reset word-select counter 528 to its first position, a signal is applied to line 2022 to reset preferred-word register 544 to its first position, and a signal is applied to line 2004 to set first-time-through flip-flop 535 to its ON state. When SS-107 times out, a signal is applied to switch SS-108 to its ON state.

The circuit is now ready to perform step 274 (FIG. 4). When SS-108 is in its ON state, a signal is applied through line 2008 (FIG. 5P) to condition AND gate 1986. However, since word-select register 528 is in its first position, gate 1804A (FIG. 5Q) is conditioned to apply the ratio in ratio register 1860A through OR gate 536 to blank-detector 530 and, since there is a ratio in this register, blank-detector 530 is not generating an output at this time so that AND gate 1986 is not fully conditioned and nothing happens during CL-108 time. Referring to FIG. 9, it is seen that the ratio in ratio register 1860A is less than 1. Therefore, compare-to-one circuit 532 is generating an output signal on less-than-or-equal-to line 1990 which is applied to partially condition AND gate 1982 in gating circuit 534. A second conditioning input to the AND gate is supplied through not-blank line 1980 from detector 530. When SS-108 times out, a signal is applied through line 2006 to the other input of this AND gate, causing an output signal on line 540, which switches SS-111 to its ON state.

When SS-111 is in its ON state, a signal is applied through line 1800 to increment word-select counter 528 by one. This counter now contains the address of the second word. When SS-111 times out, a signal is applied to switch SS-108 to its ON state. Since the ratio in ratio register 1860B is also not a blank, again nothing happens during CL-108 time. However, the ratio in ratio register 1860B is greater than 1; therefore, compare-to-one circuit 532 is generating an output signal on line 1992 to partially condition AND gates 1994 and 1996. Since first-time-through flip-flop 535 is still in its ON state, there is a signal on its ON-side output line 2000 which fully conditions AND gate 1996 when SS-108 times out, causing an output signal on line 542 which switches SS-110 to its ON state. When SS-110 is in its ON state, a signal is applied to line 2002 to switch first-time-through flip-flop 535 to its OFF state, and a signal is applied to line 2020 to condition gates 2018 to transfer the word address in word-select counter 528 to preferred-word register 544. The preferred-word register, therefore, contains the address of the second word. When SS-110 times out, a signal is applied to switch SS-111 to its ON state. As before, when SS-111 is in its ON state, word-select counter 528 is incremented, and the circuit proceeds to look at the ratio field of the next word in the word register.

Since neither of the remaining words has a ratio greater than 1, nothing happens during either of these steps, and after the ratio field of the last of these words is looked at, the circuit returns to CL-108 time. At this time, the word-select counter has a count of 5 in it. Since the ratio field of this word is blank, at CL-108 time both inputs to AND gate 1986 are conditioned, causing this AND gate to generate an output signal on line 2010 which is applied to partially condition AND gates 2012A-2012N. The preferred-word register is at this time set to

its second position, causing an output signal on line 2014B, which fully conditions AND gate 2012B to generate an output signal on line 2024B, which signal conditions gates 1898B (FIG. 5Q) to pass the syllable pattern contained in syllable registers 1821B-182NB (FIG. 5R) into coded-word-hyphenation registers 1911-191N (FIG. 5R). The output signal on line 1964 from blank-detector 530 also partially conditions AND gate 1988 (FIG. 5P). When SS-108 times out, a signal is applied to line 2006 to fully condition this AND gate, causing an output signal on line 538 which switches SS-120 to its ON state. When SS-120 is in its ON state, the read-out operation commences.

While in the example just described, there was only one possible syllable pattern having a ratio greater than 1, and, as was indicated previously, there will always be at least 1 such ratio, situations will arise where there are 2 or more syllable patterns having a ratio greater than 1. To illustrate the sequence of events which occur in such a situation, assume that the word "Mercantile" had a fifth possible syllable pattern and that this pattern had a ratio greater than 1. Therefore, when the word-select counter 1800 was advanced to this word position, the fifth word position in the word register, and SS-108 times out, compare-to-one circuit 532 is generating an output signal on greater-than-one line 1992 to partially condition AND gate 1994 (FIG. 5P). Since first-time-through flip-flop 535 was reset to its OFF state when the second word was found to have a ratio greater than 1, there is an output signal on line 1998 from the OFF side of this flip-flop fully conditioning AND gate 1994 to generate an output signal on line 546 which causes SS-109 to be switched to its ON state.

The circuit is now set to perform step 280 (FIG. 4). When SS-109 is in its ON state, a signal is applied through line 2034 (FIG. 5P) to condition one input of AND gate 2030B. The other input to this AND gate is output line 2014B from preferred-word register 544, which line, since register 544 is set to its second position, is up at this time. The resulting output on line 2040B is applied to condition gates 1866B to pass the number of syllables in this case 3, of the preferred word through lines 1872B, OR gates 1874, and lines 1878 to the preferred-word input of compare-circuit 1880. The signal on line 2034 also conditions an AND gate 2026E (not shown), the other input to which is the output line 1802E from word-select counter 528. This results in the number of syllables for the fifth word being applied through a line 1868E, OR gates 1870, and lines 1876 to the selected-word input of compare-circuit 1880. As indicated previously, when two possible syllable patterns have ratios greater than 1, the one with the least number of syllables is the preferred pattern. Therefore, if the pattern in the second position, the pattern indicated by preferred-word register 544, has less syllables, compare-circuit 1880 generates an output signal on line 1882 which, when SS-109 times out, fully conditions AND gate 1884 to generate an output signal on line 552 which switches SS-111 to its ON state, causing the second word to be left in the preferred-word register and the circuit to proceed to look at the next word. If, on the other hand, the pattern in word register 5 has a lesser number of syllables, for example two syllables, then compare-circuit 1880 generates an output signal on line 1890 which, when SS-109 times out, fully conditions AND gate 1892 to generate an output signal on line 550 which causes SS-110 to be switched to its ON state. From the appendix and previous discussion, it can be seen that this causes the word then in the word-select counter, in this case the fifth word, to be transferred to the preferred-word register and then causes the circuit to advance to the next-word register to see what its ratio is. Finally, if it is found that the two words applied to compare-circuit 1880 have the same number of syllables, in this case 3, an output is derived on line 1886 which, when SS-109 times out, fully conditions AND

gate 1888 to generate an output signal on line 554 which causes SS-112 to be switched to its ON state.

It will be remembered from previous discussion that under these conditions the pattern having the highest ratio is the preferred pattern. When SS-112 is in its ON state, the circuit is performing step 282 (FIG. 4). At this time, a signal is applied to line 2036, which signal partially conditions AND gate 2032B (FIG. 5P) and 2028E (not shown). The other input to AND gate 2032B is the output line 2014B from preferred-word register 544, and the other input to AND gate 2028E is the output line 1802E (not shown) from word-select counter 528. Output line 2044B from AND gate 2032B is connected to condition gates 1974B (FIG. 5Q) to apply the ratio in register 1860B through lines 2050B, OR gates 2052 and lines 2056 to the preferred-word input of compare-circuit 2058. Output line 2042E from AND gate 2028E is connected to condition gates 1972E to pass the ratio contained in register 1860E through lines 2046E (none of the previously described elements are shown in the figure), OR gates 2048 (FIG. 5Q), and lines 2054 to the word input of compare-circuit 2058. If the fifth word, the word indicated by word-select counter 528 has the higher ratio, compare-circuit 2058 generates an output signal on line 2060 which, when SS-112 times out causing a signal to appear on line 2068, fully conditions AND gate 2062 to generate an output signal on line 558 which switches SS-110 to its ON state. As indicated previously, when this occurs the address in word-select counter 528, the address 5, is transferred into preferred-word register 544, and the circuit then proceeds to look at the next word in the word register. If, on the other hand, the ratio of the word in the word register is less than or equal to the ratio of the preferred word, the second word in word register 488, compare-circuit 2058 generates an output signal on line 2064 which, when SS-112 times out causing a signal on line 2068, fully conditions AND gate 2066 to generate an output signal on line 560 which signal is applied to switch SS-111 to its ON state. Under these conditions, the entry in the preferred-word register is left alone and the circuit proceeds to look at the next word position in word register 488.

Read-out pattern

When SS-120 is switched to its ON state, this indicates that a preferred pattern has been selected and that the circuit is ready to read out this preferred pattern (i.e. to perform step 290 of FIG. 1). It will be remembered that the last operation performed at CL-108 time before the circuit switched SS-120 to its ON state, was to transfer the preferred syllable pattern from word register 488 (FIG. 5R) to coded-word-hyphenation register 564 (FIG. 5K). Each of these syllables is stored in an individual register 1911-191N. When SS-120 is in its ON state, a signal is applied to line 616 (FIG. 5A) to reset output-control ring 612 to its first position, a signal is applied to line 2190 (FIG. 5L) to reset input-control ring 2188 for the output register to its first position, a signal is applied to line 2074 (FIG. 5K) to reset group-control ring 2070 to its first position, and a signal is applied to line 2076 to reset unit-control ring 2072 to its first position. When SS-120 times out, a signal is applied to switch SS-121 to its ON state.

The first time that SS-121 is in its ON state, AND gate 2081A is fully conditioned by the signals applied to it on line 2079A from group-control ring 2070 and line 2091 from unit-control ring 2072. The resulting output signal on line 2021A causes the reduced character set character "N" stored in the first position of register 1911 to be applied through lines 2131 and OR gates 2140 to blank decoder 2144. Since this character is not a blank, decoder 2144 generates an output signal on line 2148 which partially conditions AND gate 2150. This AND gate is fully conditioned by a signal applied to line 2162 when SS-121 is in its ON state. The resulting output

signal on line 574 is applied to condition gates 634 to pass the character stored in the first position of input-buffer register 302 (FIG. 5A) through lines 2170 (FIG. 5L), OR gates 2174, and lines 576 to the first position of output register 346. The character "m" is in this way stored in output register 346. When SS-121 times out, a signal is applied through line 2152 (FIG. 5L) to one input of AND gate 2116. Since unit-control ring 2072 is in its first position, there is no signal on line 2096, and inverter 2112 therefore applies a second conditioning signal through line 2114 to this AND gate. The third input to AND gate 2116 is derived from not-blank line 2148 from blank decoder 2144. AND gate 2116 being fully conditioned causes an output signal to appear on line 2154, which signal switches SS-122 to its ON state.

When SS-122 is in its ON state, a signal is applied to line 620 (FIG. 5A) to increment output-control ring 612 to its second position, causing the character "e" to be applied to lines 332, a signal is applied to line 2192 (FIG. 5K) to increment input-control ring 2188 to its second position, and a signal is applied to line 2080 (FIG. 5K) to increment unit-control ring 2072 to its second position. When SS-122 times out, a signal is applied to again switch SS-121 to its ON state.

At this time, AND gate 2082A is fully conditioned, causing the reduced character set letter "v" to be applied to blank decoder 2144 and ultimately resulting in the character "e" being stored in the second position of output register 346. The third letter of the first syllable of "Mercantile," the character "r," is, a similar manner, stored in output register 346.

During the next CL-121 time, AND gate 2084A is fully conditioned, causing a blank character to be applied to blank decoder 2144. Decoder 2144 therefore generates an output signal on equal-line 2146 which partially conditions AND gate 2108. Since unit-control ring 2072 is not in its first position, there is no signal on line 2091, and inverter 2102 is generating an output signal on line 2104 which is applied as the second input to AND gate 2108. The signal applied to line 2162 when SS-121 is in its ON state fully conditions this AND gate to generate an output signal on line 578 which is applied through OR gate 2164 and line 2166 to condition gates 2168 to pass the coded character for a hyphen from generator 572 through lines 2170, gates 2168, lines 2172, OR gates 2174, and lines 576 to the fourth position in output register 346. The signal on equal-line 2146 is also applied as one input to AND gate 2106, a second input to this AND gate being output line 2104 from inverter 2102. When SS-121 times out, a signal is applied to line 2152 to fully condition AND gate 2106, causing an output signal on line 2160 which switches SS-128 to its ON state.

When SS-128 is in its ON state, a signal is applied to line 2078 (FIG. 5K) to increment group-control ring 2070 to its second position, a signal is applied to line 2076 to reset unit-control ring 2072 to its first position, and a signal is applied to line 2192 (FIG. 5L) to increment input-control ring 2188 to its fifth position. It is noted that output-control ring 612 is not incremented at this time so that it is still sitting over the fourth letter of the word, the letter "c." When SS-128 times out, a signal is applied to again switch SS-121 to its ON state. From previous discussion, it can be seen that the second syllable of the word, the syllable "can" is stored in the output register in a manner identical to that described for the first syllable, and a hyphen is inserted in the output register at the end of this syllable. The storing of the last syllable of the word, the syllable "tile," is accomplished in an identical manner.

Before describing the sequence of events which occur after the last syllable has been stored, mention should be made of the sequence of operations which occur when a six-letter syllable is encountered in one of the registers 1911-191N, a situation which does not occur in the word "Mercantile." Under these circumstances, when SS-121

is in its ON state, blank decoder 2144 is still generating an output signal on line 2148 and the character is stored in output register 346 in the manner previously described. However, when SS-121 times out, unit-control ring 2172 is generating an output signal on line 2096 which, in conjunction with the signal on line 2148, and the signal applied to line 2152, fully conditions AND gate 2110 to generate an output signal on line 2156, which signal is applied to switch SS-124 to its ON state. When SS-124 is in its ON state, a signal is applied to line 2078 to increment group-control ring 2070, and a signal is applied to line 2192 to increment input-control ring 2188. Input-control ring 2188 is therefore set over the character position following that in which the last character was stored. When SS-124 times out, a signal is applied to switch SS-125 to its ON state. When SS-125 is in its ON state, a signal is applied through line 580 (FIG. 5L) and OR gate 2164 to condition gates 2168 to apply the hyphen from hyphen generator 572 through lines 576 to the position in output register 346 indicated by input-control ring 2188, in this case the position following that in which the last character was stored. When SS-125 times out, a signal is applied to switch SS-126 to its ON state. When SS-126 is in its ON state, a signal is applied to line 620 to increment output-control ring 612, a signal is applied to line 2192 to again increment input-control ring 2188, and a signal is applied to line 2076 to reset unit-control ring 2072 to its first position. The circuit is therefore completely reset to look at the next syllable. When SS-126 times out, a signal is applied to again switch SS-121 to its ON state.

Returning to the example with the word "Mercantile," when a blank is detected after the last character of the

last syllable, a hyphen is stored in the output register in a manner previously described. The circuit then proceeds to CL-128 time during which the group-control ring is incremented, the unit-control ring reset and input-control ring 2188 is stepped one position. The circuit then returns to CL-121 time. At this time, unit-control ring 2072 is in its first position and the character selected in coded-word-hyphenation registers 564 is a blank. Therefore, neither AND gate 2108 nor AND gate 2150 is fully conditioned at CL-121 time and this time period is effectively idle. When SS-121 times out, the signals applied to lines 2146, 2091, and 2152 fully condition AND gate 2100 to generate an output signal on line 2158, which switches SS-129 to its ON state. When SS-129 is in its ON state, a signal is applied to line 2194 to decrement input-control ring 2188 by one. This sets the input-control ring over the position in output register 346 at which a hyphen was stored after the last syllable of the word. When SS-129 times out, a signal is applied to switch SS-130 to its ON state. When SS-130 is in its ON state, a signal is applied to line 2184 to condition gates 2178 to pass a blank from blank generator 2182 through lines 2176, OR gates 2174, and lines 576 to output register 346. The hyphen inserted at the end of the word is in this way eradicated. When SS-130 times out, a signal is generated which indicates that the function of this circuit has been completed.

While the invention has been particularly shown and described with reference to a preferred embodiment thereof, it will be understood by those skilled in the art that various changes in form and details may be made therein without departing from the spirit and scope of the invention.

Single shot No.	Turn-on condition	Functions performed while on	Functions performed when single-shot times out	Next clock time
0.....	117 τ	Reset next-character-number counter 748 (FIG. 5D) to one (i.e. apply a signal to line 750). Reset <i>l/w</i> counter 312 (FIG. 5C) to one (i.e. apply a signal to line 768). Reset output-control ring 612 (FIG. 5A) to first position (i.e. apply signal to line 616). Reset argument-input-control ring 704 (FIG. 5B) to position one (i.e. apply a signal to line 706). Transfer contents of starting-point register 1208 (FIG. 5D) to TAC 386 (i.e. apply a signal to line 1220 to condition gates 1218). Apply contents of supplementary-starting-point register 1210 (FIG. 5D) to supplementary-address counter 392 (i.e. apply a signal through line 1260 to gates 1258).	Switch SS-0a to its ON state.....	CL-0a.
0a.....	0 τ	Route * from generator 694 (FIG. 5B) into argument register 380 (i.e. apply a signal through line 696 to condition gates 690).	Switch SS-0b to its ON state.....	CL-0b.
0b.....	0a τ or 3 τ or 22 τ or 31 τ	Increment argument-input-control ring 704 (FIG. 5B) by one (i.e. apply a signal to line 708).	Switch SS-1 to its ON state.....	CL-1.
1.....	0b τ or 33 τ	Route selected character from input-buffer register 302 (FIG. 5A) to argument register 360 (i.e. apply conditioning signal through line 682 to gates 630). Set match indicators in associative memory 382 (FIG. 5B) to their match side, and set match flip-flop 716 to its OFF state (i.e. apply a signal to line 714). Step <i>l/w</i> counter (FIG. 5C) by one (i.e. apply a signal through line 860 to OR gate 856). Step next-character-number counter 748 (FIG. 5D) by one (i.e. apply a signal to line 752).	Switch SS-1a to its ON state.....	CL-1a.
1a.....	1 τ	Increment output-control ring 612 (FIG. 5A) by one (i.e. apply a signal to line 620). (Note that end-of-word flip-flop 640 (FIG. 5B) is switched to its ON state if selected character is a blank.)	Switch on SS-1b if end-of-word flip-flop is in its ON state (i.e. condition AND gate 648). Switch on SS-1c if end-of-word flip-flop is in its OFF state (i.e. condition AND gate 656).	CL-1b or CL-2.
1b.....	1a τ	Decrement output-control ring 612 (FIG. 5A) by one (i.e. apply a signal to line 618).	Switch on SS-1c.	CL-1c.

1d.....	1c τ	Increment argument-input-control ring 704 (FIG. 5B) (i.e. apply a signal to line 708).	Switch on SS-1e.....	CL-1e.
1e.....	1d τ	Route * to argument register 380 (i.e. apply a signal through line 696 (FIG. 5B) to condition gates 690).	Switch on SS-2.....	CL-2.

Single shot No.	Turn-on condition	Functions performed while on	Functions performed when single-shot times out	Next clock time
2.....	1a _r or 1e _r	Perform an association between the contents of argument register 360 and the contents of associative memory 362 (i.e. apply a signal to line 712 (FIG. 5B)).	Switch on SS-3.....	CL-3.
3.....	2 _r	If no match, switch match flip-flop 716 (FIG. 5B) to its ON state; if a match, read syllable and frequency of occurrence from associative memory 362 into appropriate fields in MB R 368 (FIG. 5F) and route contents of next-character-number counter 748 (FIG. 5D) into next-character-number field of MBR 368 (i.e. apply a signal to test line 718).	If a match is found, switch SS-20 to its ON state (i.e. condition AND gate 724 (FIG. 5B)). If no match and l/w counter equals 7, or if no match and end-of-word flip-flop 640 is in its ON state, switch SS-4 to its ON state (i.e. condition AND gate 650 or 728). If no match is found and l/w counter is not equal to 7, switch on SS-06 to its ON state (i.e. condition AND gate 730).	CL-20 or CL-4 or CL-0b.
4.....	3 _r	Put one in level-termination field of MB R 368 if TE flip-flop 408 is in its ON state (i.e. apply a conditioning signal through line 1340 (FIG. 5E) to AND gate 822).	If TE trigger 408 is reset, switch SS-5 to its ON state (i.e. condition AND gate 812 (FIG. 5A)). If TE flip-flop is in its ON state, switch SS-31 to its ON state (i.e. condition AND gate 820).	CL-5 or CL-31.
5.....	4 _r	Route 0 into chain-address field of MB R 368 (i.e. apply conditioning signal through line 1394 (FIG. 5E) to gates 418). Set memory to write status (i.e. apply signal through line 1306 (FIG. 5F) to memory-status flip-flop 1304).	Switch SS-6 to its ON state.....	CL-6.
6.....	5 _r	Perform memory cycle (i.e. apply a signal to line 1302 (FIG. 5F)).	Switch on SS-7.....	CL-7.
7.....	6 _r	Reset MB R 368 (FIG. 5F) to blank (i.e. apply a signal to line 1314).	Switch SS-8 to its ON state.....	CL-8.
8.....	7 _r	Route a 0 to chain-address field of MB R 368 (i.e. apply a conditioning signal through line 1394 (FIG. 5E) to gates 418).	Switch on SS-29.....	CL-29.
20.....	3 _r	Increment TAC 386 by 1 (i.e. apply a signal to line 1228 (FIG. 5D)). Put 1 into level-termination field of l/w counter equals seven or if EOW flip-flop 640 is in its ON state (i.e. condition AND gates 651 (FIG. 5E) and 786).	Switch on SS-21.....	CL-21.
21.....	20 _r	Transfer TAC to MAR and transfer MAR to PAR (i.e. apply a conditioning signal to line 1236 (FIG. 5D)). Set memory to write status (i.e. apply signal to line 1306 (FIG. 5F) to switch memory-status flip-flop 1304 to write side).	Switch on SS-22.....	CL-22.
22.....	21 _r	Do memory cycle (i.e. apply a signal to line 1302 (FIG. 5F)). Set TE flip-flop 408 to its ON side (i.e. apply a signal to line 826 (FIG. 5A)).	If used flip-flop 374 is in its ON state, switch SS-23 to its ON state (i.e. condition AND gate 810 (FIG. 5B)). If used flip-flop is in its OFF state and l/w counter not equal to seven, switch SS-06 to its ON state (i.e. condition AND gate 722). If used flip-flop in OFF state and l/w counter equal to 7, switch SS-32 to its ON state (i.e. condition AND gate 784).	CL-23 or CL-0b or CL-32.
23.....	22 _r	Transfer PAR 390 to MAR 372 and transfer MAR 372 to PAR 390 (i.e. apply a conditioning signal through line 1444 (FIG. 5B) to gates 1448, etc.). Switch used flip-flop 374 to its OFF state (i.e. apply a signal to line 804 (FIG. 5B)). Set memory to its read status (i.e. apply a signal through line 1308 to the OFF side of memory-status flip-flop 1304).	Switch on SS-24.....	CL-24.
24.....	23 _r	Do a memory read cycle (i.e. apply a signal to line 1302 (FIG. 5F)).	Switch on SS-25 to its ON state.....	CL-25.
25.....	24 _r	Transfer contents of next-character-number field of MB R 368 to next-character-number register 394 (i.e. apply a conditioning signal through line 1350 (FIG. 5F) to gates 1348). Transfer TAC 386 to chain-address field of MB R (i.e. apply conditioning signal through line 1238 (FIG. 5D) to gates 1234). Set memory to write status (i.e. apply signal through line 1306 to ON side of memory-status flip-flop 1304).	Switch on SS-26.....	CL-26.
26.....	25 _r	Do memory cycle (i.e. apply signal to line 1302 (FIG. 5F) to write chain-address into table).	Switch on SS-27.....	CL-27.
27.....	26 _r	Reset MB R 368 to blank (i.e. apply a signal to line 1314 (FIG. 5F)).	Switch on SS-28 to its ON state.....	CL-28.
28.....	27 _r	Transfer TAC to CA field of MB R 368 (i.e. apply conditioning signal through line 1238 (FIG. 5D) to gates 1234).	Switch on SS-29.....	CL-29.
29.....	8 _r or 28 _r	Transfer next-character-number register 394 to next-character-number field of MB R 368 (i.e. apply conditioning signal through line 1358 (FIG. 5F) to gates 1356).	Switch on SS-30.....	CL-30.
30.....	29 _r	Transfer SAC 392 to MAR 372 and transfer MAR to PAR (i.e. apply conditioning signal through line 1298 (FIG. 5D) to gates 1272).	Switch on SS-30a.....	CL-30a.
30a.....	30 _r	Increment SAC 392 by one (i.e. apply a signal to line 1268 (FIG. 5D)).	Switch SS-31 to its ON state.....	CL-31.

Single shot No.	Turn-on condition	Functions performed while on	Functions performed when single-shot times out	Next clock time
31	30ar or 4r	Do memory write cycle (i.e. apply a signal to line 1302 (FIG. 5F)).	If <i>l/w</i> counter equal 7 or end-of-word flip-flop 640 is in ON state, switch SS-32 to its ON state (i.e. apply conditioning signal to AND gate 788 or to AND gate 046). If <i>l/w</i> counter not equal to 7 and end-of-word flip-flop in OFF state, switch SS-0b to its ON state (i.e. apply conditioning signal to AND gate 654 (FIG. 5B)).	CL-32 or CL-0b.
32	22r or 31r or 33br	Transfer next-character-address counter 420 to MAR 372 and transfer MAR to PAR (i.e. apply a conditioning signal through line 1200 (FIG. 5D) to gates 1196, etc.). Set memory to read status (i.e. apply signal through line 1308 (FIG. 5F) to OFF side of memory-status flip-flop 1304).	Switch SS-33 to its ON state.	CL-33.
33	32r	Do memory read cycle (i.e. apply a signal to line 1302 (FIG. 5F)).	Switch SS-33a to its ON state.	CL-33a.
33a	33r	Idle.	If next-character field of MBR is not blank, switch SS-33c to its ON state (i.e. condition AND gate 1378 (FIG. 5F)). If next character field of MBR is blank, switch SS-33u to its ON state (i.e. condition AND gate 1374).	CL-33c or CL-33u.
33b	33nr or 33er	Increment next-character-address counter 420 by one (i.e. apply a signal to line 1192 (FIG. 5D)).	Switch SS-32 to its ON state.	CL-32.
33c	33ar	Transfer next-character-number field of MBR 368 to next-character-number register 394 (i.e. apply conditioning signal through line 1350 (FIG. 5F) to gates 1348).	Switch SS-33d to its ON state.	CL-33d.
33d	33cr	Transfer SAC 392 to compare-register 446 (i.e. apply conditioning signal through line 1276 (FIG. 5D) to gates 1274).	Switch SS-33e to its ON state.	CL-33e.
33e	33dr	Transfer supplementary-starting-point register 1210 to SAC 392 (i.e. apply conditioning signal through line 1280 (FIG. 5D) to gates 1258).	Switch SS-33f to its ON state.	CL-33f.
33f	33er or 33pr	Transfer SAC 392 to MAR 372 and transfer MAR to PAR (i.e. apply conditioning signal through line 1208 (FIG. 5D) to gates 1272, etc.). Set memory to read status (i.e. apply signal through line 1308 (FIG. 5F) to switch memory-status flip-flop 1304 to OFF state).	Switch SS-33g to its ON state.	CL-33g.
33g	33r	Do memory read cycle (i.e. apply signal to line 1302 (FIG. 5F)).	Switch on SS-33h.	CL-33h.
33h	33gr	Idle.	If character numbers applied to compare circuit 442 are equal, switch SS-33i to its ON state (i.e. condition AND gate 1364 (FIG. 5F)). If character numbers applied to compare circuit 442 are not equal, switch SS-33o to its ON state (i.e. condition AND gate 1368).	CL-33i or CL-33o.
33i	33hr	Transfer CA field of MBR 368 to chain-address register 460 (i.e. apply conditioning signal through line 1406 (FIG. 5E) to gates 1402).	Switch SS-33j to its ON state.	CL-33j.
33j	33ir	Transfer next-character-address counter 420 to MAR 372 and transfer MAR to PAR (i.e. apply conditioning signal through line 1200 (FIG. 5D) to gates 1196, etc.).	Switch SS-33k to its ON state.	CL-33k.
33k	33jr	Do memory read cycle (i.e. apply signal to line 1302 (FIG. 5F)).	Switch SS-33l to its ON state.	CL-33l.
33l	33kr	Transfer chain-address register 460 to CA field of MBR 368 (i.e. apply conditioning signal through line 1400 (FIG. 5E) to gates 1396). Set memory to write status (i.e. apply signal through line 1306 (FIG. 5F) to set memory-status flip-flop 1304 to write state).	Switch SS-33m to its ON state.	CL-33m.
33m	33lr	Do memory write cycle (i.e. apply signal to line 1302 (FIG. 5F)).	Switch SS-33n to its ON state.	CL-33n.
33n	33mr	Transfer register 446 to SAC 392 (i.e. apply conditioning signal through line 1284 (FIG. 5D) to gates 1282).	Switch SS-33b to its ON state.	CL-33b.
33o	33hr	Idle.	If addresses applied to compare unit 448 are not equal, switch SS-33p to its ON state (i.e. apply conditioning signal to AND gate 1294 (FIG. 5D)). If addresses applied to compare circuit 448 are equal, switch SS-33q to its ON state (i.e. apply conditioning signal to AND gate 1290)).	CL-33p or CL-33q
33p	33or	Increment SAC 392 by one (i.e. apply signal to line 1268 (FIG. 5D)).	Switch SS-33j to its ON state.	CL-33f.
33q	33or	Transfer next-character-address counter 420 to MAR 372 and transfer MAR to PAR (i.e. apply conditioning signal through line 1200 (FIG. 5D) to gates 1196, etc.).	Switch SS-33r to its ON state.	CL-33r.

Single shot No.	Turn-on condition	Functions performed while on	Functions performed when single-shot times out	Next clock time
33r	33qr	Increment next-character-address counter by one (i.e. apply signal to line 1192 (FIG. 5D)). Set memory to read status (i.e. apply signal through line 1308 (FIG. 5F) to switch memory-status flip-flop 1304 to its OFF state).	Switch SS-33s to its ON state.	CL-33s.
33s	33rr	Do memory read cycle (i.e. apply signal to line 1302 (FIG. 5F)).	Switch SS-33t to its ON state.	CL-33t.
33t	33rt	Transfer next-character field of MBR 368 to <i>l/w</i> counter 321 (i.e. apply conditioning signal through line 774 (FIG. 5F) to gates 772). Switch TE flip-flop 408 to its OFF state (i.e. apply a signal to line 824 (FIG. 5A)). Switch used flip-flop 374 to its ON state (i.e. apply a signal to line 804 (FIG. 5B)). Switch EOW flip-flop 640 to its OFF state (i.e. apply a signal to line 642 (FIG. 5B)).	Switch SS-33w to its ON state.	CL-33w.
33u	33ar	Write a 2 into CA field of MBR 368 (i.e. apply a conditioning signal through line 1388 (FIG. 5E) to gates 434). Set memory to write status (i.e. apply a signal through line 1306 (FIG. 5F) to ON side of memory-status flip-flop 1304).	Switch SS-33x to its ON state.	CL-33x.
33v	33ur	Do memory write cycle (i.e. apply signal to line 1302 (FIG. 5F)).	If inputs to compare-circuit 1198 (i.e. next-character-address counter 420 and TAC 386) are not equal, switch SS-33b to its ON state (i.e. apply conditioning signal to AND gate 1252 (FIG. 5D)). If addresses applied to compare-circuit 1198 are equal, switch SS-85 to its ON state (i.e. condition AND gate 1248).	CL-33b or CL-85.
33w	33tr	Reset output-control ring 612 to its first position (i.e. apply a signal to line 616 (FIG. 5A)). Reset next-character-number counter 748 to a count of one (i.e. apply a signal to line 750 (FIG. 5D)).	Switch SS-33x to its ON state.	CL-33x.
33x	33wr or 33yr	Increment next-character-number counter 748 by 1 (i.e. apply a signal to line 752 (FIG. 5D)). Increment output-control ring 612 by 1 (i.e. apply a signal to line 620 (FIG. 5A)).	Switch SS-33y to its ON state.	CL-33y.
33y	33x7	Decrement <i>l/w</i> counter by 1 (i.e. apply a signal to line 776 (FIG. 5C)).	If <i>l/w</i> counter is not equal to 1, switch SS-33x to its ON state (i.e. condition AND gate 840 (FIG. 5C)). If <i>l/w</i> counter equal to 1, switch SS-33z to its ON state (i.e. condition AND gate 836).	CL-33x or CL-33z.
33z	33yT	Reset argument register 360 to blank (i.e. apply a signal to line 710 (FIG. 5B)). Reset input-control ring 704 to its first position (i.e. apply a signal to line 706 (FIG. 5B)).	Switch SS-1 to its ON state.	CL-1.
50		Overflow did not occur on 1st or 2d character and word more than 4 characters long. (Output on line 324 from AND gate 322 (FIG. 5C)).	Reset output-control ring 612 to first position (i.e. apply a signal to line 616 (FIG. 5A)).	Switch on SS-52. CL-52.
51	52r or 79r	Increment output-control ring 612 by 1 (i.e. apply signal to line 620 (FIG. 5A)).		Switch on SS-51a. CL-51a.
51a	51r or 52r or 77r or 54r	Increment output-control ring 612 by 1 (i.e. apply signal to line 620 (FIG. 5A)).		Switch on SS-52. CL-52.
52	51a or 50r or 64r or 56r	If letter is a, o, or u, add 1 to vowel-group counter 1018 (i.e. condition AND gate 1014 (FIG. 5I)).	If letter is a, o, or u, and vowel count is <2, switch on SS-51 (i.e. condition AND gate 1016 (FIG. 5I)). If letter is not a vowel, a y, or a blank, switch on SS-51a (i.e. condition AND gate 986 (FIG. 5G)). If letter is a y, switch on SS-78 (i.e. condition AND gate 960). If #VGC has count of 2, go to step 210 (FIG. 1) (i.e. condition AND gate 1056). If letter is an i, switch on SS-75 (i.e. condition AND gate 948). If letter is an e, switch on SS-53 (i.e. condition AND gate 946). If character is a blank and count in #VGC is <2, word is not hyphenable (i.e. condition AND gate 962).	CL-51 or CL-51a or CL-78 or CL-115 (i.e. step 210) CL-75 or CL-53 or end of operation (i.e. word is not hyphenable).
53	52r	Increment output-control ring by 1 (i.e. apply signal to line 620 (FIG. 5A)).		Switch on SS-54. CL-54.
54	53r	If character following the e is not a, d, s, or blank, increment #VGC by 1 (i.e. condition AND gate 998 (FIG. 5G)).	If character is not d, s, or blank and count in #VGC<2, switch on SS-51a (i.e. condition AND gate 998 (FIG. 5G)). If character is a d, switch on SS-63 (i.e. condition AND gate 942). If #VGC has count of 2, go to step 210 (i.e. condition AND gate 1054) (FIG. 5I). If character is an s, switch on SS-55 (i.e. condition AND gate 958). If character following e is a blank, switch on SS-71 (i.e. condition AND gate 964).	CL-51a or CL-63 or CL-115 (i.e. step 210) or CL-55 or CL-71.
55	54r	Increment output-control ring 612 by 1 (i.e. apply signal to line 620 (FIG. 5A)).		Switch on SS-56. CL-56.

Single shot No.	Turn-on condition	Functions performed while on	Functions performed when single-shot times out	Next clock time
56..... 55r.....	If s following e is not last letter, add 1 to #VGC (i.e. condition AND gate 972 (FIG. 5G)).		If #VGC has count of 2, go to step 210 (i.e. condition AND gate 1032 (FIG. 5I)).	CL-115 (i.e. step 210) or CL-52
57..... 56r.....	Decrement output-control ring 612 by 1 (i.e. apply a signal to line 618 (FIG. 5A)).		If #VGC has count of <2 and character following s is not a blank, switch on SS-52 (i.e. condition AND gate 974).	or CL-57.
58..... 57r.....	Decrement output-control ring 612 by 1 (i.e. apply a signal to line 618 (FIG. 5A)).		If #VGC has count of <2 and character following s is a blank, switch on SS-67 (i.e. condition AND gate 965).	
59..... 58r.....	Decrement output-control ring 612 by 1 (i.e. apply a signal to line 618 (FIG. 5A)).			CL-58.
60..... 59r.....	If character preceding e is a, c, g, h, s, or x, and 1 to #VGC (i.e. condition AND gate 1002 (FIG. 5G)).		If #VGC has count of 2, go to next step (i.e. condition AND gate 1050 (FIG. 5I)).	CL-115 (i.e. step 210) or end of operation (i.e. word not hyphenable (i.e. condition AND gate 1034)).
63..... 54r.....	Increment output-control ring 612 by 1 (i.e. apply signal to line 620 (FIG. 5A)).		If #VGC has count of <2, word is not hyphenable (i.e. condition AND gate 1034).	CL-60.
64..... 63r.....	If character not a blank, add one to #VGC (i.e. condition AND gate 976 (FIG. 5G)).		If #VGC is equal to two, go to step 210 (i.e. condition AND gate 1048 (FIG. 5I)).	CL-115 (i.e. step 210) or CL-52
65..... 64r.....	Decrement output-control ring 612 by 1 (i.e. apply signal to line 618 (FIG. 5A)).		If count in #VGC is less than two and character is not a blank, switch on SS-52 (i.e. condition AND gate 978 (FIG. 5G)).	or CL-65.
66..... 65r.....	Decrement output-control ring 612 by 1 (i.e. apply signal to line 618 (FIG. 5A)).		If count in #VGC is less than two and character is a blank, switch on SS-65 (i.e. condition AND gate 966).	CL-64.
67..... 66r.....	Decrement output-control ring 612 by 1 (i.e. apply signal to line 618 (FIG. 5A)).			CL-66.
68..... 67r.....	If character is a d or a t, add 1 to #VGC (i.e. condition AND gate 1006 (FIG. 5II)).		If count in #VGC is equal to two, go to step 210 (i.e. condition AND gate 1046 (FIG. 5I)).	CL-115 (i.e. step 210) or end of operation (i.e. word not hyphenable).
71..... 54r.....	Decrement output-control ring 612 by 1 (i.e. apply a signal to line 618 (FIG. 5A)).		If count in #VGC is less than two, word not hyphenable (i.e. condition AND gate 1036 (FIG. 5H)).	CL-67.
72..... 71r.....	Decrement output-control ring 612 by 1 (i.e. apply a signal to line 618 (FIG. 5A)).		If character is not an l, word is not hyphenable (i.e. condition AND gate 956 (FIG. 5J)).	CL-68.
73..... 72r.....	Decrement output-control ring 612 by one (i.e. apply signal to line 618 (FIG. 5A)).		If character is an l, switch on SS-73 (i.e. condition AND gate 980).	End of operation (i.e. word not hyphenable) or CL-73.
74..... 73r.....	If character is a stop character (i.e. b, d, g, j, k, p, or t) add 1 to #VGC (i.e. condition AND gate 1010 (FIG. 5J)).		If count in #VGC is less than two, word not hyphenable (i.e. condition AND gate 1032 (FIG. 5J)).	End of operation (i.e. word not hyphenable) or CL-115 (i.e. step 210).
75..... 52r.....	Add 1 to #VGC (i.e. apply a signal to OR gate 1024 (FIG. 5II)).		If count in #VGC equal to two, go to step 210 (i.e. condition AND gate 1044).	CL-76 or CL-115 (i.e. step 210).
76..... 75r.....	Increment output-control ring 612 by 1 (i.e. apply a signal to line 620 (FIG. 5A)).		If count in #VGC is less than two, switch on SS-76 (i.e. condition AND gate 1030 (FIG. 5J)).	CL-76 or CL-115 (i.e. step 210).
77..... 76r.....	Idle		If count in #VGC equal to two, switch on SS-115 (i.e. condition AND gate 1040 (FIG. 5I)).	CL-115 (i.e. step 210) or CL-51a.
78..... 52r.....	Decrement output-control ring 612 by 1 (i.e. apply a signal to line 618 (FIG. 5A)).		If character is not an a, switch on SS-51a (i.e. condition AND gate 932).	CL-115 (i.e. step 210) or CL-51a.
79..... 78r.....	If character is not a vowel, a y, or a blank, add 1 to #VGC (i.e. condition AND gate 988 (FIG. 5H)).		If count in #VGC equal to two, switch on SS-115 (i.e. condition AND gate 1040 (FIG. 5I)).	CL-115 (i.e. step 210) or CL-51a.
85..... 33r.....	Reset syllable registers, address registers, number-of-syllable registers, and ratio registers in word registers 488 (i.e. apply a signal to line 1861 (FIG. 5R)).		If count in #VGC less than two, switch on SS-51 (i.e. condition AND gate 1038 (FIG. 5H)).	CL-85a.
	Reset frequency registers 1601-160N (i.e. apply a signal to line 1600 (FIG. 5M)).			
	Reset word-select counter 528 to a count of 1 (i.e. apply a signal to line 1798 (FIG. 5P)).			

Single shot No.	Turn-on condition	Functions performed while on	Functions performed when single-shot times out	Next clock time
85a	85 _r or 105 _r	Transfer address in starting-point register 1208 to TAC 386 (i.e. apply a signal through line 1220 (FIG. 5D) to condition gates 1218). Reset column-select counter 508 to its first position (i.e. apply a signal to line 1530 (FIG. 5M)). Reset number-of-syllable counter 1670 to a count of 1 (i.e. apply a signal to line 1672 (FIG. 5M)). Reset intermediate store 1736 to a count of 0 (i.e. apply a signal to line 1758 (FIG. 5N).) Reset flip-flop 487 to its OFF state (i.e. apply signal to line 1424 (FIG. 5E)).	Switch SS-85b to its ON state.	CL-85b.
85b	85a _r	Increment TAC 386 by 1 (i.e. apply a signal to line 1228 (FIG. 5D)).	Switch SS-86 to its ON state.	CL-86.
86	85b _r or 87b _r or 88 _r	Transfer TAC 386 to MAR 372 and transfer MAR to PAR (i.e. apply a signal through line 1236 (FIG. 5D) to condition gates 1232, etc.). Set memory to read status (i.e. apply a signal to line 1308 (FIG. 5F) to switch memory-status flip-flop 1304 to its OFF state).	Switch SS-87 to its ON state.	CL-87.
87	86 _r or 88a _r	Perform memory cycle, read entry from core storage into MBR 368 (apply a signal to line 1302 (FIG. 5F)).	Switch on SS-87a.	CL-87a.
87a	87 _r	If used bit in MBR 368 is present, transfer MAR to TAC (i.e. apply a conditioning signal through line 1502 (FIG. 5D) to AND gate 1500). If used bit equals 0, switch SS-88 to its ON state (i.e. apply conditioning signal to AND gate 1494 (FIG. 5F)). If used bit equals 1, switch SS-87b to its ON state (i.e. apply conditioning signal to AND gate 1498).	If used bit equals 0, switch SS-88 to its ON state (i.e. apply conditioning signal to AND gate 1494 (FIG. 5F)). If used bit equals 1, switch SS-87b to its ON state (i.e. apply conditioning signal to AND gate 1498).	CL-88 or CL-87b.
87b	87a _r	Increment TAC 386 by 1 (i.e. apply a signal to line 1228 (FIG. 5D)).	Switch SS-86 to its ON state.	CL-86.
88	87a _r	Increment TAC 386 by 1 (i.e. apply a signal to line 1228 (FIG. 5D)). If chain address not 2 and not 0, switch SS-88a to its ON state (i.e. apply conditioning signal to line 1418 (FIG. 5E)). If chain-address field contains a 2, switch SS-89 to its ON state (i.e. apply conditioning signal to AND gate 1414)). If chain-address field contains a 0, and LTM field does not contain a mark, switch SS-88 to its ON state (i.e. apply conditioning signal to AND gate 1343). If chain-address field contains a 0 and there is a mark in the LTM field, switch SS-100 to its ON state (i.e. apply conditioning signal to AND gate 1429).	If chain address not 2 and not 0, switch SS-88a to its ON state (i.e. apply conditioning signal to line 1418 (FIG. 5E)). If chain-address field contains a 2, switch SS-89 to its ON state (i.e. apply conditioning signal to AND gate 1414)). If chain-address field contains a 0, and LTM field does not contain a mark, switch SS-88 to its ON state (i.e. apply conditioning signal to AND gate 1343). If chain-address field contains a 0 and there is a mark in the LTM field, switch SS-100 to its ON state (i.e. apply conditioning signal to AND gate 1429).	CL-88a or CL-89 or CL-86 or CL-100.
88a	88 _r	Step column-select counter 508 by 1 (i.e. apply signal to line 1532 (FIG. 5M)).	Switch SS-87 to its ON state.	CL-87.
89	88 _r	Form sum of frequencies in frequency registers 1601-160N (i.e. apply conditioning signal through line 1620 (FIG. 5M) to gates 1621-162N). Reset column-select counter 508 to first position (i.e. apply a signal to line 1530 (FIG. 5M)).	Switch SS-90 to its ON state.	CL-90.
90	89 _r	Transfer contents of adder 1640 to dividend input of divider 1700 and transfer contents of number-of-syllable counter 1670 to divisor input of divider 1700 (i.e. apply conditioning signal through line 1668 (FIG. 5M) to gates 1662 and 1664).	Switch SS-91 to its ON state.	CL-91.
91	90 _r or 94 _r	Transfer contents of divider 1700 to 1 input of subtractor 1718 and transfer contents of selected frequency register 1601-160N to other input of subtractor 1718 (i.e. apply conditioning signal through line 1712 (FIG. 5M) to gates 1704 and 1710).	Switch SS-92 to its ON state.	CL-92.
92	91 _r	Apply output of subtractor 1718 to squarer 1728 (i.e. apply conditioning signal through line 1724 (FIG. 5M) to gates 1722).	Switch SS-93 to its ON state.	CL-93.
93	92 _r	Apply contents of squarer 1728 to 1 input of adder 1746 and apply contents of intermediate store 1736 to other input of adder 1746 (i.e. apply conditioning signal through line 1740 (FIG. 5N) to gates 1732 and 1738). If counts applied to compare-circuit 1538 are not equal (i.e. if the count in column-select counter 508 is not equal to the count in number-of-syllable counter 1670) switch SS-94 to its ON state (i.e. apply a conditioning signal to AND gate 1668 (FIG. 5M)). If the counts applied to compare-circuit 1538 are equal, switch SS-95 to its ON state (i.e. apply a conditioning signal to AND gate 1684).	If counts applied to compare-circuit 1538 are not equal (i.e. if the count in column-select counter 508 is not equal to the count in number-of-syllable counter 1670) switch SS-94 to its ON state (i.e. apply a conditioning signal to AND gate 1668 (FIG. 5M)). If the counts applied to compare-circuit 1538 are equal, switch SS-95 to its ON state (i.e. apply a conditioning signal to AND gate 1684).	CL-94 or CL-95.
94	93 _r	Transfer contents of adder 1746 to intermediate store 1736 (i.e. apply conditioning signal through line 1754 (FIG. 5N) to gates 1750). Set column-select counter 508 by 1 (i.e. apply signal to line 1532 (FIG. 5M)).	Switch SS-91 to its ON state.	CL-91.

Single shot No.	Turn-on condition	Functions performed while on	Functions performed when single-shot times out	Next clock time
95.....	93 τ	Transfer contents of adder 1746 to dividend input of divider 1766 and transfer contents of number-of-syllable counter 1670 to divisor input of divider 1766 (i.e. apply conditioning signal through line 1760 (FIG. 5N) to gates 1752 and 1680).	Switch SS-96 to its ON state.....	CL-96.
96.....	95 τ	Transfer contents of divider 1766 to square rooter 1776 (i.e. apply conditioning signal through line 1772 (FIG. 5N) to gates 1770).	Switch SS-97 to its ON state.....	CL-97.
97.....	96 τ	Transfer contents of square rooter 1776 to divisor input of divider 1788. Transfer contents of divider 1790 to dividend input of divider 1788 (i.e. apply conditioning signal through line 1782 (FIG. 5N) to gates 1780 and 1706).	Switch SS-98 to its ON state.....	CL-98.
98.....	97 τ	Transfer contents of divider 1788 to ratio register of selected word in word register 488 (i.e. apply conditioning signal through line 1794 (FIG. 5N) to gates 1792). Transfer contents of number-of-syllable counter 1670 to number-of-syllable register of selected word in word register 488 (i.e. apply conditioning signal through line 1850 (FIG. 5N) to gates 1678).	Switch SS-99 to its ON state.....	CL-99.
99.....	98 τ	Reset frequency registers 1601-160N (i.e. apply signal to line 1600 (FIG. 5M)).	Switch SS-100 to its ON state.....	CL-100.
100.....	99 τ or 103 τ	Decrement column-select counter 508 by 1 (i.e. apply signal to line 1534 (FIG. 5M)).	If column-select counter not equal to 0, switch SS-101 to its ON state (i.e. apply conditioning signal to AND gate 1548 (FIG. 5M)). If column-select counter has count of 0, switch SS-107 to its ON state (i.e. apply conditioning signal to AND gate 1546).	CL-101 or CL-107.
101.....	100 τ	Transfer contents of selected-address register in word registers 488 to MAR 372 (i.e. apply conditioning signal through line 1968 (FIG. 5T) to gates 1468). Transfer contents of MAR to PAR (i.e. apply signal to line 1446 (FIG. 5D)). Set memory to read status (i.e. apply signal through line 1308 (FIG. 5F) to switch memory-status flip-flop 1304 to its OFF state).	Switch SS-102 to its ON state.....	CL-102.
102.....	101 τ	Do a memory read cycle (i.e. apply a signal to line 1302 (FIG. 5F)).	Switch SS-103 to its ON state.....	CL-103.
103.....	102 τ	Set memory to write status (i.e. apply a signal through line 1306 (FIG. 5F) to switch memory-status flip-flop 1304 to its ON state). Put 1 in used field of MBR 368 (i.e. apply conditioning signal through line 1488 (FIG. 5F) to gates 1482).	If LTM field in MBR contains a mark, switch SS-100 to its ON state (i.e. apply a conditioning signal to AND gate 1344 (FIG. 5F)). If LTM field does not contain a mark, switch SS-104 to its ON state (i.e. apply a conditioning signal to AND gate 1346).	CL-100 or CL-104.
104.....	103 τ	Do a memory write cycle (i.e. apply a signal to line 1302 (FIG. 5F)).	If flip-flop 487 is in its OFF state, switch SS-105 to its ON state (i.e. apply conditioning signal to AND gate 1435 (FIG. 5E)). If flip-flop 487 is in its ON state, switch SS-85a to its ON state (i.e. apply conditioning signal to AND gate 1431).	CL-105 or CL-85a.
105.....	104 τ	Increment word-select counter 528 by 1 (i.e. apply a signal to line 1800 (FIG. 5P)).	Switch SS-85a to its ON state.....	CL-85a.
107.....	100 τ	Reset word-select counter 528 to its first position (i.e. apply a signal to line 1798 (FIG. 5P)). Set preferred-word register 544 to 1 (i.e. apply a signal to line 2022 (FIG. 5P)). Set first-time-through flip-flop 535 to its ON state (i.e. apply a signal to line 2004).	Switch SS-108 to its ON state.....	CL-108.
108.....	107 τ or 111 τ	If selected ratio field is blank, transfer contents of syllable registers of preferred word to coded-word-hyphenation registers 1911-191N or coded-word-hyphenation registers 564 (i.e. apply a conditioning signal through line 2008 (FIG. 5P) to AND gate 1986).	If the contents of the selected-ratio field are greater than 1 and first-time-through flip-flop 535 is in its OFF state, switch SS-109 to its ON state (i.e. apply a conditioning signal to line 1996). If the ratio in the selected-ratio register is greater than 1 and first-time-through flip-flop 535 is in its ON state, switch SS-110 to its ON state (i.e. apply a conditioning signal to line 1996). If the ratio in the selected-ratio field is equal to or less than 1 but is not a blank, switch SS-111 to its ON state (i.e. apply a conditioning signal to AND gate 1982). If the selected-ratio register contains a blank, switch SS-120 to its ON state (i.e. apply a conditioning signal to AND gate 1988).	CL-109 or CL-110 or CL-111 or CL-120.
109.....	108 τ	Apply contents of number-of-syllable register of word indicated in preferred-word register and of word indicated in word-select counter to compare-circuit 1880 (i.e. apply a conditioning signal through line 2034 (FIG. 5P) to AND gates 2026 and 2030).	If word in word-select register has less syllables, switch SS-110 to its ON state (i.e. apply conditioning signal to AND gate 1892 (FIG. 5P)). If word indicated by preferred-word register has fewer syllables, switch SS-111 to its ON state (i.e. apply conditioning signals to AND gate 1884). If words applied to compare-register 1880 have same number of syllables, switch SS-112 to its ON state (i.e. apply conditioning signal to AND gate 1888).	CL-110 or CL-111 or CL-112.

Single shot No.	Turn-on condition	Functions performed while on	Functions performed when single-shot times out	Next clock time
110	108 _r or 109 _r or 112 _r	Switch first-time-through flip-flop 535 to its OFF state (i.e. apply a signal to line 2002 (FIG. 5P)). Transfer contents of word-select counter 528 to preferred-word register 544 (i.e. apply conditioning signal through line 2020 (FIG. 5P) to gates 2018).	Switch SS-111 to its ON state.	CL-111.
111	108 _r or 109 _r or 110 _r or 112 _r	Increment word-select counter 528 by 1 (i.e. apply a signal to line 1800 (FIG. 5P)).	Switch SS-108 to its ON state.	CL-108.
112	109 _r	Transfer contents of ratio register of word indicated by preferred-word register to 1 input of compare-circuit 2058 and transfer contents in ratio field of word indicated by word-select counter to other input of compare-circuit 2058 (i.e. apply conditioning signal through line 2036 (FIG. 5P) to AND gates 2028 and 2032).	If ratio for word indicated by word-select counter is greater, switch SS-110 to its ON state (i.e. apply a conditioning signal to AND gate 2062 (FIG. 5Q)). If ratio of word indicated by preferred-word register is greater, switch SS-111 to its ON state (i.e. apply a conditioning signal to AND gate 2066).	CL-110 or CL-111
115	A signal on output line 326 from OR gate 1142 (i.e. 52 _r or 54 _r or 56 _r or 60 _r or 64 _r or 68 _r or 74 _r or 75 _r or 77 _r or 79 _r).	Transfer contents of input-buffer register 302 into argument register 340 (i.e. condition AND gates 660 (FIG. 5A)). Set match indicators in associative memory 338 to match side (i.e. apply a signal to line 668). Set flip-flop 670 to its OFF side (apply signal to line 668 (FIG. 5A)).	Switch SS-116 to its ON state.	CL-116.
116	115 _r	Perform association between contents of argument register 340 and contents of portion 341 of associative memory 338 (i.e. apply a signal to line 668 (FIG. 5A)).	Switch on SS-117.	CL-117.
117	116 _r	Test contents of match indicators in associative memory 338 (i.e. apply signal to line 672 (FIG. 5A)) and store proper hyphenation pattern in output register 346 (FIG. 5Z) after a match is found. If a match is not found, switch flip-flop 670 to its ON state.	If match found, signal end of operation (i.e. condition AND gate 350 (FIG. 5A)). If match not found, switch on SS-0 (i.e. condition AND gate 354).	End of operation (i.e. proper hyphenation pattern) or CL-0 (i.e. step 212).
120	108 _r	Reset output-control ring 612 to its first position (i.e. apply a signal to line 616 (FIG. 5A)). Reset group-control ring 2070 to its first position (i.e. apply a signal to line 2074 (FIG. 5K)). Reset unit-control ring 2072 to its first position (i.e. apply a signal to line 2076 (FIG. 5K)). Reset input-control ring 2188 to its first position (i.e. apply a signal to line 2190 (FIG. 5L)).	Switch SS-121 to its ON state.	CL-121.
121	120 _r or 121 _r or 126 _r or 128 _r	If selected character is not a blank, transfer selected character in input-buffer register into selected position of output register 346 (i.e. apply a conditioning signal to AND gate 2150 (FIG. 5L) causing an output signal on line 574 to condition gates 634). If selected character in coded-word-hyphenation register is blank and character is not first character of a syllable, transfer hyphen from hyphenation generator 572 to selected position of output register 346 (i.e. condition AND gate 2108 (FIG. 5L) to generate an output signal on line 578 which conditions gates 2168).	If selected character is not a blank and unit-control ring is not in its sixth position, switch SS-122 to its ON state (i.e. apply a conditioning signal to AND gate 2116 (FIG. 5L)). If selected character is not a blank and unit-control ring is in its sixth position, switch SS-124 to its ON state (i.e. apply a conditioning signal to AND gate 2110). If selected character is a blank and unit-control ring is not in its first position, switch SS-128 to its ON state (i.e. apply a conditioning signal to AND gate 2106). If selected character is a blank and unit-control ring is in its first position, switch SS-129 to its ON state (i.e. apply conditioning signal to AND gate 2100).	CL-122 or CL-124 or CL-128 or CL-129.
122	121 _r	Increment output-control ring 612 by 1 (i.e. apply a signal to line 620 (FIG. 5A)). Increment input-control ring 2188 by 1 (i.e. apply a signal to line 2192 (FIG. 5L)). Increment unit-control ring 2072 by 1 (i.e. apply a signal to line 2080 (FIG. 5K)).	Switch SS-121 to its ON state.	CL-121.
124	121 _r	Increment input-control ring 2188 by 1 (i.e. apply a signal to line 2192 (FIG. 5L)). Increment group-control ring 2070 by 1 (i.e. apply a signal to line 2078 (FIG. 5K)).	Switch SS-125 to its ON state.	CL-125.
125	124 _r	Gate hyphen character into selected position of output register 2188 (i.e. apply conditioning signal through line 580 (FIG. 5K) and OR gate 2164 to gates 2168).	Switch SS-126 to its ON state.	CL-126.
126	125 _r	Increment output-control ring 612 to 1 (i.e. apply a signal to line 620 (FIG. 5A)). Increment input-control ring 2188 by 1 (i.e. apply a signal to line 2192 (FIG. 5L)). Reset unit-control ring to first position (i.e. apply a signal to line 2076 (FIG. 5K)).	Switch SS-121 to its ON state.	CL-121.
128	121 _r	Increment input-control ring 2188 by 1 (i.e. apply a signal to line 2192 (FIG. 5L)). Increment group-control ring 2070 by 1 (i.e. apply a signal to line 2078 (FIG. 5K)). Reset unit-control ring 2072 to its first position (i.e. apply a signal to line 2076 (FIG. 5K)).	Switch SS-121 to its ON state.	CL-121.
129	121 _r	Decrement input-control ring 2188 by 1 (i.e. apply a signal to line 2194 (FIG. 5L)).	Switch SS-130 to its ON state.	CL-130.
130	129 _r	Transfer blank from generator 2182 to selected position in output register 346 (i.e. apply conditioning signal through line 2184 (FIG. 5L) to gates 2178).	Signal end of operation.	End of operation.

What is claimed is:

1. Text composing apparatus for automatically hyphenating a word comprising the combination of:
  - means for storing an input word;
  - means for storing a table denoting the relative frequencies with which hyphens occur with respect to characters that constitute or represent letters in a representative large quantity of known words having known occurrence frequencies;
  - means operable under the control of said input word storing means and said table storing means for making a letter-by-letter analysis of at least a selected portion of the input word to determine which ones, if any, of all the stored hyphen and character patterns are of possible application to the input word;
  - means operable under the control of said analyzing means for ascertaining which, if any, of the possible hyphen and character patterns represents the most probable hyphenation of the word or selected portion thereof being considered; and
  - means under control of said ascertaining means for manifesting a particular hyphenation of the word in accordance with said most probable hyphen and character pattern.
2. Text composing apparatus for automatically hyphenating a word comprising the combination of:
  - means for storing an input word;
  - means for converting the stored input word to a reduced character set;
  - means for storing the reduced character set;
  - means under control of said reduced character set storing means for determining the most probable syllable pattern for the word as represented by the reduced character set; and
  - means under control of said syllable pattern determining means for manifesting a particular hyphenation of the word in accordance with said most probable syllable pattern.
3. A method of operating a data processing system having data storage means and data manifesting means for automatically hyphenating a word, said method comprising the steps of:
  - operating a portion of said storage means as a reference table for denoting the relative frequencies with which hyphens occur with respect to characters that constitute or represent letters in a representative large quantity of known words having known occurrence frequencies;
  - operating said system under the control of said reference table to determine from a letter-by-letter analysis of at least a selected portion of an input word which ones, if any, of all the hyphen and character patterns stored in said reference table are of possible application to such input word;

operating a portion of said storage means as a pattern table for storing the possible hyphen and character patterns thus determined;

further operating said system in response to the data stored in said pattern table to determine which one, if any, of the possible hyphen and character patterns represents the most probable hyphenation of the word or selected portion thereof being considered; and

operating said manifesting means to manifest a particular hyphenation of the word in accordance with said most probable hyphen and character pattern.

4. A method of operating a data processing system having data storage means and data manifesting means for automatically hyphenating a word, said method comprising the steps of:

- operating said system in accordance with a predetermined character conversion algorithm for converting the word to a reduced character set in which only certain characters are utilized to represent the letters of the actual word;
- operating a portion of said storage means as a reference table for denoting the relative frequencies with which syllables represented by said characters occur in a representative large quantity of known words having known occurrence frequencies;
- operating said system under the control of said reference table to determine all possible syllable patterns utilizing characters in the reduced character set for said word;
- operating a portion of said storage means as a pattern table for storing the possible syllable patterns determined;
- further operating said system in response to the data stored in said pattern table to determine which one, if any, of the possible syllable patterns represents the most probable hyphenation of the word; and
- operating said manifesting means to manifest said most probable hyphenation of the word.
